UNITED STATES PATENT OFFICE

EDWARD S. PETERSON, OF CHICAGO, ILLINOIS, ASSIGNOR, BY MESNE ASSIGNMENTS, TO
ASSOCIATED ELECTRIC LABORATORIES, INC., OF CHICAGO, ILLINOIS, A CORPORA-
TION OF DELAWARE

TELEPHONE SYSTEM

Application filed January 5, 1931. Serial No. 506,557.

The present invention relates to telephone systems in general, but is concerned more particularly with telephone systems wherein automatic switches are operated under the control of an operator to set up the connections desired by calling subscribers.

The system disclosed herein may be considered an improvement over the systems disclosed in the following patents and applications:

- 10 Patent 1,752,543, granted April 1, 1930 to Ruggles.
- 15 Patent 1,760,640, granted May 27, 1930 to Gohorel.
- 20 Patent 1,776,570, granted Sept. 23, 1930 to Ruggles.
- 25 Application S. N. 237,140, filed Dec. 2, 1927 by Ruggles.
- 30 Application S. N. 270,198, filed Apr. 16, 1928 by Saunders et al.
- 35 Application S. N. 297,631, filed Aug. 6, 1928 by Peterson et al.

General description

40 An object of the present invention is the production of new and improved circuit arrangements whereby a part of the lines entering an exchange may be local-battery, semi-automatic lines from which outgoing connections are set up through automatic switches under the control of an operator, while the remaining lines may be regular common-battery automatic lines from which the automatic switches are directly controlled to set up desired connections. Arrangements are provided for giving standard reverse-current supervision when calls are made to local-battery lines, as well as when calls are made to common-battery automatic lines, thus providing for the correct operation in case calls are from operator's switchboards (private branch operator's switchboards, for example) and providing also for the operation of meters, or message registers, in case it is desired to give metered service.

Amongst the various specific features of the present invention, the following are listed as being more or less outstanding.

- 50 1. In order to relieve those subscribers

who are willing to pay a higher rental of the necessity of operating a hand generator to signal the operator and to later release the connection, it is proposed to equip certain telephones with an individual line battery consisting of two or three dry cells, and to revise the circuit of the substation so that the regular local transmitter battery will be in series with the additional battery of dry cells for impressing a potential across the conductors of the line as long as the receiver is removed. The resulting current-flow takes the place of the ringing current generated by the hand generator, as will be hereinafter described.

2. In order to maintain the line relay of a calling line switch operated and to thereby maintain the operating chain circuit open so as to avoid the so-called double plunging of line switches, a locking circuit for any operated line relay is maintained closed until the master-switch operation has been started as a result of the seizure of the trunk line by the operated line switch, whereupon the locking circuit is opened to release the line relay of the operated line switch.

This feature may be applied to plunger line switches generally, as it obviates the use of a copper collar or copper slug on the armature end of the line relay.

3. In order that a calling subscriber shall know whether or not the operation of his hand generator to signal the operator has been effective in starting the apparatus in the central exchange to bring the operator's attention to the call, arrangements are made for sending back a special tone to the calling line from the time the lineswitch operates until the calling subscriber is placed in communication with the operator. This is of special value on account of the fact that a party-line subscriber may finish a conversation and forget to operate his hand generator to cause the connection to be released. In this case the application of ringing current made by the next subscriber on the party line, may result merely in the release of the previous connection and not in the signalling of the operator. With the improved arrangement just mentioned, a sub-

80

85

90

95

100

scriber does not hear the "operator" tone on the line in such a case and he is expected to "ring" again so as to cause his lineswitch to operate.

4. In order to provide a simpler and more reliable arrangement for signalling the called semi-automatic subscriber than has been used heretofore in connection with rural semi-automatic lines, the connectors having access to these lines have been arranged so that the application of coded ringing current is repeated periodically until the called subscriber responds, instead of the previous practice of sending out the coded ringing current following a prolonged attention ring and then terminating the ringing operation independent of the removal of the receiver at the called substation. The present arrangement has not been employed heretofore owing to the fact that it necessitates the application of a current source to the called line from the exchange, so that a current flow will be brought about by the removal of the receiver at the called substation when a direct-current bridge is placed across the line, there being a condenser in series with each of the ringers. It has been considered heretofore that the uncertain state of repair and the consequent poor insulation of many of the rural lines makes this operation impractical. It has been determined, however, by experimentation that this method of operation is satisfactory as long as the source of direct current is not applied during the ringing period. The ring-cut-off relay of the connector used to call a semi-automatic line then does not have to resist the combined flow of alternating current and direct current through a leaky line prior to the removal of the receiver. The common ringing apparatus has accordingly been revised so that the source of direct current for operating the ring-cut-off relay responsive to the removal of the receiver at the called substation is applied only during the silent period. With this provision, the ring-cut-off relay of the connector may be adjusted so that it will not operate until the receiver is removed at the called substation if the line is in good condition and will operate prior to the removal of the receiver only if the line is in such poor condition that conversation over the line is practically impossible.

5. Since the connectors used to complete connections to semi-automatic lines are provided with ring-cut-off relays, these connectors may be used to give answering supervision by reversing the current flow over the incoming conductors, thus enabling answering supervision to be given to the calling operators and enabling measured service to be given to lines by means of message registers or call meters, if so desired. In addition, arrangements are provided for again reversing the current flow when the called

subscriber "rings off" in case the connection is to another semi-automatic line.

6. When a semi-automatic party-line subscriber desires to call another subscriber on the same line, and the operator causes the selector repeater in use to extend a connection to a ring-back switch which is then set for the proper signalling of the called subscriber on the calling line, the ring-off relay in the selector repeater is disconnected so as to prevent the release of the connection responsive to the ringing current coming back from the ring-back switch. In order to bring the release of the connection again under the control of the calling line, the ringing circuit is automatically opened and the ring-off relay is again connected up by a timing device after an interval of one minute, as by this time the calling subscriber will have taken note of his code of ringing current if he is within hearing distance of his telephone.

7. The sending device employed in the register senders of the system disclosed herein is arranged so that the interval between successive digits is governed by a group of counting relays which count off a definite number of impulses from the impulse generator of the sender, instead of depending upon the releasing time of slow-acting relays as in the case of most previous senders.

8. Owing to the fact that the semi-automatic lines have local-battery substantions thereon and are not supplied with talking current from the central exchange, it has not been found practical to use the same toll train for use in completing connections to semi-automatic lines as is used in completing connections to the common-battery automatic lines. This is largely due to the arrangement in the standard toll train wherein a toll transmission selector, preceding the toll connector, is used to supply talking current to the called line and to give answering and disconnect supervision to the toll operator. Accordingly, a toll connector has been designed especially for use in completing connections to semi-automatic local-battery lines and has been arranged to give the operator the same type of supervision she receives when using the standard toll train, or as nearly so as is practical.

Description of drawings

Other objects and features of the invention are concerned with the provision of suitable circuit arrangements for enabling complete and satisfactory telephone service to be given in a system including a mixed-service exchange of the above type, and will be understood best upon a further perusal of the specification in connection with the accompanying drawings, comprising Figs. 1 to 15. Of these drawings, Fig. 1 is a trunking diagram of the system used to illustrate

the invention; Figs. 2 to 14 show by means of the usual circuit diagrams a sufficient amount of the apparatus involved in the system of Fig. 1 to enable the invention to be understood; and Fig. 15 is a layout drawing showing how the sheets on which Figs. 2 to 14 are drawn should be assembled together in order to be understood best.

10 *Description of trunking layout, Fig. 1*

Referring now particularly to Fig. 1, two exchanges, EX-1 and EX-2, are shown. The exchange EX-1 is a remotely-controlled semi-automatic magneto exchange, the control over the switching apparatus therein being exercised through the medium of the operating trunks OT1 and OT2 by operators located in the exchange EX-2.

20 The exchange EX-2 is a combination exchange. It is assumed that there are at present in the neighborhood of two thousand common-battery automatic lines served by the exchange EX-2, of which the lines of substation A7 and A8 are shown; and that 25 there are about one hundred semi-automatic magneto lines, of which the lines of substations A4, A5, and A6 are shown. In the exchange EX-1, there are assumed to be about 200 lines of which the lines of substations 30 A1, A2, and A3 are shown.

Local calls in exchange EX-2

Referring now particularly to the exchange EX-2, the way in which calls are completed therein will be explained generally. Assume first that the subscriber at substation A7, whose number is 3280, desires to call the subscriber at substation A8, whose number is 4450.

Call from automatic substation A7 to automatic substation A8

45 When the subscriber at substation A7 removes his receiver, the lineswitch LS6 operates in the usual manner responsive to the current flow over the two conductors of his line in series, and selects a regular two-wire first selector FS. This selector, it may be stated, operates as a thousand selector when a call is being made through it to any one of the common-battery lines.

The calling subscriber at substation A7 now operates his calling device in accordance with the first digit 4 in the desired number, whereupon the wipers (not shown) of the selector FS are raised step by step and come to rest opposite the fourth level of bank contacts, and are then rotated over 60 the bank contacts in the fourth level in search of an idle trunk line. It will be assumed that the first trunk found to be idle is the one extending to the hundreds selector or second selector SS2.

65 Having been selected in response to the

dialling of the first digit 4, the second selector SS2 is prepared for operation in the usual manner, and it responds to the dialling of the second digit 4 by raising its wiper opposite the fourth level of bank contacts and selecting an idle trunk extending to a connector in the fourth hundreds group of the fourth thousands group, the local connector LC5, for example.

Having been selected responsive to the dialling of the first two digits 4 and 4 in the desired number, the local connector LC5 responds to the last two digits 5 and 0, by raising its wipers opposite the fifth level of bank contacts and by rotating them over the bank contacts in the fifth level, until they come to rest on the tenth set of these bank contacts, thus connecting with the line of substation A8. The usual busy test is made, and if the line is found to be idle, ringing current is applied in the usual manner, and the subscriber at substation A8 is thereby signalled that he is desired in conversation.

When the subscriber at substation A8 responds to the ringing of his bell by removing his receiver (not shown), the local connector LC5 reverses the direction of current flow in the trunk line incoming thereto for the purpose of operating a message register or meter at the calling substation in case the calling substation is so equipped, or for the purpose of giving supervision to an operator in case one is calling, or for similar purposes.

The two subscribers may thereupon carry on their conversation, and when it is completed they both replace their receivers. As in most standard automatic systems, the two selectors FS and SS2 release responsive to the receiver being replaced at the calling substation A7, but the connector LC5 does not release responsive to the replacement of the receiver at the calling substation in case the called subscriber has not replaced his receiver. The connector LS5 is accordingly not released until the receiver has been replaced at both substations.

Call from automatic substation A8 to automatic substation A7

In case the subscriber at substation A8 desires to call the subscriber at substation A7, whose number is 3280, the removal of the receiver at substation A8 results in the operation of the lineswitch LS5 to seize a first selector, such as the selector FS, following which the connection is set up in the manner described above, except that the calling subscriber in this case dials the digits 3, 2, 8, and 0. The connection may take the path shown through the second selector SS1 and the connector LC4.

*Selector repeaters multipled with first
selectors*

In order that the semi-automatic subscribers may be connected with any desired one of the automatic lines, the selector repeater SR2, which is one of a group provided to handle calls from the semi-automatic lines, has all of its levels with the exception of the ninth and tenth multiplied with the corresponding levels of the first selector FS. The selector repeater SR2 is so arranged that the impulses delivered thereto after it has been set are repeated to the selectors and connectors such as FS1 and FS2 and LC4 and LC5 to operate them in the same manner as when the subscriber at substation A7, or the subscriber at substation A8, is calling. Accordingly, the selector repeaters, such as SR2, and the first selector, such as FS, have common access on the second level to the group of connectors represented by the local connector LC3, which have access to the 100-line group of semi-automatic magneto lines.

Call from semi-automatic substation A6 to semi-automatic substation A4

The way in which the subscriber at substation A6, whose number is 2751, sets up a connection to the party-line subscriber at substation A4 whose number is 2322, will now be described. When the subscriber at substation A6 desires to make a call, he removes the receiver at his telephone in order to signal the operator, as in regular manual practice. When this occurs, the line switch LS3, actuated by current from the local battery at the calling telephone, responds by extending the calling line to an idle selector repeater, such as SR2. When the selector repeater SR2 is seized, a finder, such as the finder F3, is started to connect a sender, such as the sender SE1, to the selector repeater SR2. Also, the operator's finder F4 operates to associate the operator's telephone OT1 with the sender SE1. When this connection is completed, the operator converses with the calling subscriber and ascertains the desired number 2322. Upon doing this, the operator sets up the digits of the desired number on the registering apparatus of the register sender in use, following which the register sender sends out the digits of the number and then initiates the release of the finder F3.

When the first digit 3 is sent out, the selector repeater SR2 operates to raise its wipers (not shown) opposite the second level of bank contacts, and thereupon selects an idle connector, such as the local connector LC3. When the connector LC3 is seized, it is prepared for operation in the same way as any regular two-wire connector, and it responds to the next two digits 3 and 2 in

the desired number to raise its wipers opposite the third level of bank contacts and to rotate them into engagement with the second set of bank contacts in the third level. The fourth and last digit 2, the party-selecting digit, is responded to by a party selector which selects the ringing code corresponding to the digit 2, following which the selected code is intermittently transmitted over the called line.

When the subscriber at substation A4 responds to the ringing of his bell by removing his receiver, a direct current momentarily flows over his line and causes the cessation of the ringing operation and the completion of the talking connection. The current flow in the incoming conductors of the connector LC3 are reversed in the same manner as when a regular automatic subscriber responds to the signalling of his line by a connector such as the connector LC4. The two subscribers may now converse with each other in the usual manner.

Upon the termination of the conversation, the two subscribers replace their receivers, whereupon the connection releases responsive to the cessation of current flow from the local battery at the calling telephone.

The called subscriber is expected to "ring off" when he hangs up. In case he does this before the calling subscriber hangs up, the connector LC3 responds by reversing the direction of current flow in its incoming conductors back to normal, causing the selector repeater SR2 to release and open the connection to the connector LC3 and permits its release.

Call from automatic substation A7 to semi-automatic substation A4

In case a connection is desired from an automatic line, such as the line of substation A7, to a semi-automatic line, such as the line of substation A6, the connection may be completed by way of the first selector FS and the connector LC3, and the current flow is reversed back to the calling line by the connector LC3 when the called subscriber at substation A4 responds, as is the case when the line at substation A7 is connected to a called automatic line. In case the called semi-automatic subscriber "rings off" before the calling subscriber hangs up his receiver, the reversal of the direction of current flow in the calling line back to normal, effected by the connector LC3, does not result in the release of the connection, but the connection remains established until the calling subscriber replaces his receiver, whereupon the switches FS and LC3 are both released.

Call from semi-automatic substation A6 to automatic substation A7

When a call is made from a semi-auto-

matic line, such as the line of substation A6, to an automatic line, such as the line of substation A7, the connection may include the switches SR2, SS1, and LC4. In this case, the switches SR2, and SS1 are released in case the calling subscriber at substation A6 "rings off" while the receiver is still off at substation A7, leaving the connector LC4 operated under the control of the called line. On the other hand, if the subscriber at substation A7 replaces his receiver before the calling subscriber at substation A6 "rings off", the selector repeater SR2 is released responsive to the reversal of current flow in its back bridge back to normal, whereupon the switches SS1 and LC4 are both released.

Local calls in exchange EX-1

20 In the exchange EX-1, local calls are completed in the following manner: Assuming that the subscriber at substation A1, whose number is 3681, desires to call the subscriber at substation A3, whose number is 4581; the application of ringing current to the calling line by the usual operation of the hand generator at substation A1 results in the operation of the lineswitch LS2 to seize an idle selector repeater such as SR1. When the repeater SR1 is seized, a finder, such as F1, is started and it makes connection with the selector repeater SR1. Also, a control is exercised over the operating trunk OT1 to cause a finder such as F3 to connect a sender to the operating trunk OT1, and the operator's finder F4 connects the operator's telephone OT to the sender.

40 The operator now converses with the calling subscriber at substation A1 and ascertains the desired number 4581. This number is set up by the operator on the register sender in use, whereupon the digits, 4, 5, 8, and 1, of the number are transmitted over the operating trunk OT1 to set the necessary switches in the exchange EX-1 after which the finders F1 and F3 used in completing the controlling connection to the sender are released.

50 Responsive to the first digit 4, the selector repeater SR1 raises its wipers opposite the fourth level and rotates them in search of an idle trunk line. Assuming that the trunk line leading to the local connector LC2 in the fourth hundreds group is the first one found to be idle, the connector LC2 is seized and is prepared for operation.

55 Responsive to the second and third digits 5 and 8, the local connector LC2 raises its wipers opposite the 5th level of bank contacts and rotates them into engagement with the eighth set of contacts in this level. The fourth and last digit 1 conditions the associated apparatus to signal the called line in accordance with the first of the ten codes, the first of the ten party-line codes being used

to signal individual lines such as the line of substation A3. If the line is idle, the application of ringing current is made intermittently to the called line until the subscriber responds.

70 The release of the connection occurs when either subscriber "rings off". If the subscriber at substation A3 is calling the subscriber at substation A2, whose number is 3687, the completed connection may include the line switch LS1, the selector repeater SR1 (raised to the third level), and the local connector LC1 (set on the eighth set of bank contacts in the sixth level). The application of ringing current to the called line is 75 in accordance with the fourth and last digit 7, the seventh of the ten codes being used to signal the subscriber at substation A2.

80 Two operating trunks OT1 and OT2 are provided because the amount of traffic originated by two hundred lines is ordinarily more than can be satisfactorily handled over one operating trunk.

Handling reverting calls

85 In the exchange EX-1, it will be noted that the ring-back switch RBS-1 is accessible to the selector repeater SR1 by way of the ninth level. When a party-line subscriber desires to converse with another subscriber on the same line, he signals the operator in the usual manner, who ascertains the destination of the call and then causes the connection to be extended by the selector repeater to a ring-back switch such as RBS-1. The ring-back switch is set to send the code of the desired subscriber back over the calling line. The calling subscriber hangs up as soon as he finishes conversing with the operator, and he waits until his bell sounds the called party's code. The ringing circuit is automatically opened when either of the two subscribers removes his receiver.

90 A similar arrangement is employed in the second exchange, involving ring-back switches such as RBS-2.

Interchange calls (toll calls)

100 Toll connections to and from the regular common-battery lines of exchange EX-2 are handled through the toll board shown in the lower right-hand corner of Fig. 1 by means of regular standard toll-service equipment (not shown). Special toll-service trunk equipment and toll-recording equipment is provided for handling all toll calls involving any semi-automatic lines of either exchange. In case a subscriber desires to converse with a subscriber other than one in his own exchange, it is necessary for him to get into communication with the toll-recording operator who directly completes the toll connection; or passes the information over to the regular toll operator for her use 105 in later completing the connection, in case 110

the connection cannot be set up while the calling subscriber waits on the line.

- 5 A subscriber of exchange EX-1, desiring a toll connection, signals the operator in the manner described, and asks for "long distance". The regular traffic operator at the telephone OT of Fig. 1 sets up the digit 0 on the register sender, causing the selector repeater SR1 of Fig. 1 to be raised to the 10 tenth level. This extends the connection to an idle toll trunk such as the toll trunk TT. It may happen in some installations that one toll trunk will be sufficient, but in most cases two or more toll trunks such as TT 15 will have to be provided. Connection to the toll trunk TT from the tenth level of the selector repeater SR1 is made by way of the ringing repeater RR which automatically makes a momentary application of ringing 20 current to the toll trunk TT upon seizure in order to signal the operator through the medium of the trunk circuit TR3. The operator responds by plugging into the jack J3 by means of her cord circuit (not shown). 25 The operator then completes the toll connection or records the request for such connection, according to circumstances.
- In order to complete a toll connection to one of the lines of exchange EX-1, the line 30 of substation A3, for example, either the toll operator or the toll-recording operator may plug into the jack J3 or into one of its multiples and complete a connection with the toll trunk TT by way of the trunk circuit 35 TR3. By this operation, the toll selector TS, which is a regular two-wire selector, is prepared for operation in the usual manner. The calling operator then dials the four digits 4, 5, 8, and 1 of the number. The toll 40 selector TS responds by raising its wipers to the fourth level and seizing an idle toll connector such as TC2, one or more being provided for each hundred-line group, depending upon conditions. The toll connector TC2 responds to the second and third 45 digits 5 and 8 by making connection with the line of substation A3, and is conditioned for the proper signalling of the substation by the final digit 1.
- 50 The toll connector TC2 is arranged to give supervision to the calling operator comparable to that given when the operator is using a standard toll train to call a regular two-wire automatic line.
- 55 It will be noted that the toll connector TC1 has its banks connected in multiple with the local connector LC1 in order to provide for the completion of toll calls to the third hundreds group.
- 60 Regarding the handling of toll calls involving the semi-automatic lines of exchange EX-2, it will be noted that the trunk lines leading from the tenth level of the selector repeater SR2 extends to the toll board by 65 way of trunk circuits, such as TR1; and that

the toll connector TC3, similar to the toll connectors TC1 and TC2, is accessible by way of the toll board through the jack J2 and the trunk circuit TR1.

General description of Figs. 2-14

Referring now to the circuit drawings, Figs. 2 to 14, these drawings will be explained a little further. As mentioned hereinbefore, the sheets on which these drawings are made should be assembled in the manner indicated in Fig. 15, drawn on the same sheet with Fig. 9. When the drawings are thus assembled, Figs. 2, 3, and 4 show the switching equipment necessary for setting up connections in exchange EX-2 from either of the two semi-automatic lines of Fig. 2 to the other, or from either of these lines to any other semi-automatic line in the same exchange. The line of substation A6, Fig. 2, terminates at the exchange in the lineswitch LS3 which has access to a number of trunk lines, one of which is the trunk line including conductors 221 to 224, and extending to the selector repeater SR2, Fig. 3. The lineswitch LS4, in which the party line of substation A5 terminates, also has access to the trunk line extending to the switch of Fig. 3, as the bank contacts of all of the lineswitches terminating the semi-automatic lines are multipled together. Fig. 2 shows also the master switch MS which controls the lineswitches such as LS3 and LS4.

The selector repeater SR2 of Fig. 3 has access by way of the second level to local connectors such as the local connector LC3 of Fig. 4, which is accessible by way of the trunk line comprising conductors 361—363.

The finder F3, shown in Fig. 5, is one of a group of finders, each individual to a separate register sender, having access to the selector repeaters such as SR2, as explained in connection with Fig. 1. The starting of an idle one of these finders is controlled by the finder-control relays FCR2, which in turn are controlled over the start conductor 350.

The apparatus to the right of the irregular dotted line running up across Fig. 6, together with the apparatus of Figs. 7 and 8, constitutes one register sender (the sender SE-1 of Fig. 1), and is individual to the finder F3, Fig. 5. The remaining equipment to the left of the dotted line in Fig. 6 is associated with the operator and is common to all of the register senders. This includes the finder F4, which connects the operator's telephone T1 to the register sender and finder F3, and the operator's digit keys, shown at the extreme left-hand portion of the sheet.

Fig. 11 shows the finders F1 and F2 that terminate the operating trunks OT1 and

OT2 in the exchange EX-1 of Fig. 1. The conductors 1136, 1137, and 1138 are assumed to be the three conductors that extend to the selector repeater SR1 of Fig. 1 in the same way that the conductors 353, 352, and 351 extend from the finder F3 of Fig. 5 to the selector repeater SR2 of Fig. 3.

The finder control relays FCR1 of Fig. 11 are provided to control the starting of the finders F1 and F2. The alarm circuit AC is provided for the purpose of setting up a special condition on one or the other of the operating trunks OT1 and OT2 when an abnormal or alarm condition arises in the un-
15 attended No. 1 exchange. An alarm condition on either of the operating trunks causes the call to be "side-tracked" to a special operator's circuit, shown in Fig. 10 in association with the trunk circuit TR4.

20 On the other end, the operating trunks OT1 and OT2 terminate at the exchange EX-2 of Fig. 1 in the trunk circuits TR4 and TR5, Figs. 1 and 10. The conductors 1035—1040, leading to the right from the 25 trunk circuits of Fig. 10, are accessible to the finder F3 of Fig. 5 and to the other finders in the same group.

Fig. 9 shows the ring-back switch RBS (see also Fig. 1) which is used in a manner 30 to be explained more in detail hereinafter when a call is made from a substation on a party line to another substation on the same line. As many of these ring-back switches as are necessary to meet the traffic conditions 35 may be provided.

The trunk circuit TR1 of Fig. 1, which is used in the completion of calls from the tenth level of the selector repeaters in the No. 2 exchange to the toll-recording operator, is shown in Fig. 13 and is accessible by way of the tenth level of the selector repeater SR2 shown in Fig. 2.

The trunk circuit TR2, Fig. 13, is used by the toll operator or the toll-recording operator in completing connections to semi-automatic lines in exchange No. 2 by way of the toll connector TC3, Figs. 1 and 14. For this purpose, the banks of the toll connector TC3 are connected in multiple with the bank 50 of the local connectors, such as LC3 of Fig. 4.

Fig. 12 shows the toll trunk TT connecting the two exchanges together. This toll trunk terminates at the No. 2 exchange in 55 the trunk circuit TR3, associated with the jack J3 and its multiples, while it passes through the ringing repeater RR in the No. 1 exchange and terminates in the toll selector TS. The trunk is accessible to the selector repeater SR1 and the other selector repeaters in the No. 1 exchange by way of conductors 1245 to 1248.

Detailed description

65 The invention having been described gen-

erally, a detailed description of the operation of the apparatus shown will now be given. For this purpose it will be assumed that the subscriber at substation A6, Figs. 1 and 2, desires to converse with the subscriber at substation A5 on the party line comprising conductors 203 and 204.

Local semi-automatic call in exchange EX-2

When the subscriber at substation A6 desires to make a call, he removes his receiver. Current thereupon flows over his line from the two batteries 202 and 201 in series, and passes through the lower winding of line relay 215 which is bridged across the two conductors of the calling line through contacts controlled by the cut-off armature 216 of the operating magnet 218. Line relay 216 operates and closes a locking circuit for its upper winding at its upper armature 25 through contacts controlled by the plunger-operating armature 217 of the magnet 218. In addition, relay 215 closes a circuit at its lower armature for the lower or pull-down winding of the operating magnet 218, 30 through the contacts of the preceding line relays of the group of lineswitches. This circuit includes contacts of the open-chain relay 239 of the master switch MS and the high-resistance lower winding of delay relay 240, and contacts of the start relay 241, and the grounded conductor 226. As is well known, the high-resistance lower winding of the delay relay 240 is included in the lineswitch-operating circuit in order to momentarily delay the operation of a lineswitch so as to give time for the self-aligning plunger of a lineswitch to become completely aligned after it has been restored, in case the line relay immediately reoperates. 35 The delay relay 240, the operation of which is slowed up somewhat by the normally short-circuited upper winding, operates after a slight interval and places the upper winding thereof in circuit in place of the lower winding. The current flow through the low-resistance upper winding maintains the delay relay operated, and it energizes the magnet 218 sufficiently to operate both of its armatures 216 and 217.

As a result of the operation of armature 216, the lower winding of relay 215 is removed from in bridge of the talking conductors; and as a result of the operation of armature 217, the plunger (not shown) enters the lineswitch banks and operates the bank springs 227—230 (assuming the master switch to be standing in the position shown) to extend the calling line through to the trunk conductors 221—224, leading to the selector repeater SR2, Fig. 3. As a further result of its operation, armature 217, at the local spring contacts controlled thereby, shifts the locking circuit of the upper winding of line relay 215 so that it includes 130

- the common locking conductor 244, supplied with locking ground potential through the winding of the chain-control relay 238 and contacts of the open-chain relay 239.
- 5 The current flow in the locking circuit is sufficient to maintain relay 215 operated and is sufficient to operate relay 238, but relay 238 is rendered slightly slow to operate by the copper collar placed on the armature 10 end of the winding core thereof, as indicated by the solid-black upper portion of the relay. In this way, the chain-control relay does not ordinarily interfere with the regular operation of the master switch.
- 15 When the springs 227-230 of the lineswitch LS3 are operated, a holding circuit for the upper winding of magnet 218 is closed at spring 228 by way of the ground-ed release-trunk conductor 222, conductor 20 222 being normally grounded in the selector repeater SR2 at the contacts of release relay 317. By the closure of this holding circuit, the lineswitch LS3 is held operated after the circuit of the lower winding of 25 magnet 218 is opened as it shortly is.
- As a result of the operation of spring 229, ground potential is placed on the trunk conductor 223, resulting in the operation of relay 204 of the selector repeater SR2 30 with results to be explained hereinafter, and resulting in the closure of a circuit through the associated contact in the bank of wiper 242 of the master switch and the said wiper for the upper winding of start relay 241.
- 35 When start relay 241 operates, it opens the operating chain-circuit of the lineswitches at its inner armature, resulting in the opening of the circuit of the lower winding of magnet 218, leaving this magnet now energized solely by means of its upper winding. Relay 240 now falls back. In addition, start relay 241 closes a circuit from the grounded conductor 226 for the locking magnet 237 of the master switch, causing 40 magnet 237 to operate and advance the master switch in search of another idle trunk line. As a further result of its operation, locking magnet 237 closes a circuit for the open-chain relay 239, thereby opening the 45 operating chain-circuit of the lineswitches at an additional point. Relay 239 closes a local circuit for its upper winding at its inner contacts so as to render the relay slightly slow in releasing. Relay 239 also 50 opens the locking circuit of the upper winding of line relay 215, whereupon this line relay falls back. This occurs before the chain control relay 238 has had time to operate.
- 55 The locking magnet 237 falls back and again opens the circuit of the lower winding of the open-chain relay 239 as soon as another idle trunk has been selected, this being brought about by the deenergization 55 of start relay 241. Relay 239 falls back

after a slight interval so as to permit the operation of any one of the unoperated lineswitches.

It may be pointed out at this time that the common conductor 226 is provided for 70 the purpose of preventing unnecessary operation of the master switch MS at a time when all of the selector repeaters such as SR2 are busy, ground potential being removed from conductor 226 at all points under this condition. In this case, relay 238 operates after a slight interval and closes the circuit of the open-chain relay 239, operating the open-chain relay to open the locking circuit of the line relay of the last-operated lineswitch, whereupon the chain-control relay 238 falls back also, and the circuit of relay 239 is again opened.

Extending the connection to the operator 85

In the selector repeater SR2, when relay 304 responds to the application of ground potential to the incoming conductor 223 by spring 229 of the lineswitch LS3, it applies potential from the operator tone conductor 347 to talking conductor 221 by way of the associated condenser, informing the calling subscriber that the exchange apparatus is functioning to signal the operator; it grounds the local conductors 338 and 339 at its inner upper and middle upper armatures; opens a point in the circuit of the release magnet 331 of the selector repeater, and a point in the circuit of release magnet 342 of the timing switch TS at its middle lower armature; at its inner lower armature it disconnects ground potential from the test conductor 353 and connects the said test conductor to the cut-off or stop relay 309, enabling the finder to be started to stop on the contacts in its bank associated with the selector repeater SR2; and at its lower armature relay 304 places ground potential on the finder-start conductor 350 through the contacts of relay 303.

Responsive to the grounding of conductor 350, relay 534 operates and closes a circuit for relay 533. It is to be noted that there is a weight attached to the contact of the armature spring of relay 534. This weight causes the contact to vibrate for an interval after the relay operates and the operation of the relay 533 is thereby delayed slightly. This precaution is taken to prevent the starting of a finder responsive to a transitory grounding of the start conductor 350.

When relay 533 operates, it closes a circuit through contacts of relay 532 and through contacts of relay 508 for the start relay 505 of the first finder F3 of the group, 125 assuming that this finder is idle. When relay 505 operates, it closes at its inner armature a circuit for the upper winding of test relay 501 and stepping magnet 509 in series. This circuit includes the resting con- 130

tact and armature 529 and the normally-closed contacts controlled by armature 527. Relay 501 does not operate at this time over this circuit in series with relay 509 because it is shunted by ground potential encountered on the non-calling test contacts by wiper 512, which is connected to the junction of relay 501 and magnet 509 by way of the upper contacts of relay 504 and the upper contacts of start relay 505. Magnet 509 is operated by the ground potential encountered by wiper 512; and, by its buzzer-like action, occasioned by its self-interrupting contacts, drives the wipers 510-512 over the bank contacts in search of the calling terminals; in this case the terminals of the selector repeater SR2, to which conductor 351-353 are connected. When this calling set of terminals is found, ground potential is not directly encountered by wiper 512 over conductor 353 on account of the fact that the inner lower armature of relay 304 has, as previously mentioned, disconnected conductor 353 from ground directly and connected it to ground through to the high-resistance and high-impedance upper winding of relay 309. A small current flows through this circuit, but the current flow is insufficient to cause a further operation of magnet 509. Moreover, the impedance of the winding is sufficiently great to prevent a quick building-up of current flow. The relay is stiffly adjusted so that it does not operate for the time being.

In the finder F3, the relay 501, which has been short circuited heretofore by the ground potential directly encountered by wiper 412, is now no longer short circuited and it operates in series with stepping magnet 509. Stepping magnet 509 does not operate at this time on account of the relatively high resistance of relay 501. Relay 501 quickly operates and at armature 527 disconnects stepping magnet 509 from the wiper 512 and substitutes resistance 517 so that operation of relay 309 of the selector repeater SR2 will not be interfered with. At its inner-lower armature, relay 501 closes a locking circuit for its lower winding through the lower contacts of relay 504, so as to maintain the relay operated after its upper winding is cut out of circuit; it places ground potential on conductor 523 at its lower armature, thereby lighting the busy lamp 518 through contacts of the busy key 519; shunts the upper contacts of relay 505 at armature 528 so as to keep wiper 512 connected up after relay 505 falls back; and at armature 529 opens the circuit of the upper winding of relay 501 and places the upper winding in a locally closed circuit so as to render the relay slow to release.

In the selector repeater SR2, relay 309 operates as soon as the current-flow over conductor 353 builds up to the required

value. When it does so, it shunts the high-impedance and high-resistance upper winding by means of the low-resistance lower winding, thereby bringing the potential of conductor 353 more nearly ground potential. In this way, the selector repeater SR2 is guarded against seizure by another finder in the same group as the finder F3. Relay 309 remains operated by the current flow through its two windings in parallel. As a further result of its operation, relay 309 closes a circuit at its inner upper armature for relay 308. Relay 308 operates and locks itself to the grounded conductor 338 at its inner upper armature; it disconnects the operator-tone conductor 347 from conductor 221 at its upper armature; and at its lower armature it disconnects ground potential from the start conductor 350 so as to avoid starting another finder, such as F3. When this occurs, relays 534, 533, and 505 fall back.

With relays 309 and 501 of SR2 and F3, respectively, operated, the talking conductors of the selector repeater SR3 to the right of the repeating coil windings are connected through conductors 351 and 352 and wipers 510 and 511 to the right-hand repeating coil windings associated with the finder F3. Operator tone from conductor 347 is now applied to conductor 341 at the finder F3, through the associated condenser, upper contacts of relay 502, and armature 525. With conductor 351 grounded by way of the middle-lower armature of relay 503 and condenser 516, the operator tone current flows through the right-hand repeating coil winding of the selector repeater SR3 and is thus repeated back to the calling line so that the calling subscriber still hears the operator tone applied from the finder F3 after the connection to the operator tone conductor has been opened at the selector repeater SR2, as above mentioned.

As a result of the placing of ground potential on conductor 523 by the lower armature of relay 501 of the finder F3, relay 623 of the register-sender relay group of Fig. 6 is operated over conductor 523 and through contacts of relays 624. Upon operating, relay 623 disconnects the test conductor 613 from the direct ground connection and connects it to conductor 614 at its inner upper armature and at its upper armature relay 623 places ground potential on start conductor 614 of the finder F4.

When ground potential is placed on start conductor 614, lamp 601 glows to inform the operator of the approaching connection, and start relay 603 of the finder F4 is operated through contacts of relay 602. At its upper armature, relay 603 connects up the cut-off or stop relay 602 to wiper 610 at its upper armature, and at its lower armature connects the operating magnet 607 to the test

wiper 611. The test wiper 611 encounters ground potential on each contact not associated with a calling register sender. As a result, the wipers 608-611 of the finder F4 are advanced step by step by the buzzer-like action of the operating magnet 607 until they come to rest on the set of bank contacts associated with the register sender shown in the drawings. At this time, wiper 611 is in engagement with test conductor 613 from which direct ground potential has been removed at the inner upper armature of relay 623. Current now flows from the operating magnet over conductor 613 to ground by way of relay 621, and additional current flows by way of conductor 614 and through wiper 610 to ground through contacts of relay 603 and through the winding of relay 602. Magnet 607 is not operated by this current flow owing to the relatively high resistance of relays 602 and 621. Relay 602 at its inner upper armature locks itself to wiper 610 independent of the contacts of relay 603; connects operating magnet 607 to wiper 611 independent of the lower contacts of relay 603 at its own lower contacts; prepares a locking circuit for relay 604 at its middle lower armature; it connects the talking conductors through to the operator's telephone T1 at its middle upper and upper armatures; and at its inner lower armature it disconnects start conductor 614 from relay 603 and extends it through contacts of relay 604 to relay 606. Relay 606 operates, and closes a circuit for relay 605. Relay 605 operates and closes a circuit for relay 604. Relay 604 locks itself to ground at the middle lower armature of relay 602 and opens the circuit of relay 606. Relay 606 falls back after a slight interval followed by the deenergization of relay 605. During the time relay 605 is operated, ground potential is applied to the lower one of the associated talking conductors. The connection of the ground potential to this talking conductor and the subsequent disconnection of ground potential therefrom results in a characteristic click in the operator's telephone informing her that a calling line has now been telephonically connected to her telephone.

As a further result of the momentary connection of ground potential to the lower one of the associated talking conductors, a circuit is closed through wiper 609 and over conductor 521 and by way of the lower left-hand repeating-coil winding of the finder F3 for relay 506. Relay 506 operates and closes a circuit for relay 502. Relay 502 operates and locks itself operated at its lower armature in multiple with the lower winding of relay 501, and at its upper armature it disconnects the operator-tone conductor 347 from the talking circuit, thus informing the calling subscriber by the cessation of the

operator tone that the operator is now in communication with him and that he may at once give the desired number to the operator. In case the operator does not receive the number at once, she may ask for the number in the usual way. When relay 506 falls back upon the cessation of the momentary application of ground potential to conductor 521 made by relay 605 of Fig. 6, it closes a circuit through contacts of relay 502 for the upper winding of relay 508. Upon operating, relay 508 opens a point in the circuit of relay 531, which circuit is normally closed at each of the finders such as S3, and closes a locking circuit for itself through contacts of the operated relay 531 and the resistance element 535. Relay 508 accordingly remains operated until all of the corresponding relays in the other finders have operated and permitted the release of relay 531. At its upper armature, relay 508 disconnects the incoming start conductor from start relay 505 and extends it to the next finder in the group.

It is to be noted that ground potential is applied to the test wiper 512 at the upper armature of relay 506 and through armatures 527 and 528 of relay 501 during the time relay 506 is operated by the impulse transmitted thereto from the finder F4. This application of ground potential to test wiper 512 shunts the cut-off or stop relay 309 of the selector repeater 502, and causes it to fall back momentarily. This operation is of no utility in connection with the selector repeater SR2, but is of use when the call is coming in from an outlying exchange, as will be explained hereinafter. It may be pointed out that the momentary deenergization of relay 309 does not produce any particular result in the selector repeater SR2 because relay 303 controlled thereby is locked up through contacts of the energized relay 304.

Storing the desired number

Relay 621 of the relay group of Fig. 6 energizes in multiple with relay 602 of the finder F4, and in series with operating magnet 607, when the finder F4 finds the register sender. The start and error keys ST and ER are connected up at the lower contacts of relay 621, and at the upper contacts of the relay ground potential is placed on the digit-control conductor 644, closing a circuit for connecting relay 702 through contacts of relay 701. Relay 702 operates and connects the setting conductors A to D associated with the operator's key set at the left of Fig. 6 with the corresponding relays A to D of the thousands register TH, Fig. 7. As a result, the operator may now set up the digits 2, 3, 2, and 5 of the desired number on the registers of Fig. 7 by operating the

corresponding ones of the digit keys shown at the left in Fig. 6.

When the digit key 2 is depressed to set up the first digit 2 in the desired number, 5 ground potential is extended over conductors A and C and through contacts of the operated relay 702 to the relays A and C of the thousands register TH, Fig. 7. These relays both operate and each locks itself to the grounded conductor 646 through the winding of relay 701. Relay 701 does not operate for the time being, because it is short circuited by the initial application of ground potential over conductors A and B. 10 As soon as the depressed digit key 2 is released, however, the shunt is removed from around the winding of relay 701, and this relay thereupon operates in series with relays A and C of the register TH. Upon 15 operating, relay 701 disconnects the grounded digit-control conductor 646 from relay 702 and extends it through the contacts of relay 711 to the connecting relay 712 associated with the hundreds register H. Relay 702 falls back and relay 712 operates. 20

Relay 701 at its middle armature applies ground potential to conductor 645 through the contacts of the unoperated transfer relay 704. Relay 625 operates preparatory to the subsequent starting of the sender to retransmit the stored digits. 25

When the operator depresses the digit key 3 to store the second digit 3 of the desired number, an application of ground potential is made to the control conductors A and D, closing a circuit through the contacts of the operated relay 712 for relays A and D of the hundreds register H. These relays A 30 and D are accordingly operated to lock themselves to the inner contacts of relay 701 through the winding of relay 711. As a result, relay 711 energizes when the depressed digit key 3 is restored. Upon operating, relay 711 makes an additional application 35 of ground potential to conductor 645 at its middle armature; prepares circuits for relay 721 and 724 at its inner armature; and at its upper armature it transfers the digit-control conductor 644 through contacts of relay 721 to the connecting relay 722. 40

When the operator depresses the digit key 2 again to cause the third 2 in the desired number to be stored, the resulting application of ground potential to conductors A and C closes circuits for relays A and C of the tens register T, Fig. 7. These relays lock themselves in series with relay 721, which relay is accordingly operated upon the release of the digit key. Relay 721 performs operations similar to those described in connection with relays 701 and 711, including the transfer of conductor 644 from relay 722 through contacts of relay 731 to connecting relay 732. Relay 732 operates and connects

the digit conductors A to D to the corresponding relays of the units register U.

When the operator depresses the digit key 5 to store the fourth and last digit 5 in the desired number, the resulting application of ground potential to the associated conductors B and D closes circuits for relays B and D of the units register U. These relays lock themselves in series with transfer relay 731 with the result that relay 731 operates when the key is released. Relay 731 opens the circuit of connecting relay 732 and makes an additional application of ground potential to conductor 645. 70

It may be pointed out at this time that the operator may cause the release of any operated ones of the registers in case she discovers that she has made an error in setting up a number. In order to do this she merely depresses the error key ER, bringing about the energization of relay 627. Relay 627 removes the holding ground potential from conductor 646, whereupon the operated ones of the transfer relays 701, 711, 721, and 731 deenergize successively accompanied by the deenergization of the corresponding operated register relays. 75

Starting the sender

After having set up the digits of the number, the operator proceeds to depress her start key ST closing a circuit through contacts of the connecting relay 621 for relay 622. Relay 622 operates and locks itself to conductor 523 in series with relay 624. Relay 624 does not operate for the time being because it is short circuited as long as the start key is depressed. When the start key is released, however, relay 624 operates in series with relay 622 and opens the circuit of relay 623. Relay 623 falls back and removes ground potential from conductor 646 its lower armature, but this ground potential has been replaced by one applied at the lower armature of relay 622. At its upper armature, relay 623 removes ground from conductor 614, extinguishing lamp 601, and at its inner upper armature it opens the circuit of the associated connecting relay 621 and of relay 602 of the finder F4, and applies ground potential to conductor 613 to render the register sender unselectable to the finder F4 upon its next operation, when start conductor 614 becomes grounded again in some other register sender. Relays 602 and 621 fall back immediately, and relay 602 opens the locking circuit of relay 604. Relay 604 falls back, and the finder F4 is in its normal position shown in the drawings. 90

Upon the energization of relay 622, a circuit is closed through the operated armature of relay 625 for relay 628. Relay 628 operates and closes a circuit for relay 630. Relay 630 operates and closes a circuit over conductor 642 for the impulse relay 313 of 100

the selector repeater SR2. This circuit includes the upper contacts of the impulse relay 802 of the sending device in Fig. 8, conductor 524, the lower right-hand repeating coil winding associated with the finder F3, armature 526, wiper 511, conductor 352, contacts of the operated relay 309, contacts of the unoperated relay 311, the lower right-hand repeating coil windings of the switch SR2, and the normally-closed contacts controlled by the inner lower armature of relay 311, to relay 313. The impulse relay 313 operates over this circuit and closes a circuit for the slow-acting control relay 314. Relay 314 operates and prepares at its upper armature a circuit for the vertical magnet 332, and at its lower armature it opens a point in the circuit of relay 305. The selector repeater is thus prepared to respond to the impulses transmitted by the sending apparatus of Fig. 8.

As a further result of the operation of relay 628 when it operates to close a circuit for relay 630 as above pointed out, relay 25 628 places a ground potential on conductor 522 at its upper armature, closing a circuit for the finder control relay 503, Fig. 3. Relay 503 closes a circuit for the slow-acting relay 504. Relay 504 operates, but 30 nothing happens as a result of the operation of relay 504 for the present, because the contacts of relay 504 are shunted by corresponding contacts of relay 503. At its middle lower armature, relay 503 disconnects 35 the condenser 516 from the lower right-hand repeating coil terminal, and at its lower armature it closes a circuit through the upper right-hand repeating coil windings, upper contacts of relay 501, wiper 510 of the 40 finder F3, conductor 351, upper contacts of relay 309 of the switch SR2, normally-closed contacts controlled by the upper armature of relay 311, upper right-hand repeating coil windings, and the resting contacts 45 and upper armature of relay 311, to battery by way of the winding of relay 310. Relay 310 operates and removes the shunt at its upper armature from the corresponding contacts of impulse relay 313, for a purpose to be explained more fully subsequently. At its lower armature, relay 310 places 50 a shunt around the lower right-hand repeating coil windings so as to remove this winding from the circuit of impulse relay 313.

55 *Sending out the stored digits*

As a further result of the energization of relay 624, a circuit is closed at its inner lower armature for relay 626. Relay 626 operates and makes an additional application of ground potential through the contacts of relay 627 to conductor 646. Also, a circuit is closed at the inner lower armature of relay 624 through the inner lower armature 60 of relay 625 and over conductor 643 for

starting the sending apparatus of Fig. 7 to operating. When this occurs, the sending relays 801—803 start energizing and deenergizing in succession: When conductor 643 is first grounded, relay 801 operates through contacts of relay 803 and it closes a circuit for relay 802. Relay 802 operates and closes a circuit for relay 803. Relay 803 operates and opens the circuit of relay 801, whereupon all of the relays fall back one after another; but, as soon as relay 803 falls back, the relays all energize again successively. This operation continues as long as conductor 643 is grounded. By suitably adjusting the relays 801 to 803, any one of them can be made to deliver impulses of about the speed and ratio desired in the operation of automatic switches. The rate of operation of any one of the relays is about ten energizations and deenergizations per second. The adjustment of the relays is just stiff enough to cause each of them to hesitate only slightly before pulling up after its circuit is closed, and the resistance shunted around the winding of each relay is just sufficient to cause each relay to hesitate slightly before restoring after its circuit is opened. Relay 801 delivers impulses over conductor 831 to the counting relays 804 to 813 and 815 to 819; the second impulse relay 802 delivers the impulses in the circuit including conductors 642 and 524 for the operation of the automatic switches; and relay 803, merely opens the operating circuit each time it operates so as to bring about the deenergization of the relays as above pointed out.

Each of the counting relays 804 to 813 and 815 to 819 is a two-step relay. When energized by means of its relatively inefficient upper winding alone, one of these relays operates only its inner lower contacts, which are marked with an "X" in each case to indicate this fact.

When conductor 831 is grounded the first time, by the first operation of relay 801, a circuit is closed through contacts of all of the relay 804 to 818 for the upper winding of relay 804. Relay 804 is operated through its first step only and closes only its first-step contacts; the contacts comprising the inner lower armature and the associated front contact. This operation closes a circuit for the two windings of the relay in series from the grounded start conductor 623 by way of contacts of relay 814. As long as ground potential is applied to conductor 831 by relay 801, the lower winding of relay 804 is short circuited and is therefore ineffective. As soon, however, as relay 801 falls back and ungrounds conductor 801, the short circuit is removed from around the lower winding of relay 804, and this relay operates fully, responsive to the current flow through both windings in se- 130

ries. At its lower contacts, relay 804 connects up the first impulse stop conductor associated with the registers of Fig. 7 and at its upper it transfers the operated conductor 831 to the second counting relay 805. As a result, the operation of the counting relays 801 to 813 proceeds with one of these relays being operated by each impulse placed on conductor 831, until the stop relay 814 is operated responsive to a grounded one of the digit stop conductors 1 to 0 being connected up.

Each time relay 802 operates, it opens the impulse circuit including conductors 642 and 524 at its upper armature, in this way sending an impulse over this circuit, an impulse being understood to be a momentary cessation of current flow in this case. Accordingly, one impulse is delivered into the impulse circuit for each operated one of the counting relays 804 to 813.

In the call under consideration, the first digit to be transmitted is the digit 2, set up on the thousands register TH, Fig. 7, where-
25 in the relays A and C are operated to extend the ground potential from the resting contact of the lower armature of relay 704 to the second of the impulse stop conductors extending along the bottom of Fig. 7 to the
30 counting relays of Fig. 8. Accordingly, when counting relay 805 operates fully, at the second removal of ground potential from conductor 831, and connects up the second digit-stop conductor 2, a circuit is closed
35 from the grounded conductor 2 for the stop relay 814. Relay 814 operates and locks itself to the grounded conductor 643 at its lower armature, through contacts of relay 819. At its upper armature, relay 814
40 shunts the sending contacts of relay 802 to prevent further impulses from being sent, for the time being, over the outgoing circuit including conductor 642 and 524. By the time this shunting occurs, the sec-
45 ond impulse has been delivered in the outgoing circuit by relay 802, as the operation of relay 802 closely follows the operation of relay 801 and the relays 805 and 814 must operate successively after relay 801 falls
50 back before relay 814 can shunt the impulse contacts of relay 802. Relay 814 also prepares a locking circuit at its inner upper armature for the digit-spacing relays 815 to 819, at the same time opening the locking
55 circuit of the operated ones of the relays 804-813. The operated ones of these counting relays now fall back. At its middle upper armature, relay 814 transfers the relay-operating circuit to the first of
60 the spacing relays 815 to 819, with the result that the next impulse delivered over conductor 831 results in the first-step operation of relay 815. Relay 815 operates fully when the impulse is terminated and trans-
65 fers the operating circuit to relay 816. Ac-

cordingly, the sending of impulses over conductor 524 is arrested by the continued en-
70 ergization of stop relay 814, while the re-
lays 815 to 819 are operating successively responsive to the operations of the control-
ling relay 801.

When start conductor 643 was first grounded, a circuit was closed through contacts of relay 814 and over conductor 751 for relay 703. Relay 703 operates and closes
75 a locking circuit for itself in series with re-
lay 704. Relay 704 cannot operate, however,
as long as conductor 751 remains grounded,
as relay 704 is short circuited by ground po-
tential on conductor 751. When relay 814
80 operates, however, it removes ground from
conductor 751, removing the short circuit
from around the winding of relay 704, and
relay 704 energizes in series with relay 703.
At its upper armature, relay 704 removes
85 ground potential at one point from the hold
conductor 645; at its inner lower armature
it transfers the operating conductor 751 to
relay 713; and at its lower armature it dis-
connects ground potential from the contact
90 pyramid of the thousand register TH and
transfers it through contacts of relay 704 to
the contact pyramid of the hundreds regis-
ter H. In this way that apparatus of Fig. 7
is altered so that the next digit to be trans-
95 mitted is the digit 3, stored on the hundreds
register H.

As soon as relay 819 has operated fully
100 responsive to the cessation of the fifth spac-
ing impulse, and following the successive
operations of relays 815 to 818, it opens the
locking circuit of relay 814 at its lower ar-
mature, whereupon relay 814 falls back and
105 opens the locking circuit of relays 815 to
819, at the same time preparing the locking
circuit again for relays 804 to 813. The op-
erated relays 815 to 819 immediately restore,
and the next ground of conductor 831 re-
sults in the operation of relay 804 again.
Also, with relay 814 now in a deenergized
110 condition, the impulse-sending contacts of
relay 802 are not shunted and the impulses
of the second digit are sent out over con-
ductor 524.

When the relays 804-813 start operating
115 again to count off the transmitted impulses
of the second digit, the source of actuating
ground potential for stop relay 814 has been
shifted, as above described, so that it is
under the control of the second contact pyra-
120 mid instead of the first; and the third of the
digit conductors is grounded instead of the
second, as it is the digit 3 which is stored
on the hundreds register H, wherein the re-
lays A and D are operated. Accordingly,
125 at the end of the third impulse transmitted
over conductor 524, the second digit 3 is ter-
minated by the energization of stop relay
814 through the lower contacts of relay 806.
Relay 814 stops the transmission of impulses
130

in the outgoing circuit over conductor 524 at its upper armature and performs the other functions previously described including the releasing of the operated ones of the relays 804 to 813 and the shifting of circuits so that the spacing relays 815 to 819 are operating successively to introduce a suitable time interval before relay 814 is again released to start the transmission of the third digit 2.

10 The counting relay pair comprising relays 713 and 714 is operated over conductor 751 incidental to the release and reoperation of stop relay 814, with the result that the controlling ground potential is shifted from the 15 hundreds register H to the tens register T.

The third digit 2 is transmitted in the manner hereinbefore described after which relay 814 is again energized over the second conductor from the ground potential supplied through the contact pyramid of the 20 tens register T, wherein relays A and C are operated. The relays 723 and 724 are operated over conductor 751 incidental to the 25 operation of relay 814, and the controlling ground potential is shifted to the contact pyramid of the units register U.

The fourth and last digit 5, stored on the units register U, wherein the relays B and D are actuated, is transmitted in the above-described manner and is terminated upon the energization of relay 814 over the fifth of the digit conductors and responsive to the complete operation of counting relays 808. At this time, as before, the transmission of 35 impulses is terminated by the shunting operation of the upper armature of stop relay 814, and the operation of the digit-spacing relays 815-819 is started.

Following the transmission of the fourth 40 and last stored digit 5, the register sender is freed and restored to common use in a manner which will be explained after the explanation of the setting up of the desired connection responsive to the transmitted digits 45 has been given.

Setting up the connection

In the selector repeater SR2, Fig. 3, the impulse-repeating relay 313, to which the 50 impulse conductor 524 outgoing from the register sender of Figs. 6 to 8 extends by way of circuit path through the finder F3 and conductor 352, as previously traced, falls back momentarily two times responsive to the two impulses or interruptions produced in the control circuit by the sending apparatus of Fig. 8 in the sending of the first 55 digit 2. Each time it falls back, repeating relay 313 opens the circuit of the associated slow-acting relay 314, but relay 314 remains operated when its circuit is only momentarily opened. As a further result of each deenergization of repeating relay 313, a circuit is closed through contacts of relays 312 60 and 314 for vertical magnet 332 by way of

series relay 315. Vertical magnet 332 is thus operated twice, and by its step-by-step operation it raises the wipers 334 to 337 opposite the second level of bank contacts. Relay 315 operates responsive to the first 70 impulse of current delivered to magnet 332, and it remains operated throughout the vertical movement owing to the fact that it is a slow-releasing relay. With relay 315 operated, and with the off-normal contacts 330 closed (they close at the beginning of the first vertical step), a circuit is completed from the grounded conductor 339 for stepping relay 316. Stepping relay 316 completes a locking circuit for itself at its upper armature through the interrupting contacts of rotary magnet 333 and the off-normal contacts 330. At its inner armature, relay 330 prepares a circuit for rotary magnet 333. 80

When relay 315 falls back upon the cessation of the impulses to the vertical magnet 332, it opens the initial circuit of the now-locked stepping relay 316 and completes the circuit of the rotary magnet 333. Rotary magnet 333 operates and drives the wipers 334-337 into engagement with the first set of bank contacts in the second level. Near the end of its stroke, magnet 333 opens the locking circuit of stepping relay 316, whereupon stepping relay 330 falls back and opens an additional point in its own previously established locking circuit and opens the circuit of the rotary magnet 333. Magnet 333 now falls back and again closes its 100 interrupter contacts.

The subsequent operation depends upon whether the trunk line terminating in the first set of bank contacts is busy or idle. If this trunk line is idle, no ground potential is encountered on the control conductor 362 thereof. As a result, the trunk line is seized. The rotary movement is continued, however, if the trunk line is busy, as stepping relay 316 operates again through wiper 336, middle upper armature normal, of relay 311, interrupter contacts of magnet 333, and off-normal contacts 330. Upon operating again, relay 316 again closes the circuit of rotary magnet 333; and the rotary movement continues until an idle trunk line is reached. It will be assumed that the first set of bank contacts found to be idle, is the set in which the conductors 361-363 terminate. When this contact set is reached, switching relay 311, which had its circuit completed through stepping relay 316 upon the closure of off-normal contacts 330, but which was maintained short circuited until relay 316 deenergized after the wipers had been advanced to the idle contact set, now operates from the ground potential on conductor 338, and in series with stepping relay 316. Stepping relay 316 does not operate at this time on ac- 110

count of the relatively high resistance of relay 311.

Upon operating, relay 311 opens a point in the previously existing test circuit including wiper 336, and connects the wiper 336 to the grounded conductor 339, thereby making the seized trunk busy immediately to the other switches having access to it. At its lower armature, relay 311 connects the time-pulse lead 349 with the operating magnet 343 of the timing switch TS so as to start the timing operation; at armature 355 it completes the connection between conductor 352 and repeating relay 313 by a more direct path which excludes the repeating-coil windings; at armature 354 it opens an additional point in the circuit of release relay 305; at its inner lower armature it opens the connection between the lower right-hand repeating-coil winding and relay 313, at the same time placing the upper winding of the electro-polarized relay 308 in bridge of the condenser connected between the right-hand repeating coil windings; at its upper armature it shifts the connection of conductor 351 and the control relay 310 so that conductor 351 is connected more directly to relay 310 over a circuit path which excludes the talking circuit of the selector repeater; and at its inner upper armature relay 311 closes a circuit for relay 312. Relay 312 operates and opens a point in the vertical magnet circuit so as to prevent the magnet 332 from operating further; it removes ground at its inner lower armature from common conductor 226 at one point; and at its upper and lower armatures it connects up the wipers 334 and 337, completing the connection to the trunk line extending to the local connector LC3 and comprising conductors 361—363.

In the local connector LC3, line relay 405, which is bridged around the condenser associated with the left-hand repeating coil windings, through contacts of the reversing relays 404, now energizes over conductors 361 and 363, through the upper and lower contacts of the wiper-connecting relay 312, through the upper contacts of the operated repeating relay 313, through the right-hand repeating-coil windings, through the upper winding of the electro-polarized relay 308 and the associated resistance, and the inner lower armature of the operated relay 311 and its working contacts. Current is now flowing through both windings of the electro-polarized relay 308 of the selector repeater, but relay 308 does not operate at this time because the current flow is in the opposite direction in the two windings, whereas current must flow in both windings in the same direction in order for the relay to operate.

In the connector LC3, line relay 405, upon operating, closes a circuit for release relay

406. Relay 406 operates and places ground potential at its upper armature on release trunk conductor 362 so as to maintain the preceding switch operated in case the call is coming from a regular two-wire selector instead of from a selector repeater as in the present case; it places ground potential at its inner upper armature on conductor 450; and at its lower armature it prepares the operating circuit, at the same time opening a point in the release-magnet circuit. When conductor 450 is grounded, relay 403 operates through the middle upper armature of relay 409, and shunts out ring-off relay 400.

When the second digit 3 is transmitted by the sender of Fig. 8, the repeating relay 313 of the selector repeater SR2 falls back three times momentarily. Each time it does so it opens the circuit of the line relay 405 of the local connector LC3 at its upper armature. It being understood, of course, that relay 310 is being maintained energized over conductor 351 as heretofore pointed out, and that the upper contacts of repeating relay 313 are not at this time shunted by the upper contacts of relay 310. Each time its circuit is opened, relay 405 falls back momentarily and closes a circuit for vertical magnet 422; the circuit at the time of its first closure including the lower armature, operated, of relay 406, the contact normally engaged by off-normal spring 425, and the said spring, series relay 407, and vertical magnet 422. By the operation of the vertical magnet the wipers 428—430 of the connector LC3 are raised step by step until they stand opposite the third level of bank contacts. Relays 407 operates upon the receipt of the first impulse of current and it remains operated throughout the vertical movement because it is a slow-releasing relay. This relay makes a circuit shift so as to maintain its own circuit and the circuit of the vertical magnet intact after the off-normal springs including spring 425 have shifted, as they do upon the first vertical step of the switch.

At the end of the vertical movement, relay 407 falls back and shifts the operating circuit from the vertical magnet to the rotary magnet.

When the third digit 2 is received, the line relay 405 falls back twice, sending two impulses of current to the rotary magnet 423. Rotary magnet 423 accordingly rotates the wipers 428—430 two steps, into engagement with the second set of bank contacts in the third level, which is the bank contact set connected with the three vertical conductors extending across the sheet and across the corresponding portion of the adjoining Fig. 14 to the terminals 254, 255, and 256. These terminals are connected by means of the three so-called normal conductors to the correspondingly numbered terminals associated

with the line of substation A5 in Fig. 2. The series relay 411 operates in parallel with magnet 423, and it remains operated throughout the entire series of impulses because it is a slow-acting relay. Upon operating, relay 411 disconnects test wiper 429 from the test winding of switching relay 412 and connects it through contacts of relay 405 to the busy relay 410, and at its inner lower armature it shunts the corresponding contacts of busy relay 410 so as to maintain its own circuit and that of the rotary magnet 423 intact in case relay 410 operates over wiper 429 during the rotary movement owing to the test wiper passing over busy test contacts.

The operation following the arrival of the wipers 428-430 upon the bank contacts of the called line, the line of substation A5, Fig. 2, depends upon whether the line is busy or idle. If the line is busy, busy relay 410 is operated over wiper 429 and over the private normal conductor connected to the bank contact on which it is standing owing to the fact that this conductor of the called lines is always grounded in case the line is in use. In case relay 410 is energized when slow-acting relay 411 falls back at the end of the rotary movement, a locking circuit is completed for relay 410 at the normally-closed contacts controlled by the upper armature of relay 411. This circuit is from the grounded release-trunk conductor 362 through the said normally-closed contacts controlled by the upper armature of relay 411, and through armature 452. With the busy relay 410 operated, a connection extends to the lower associated talking conductor from the busy-tone lead 438 through the associated condenser, the contacts of relay 412, and the lower contacts of relay 410. The tone circuit includes the right-hand repeating-coil windings, and is completed to ground through the upper contacts of relays 410 and 412, with the result that the busy-tone current flows through the right-hand repeating-coil windings and thereby passes back to the calling line to inform the calling subscriber of the busy condition. With relay 410 operated and relay 411 restored, the operating circuit is open and the final digit 5 is not received by the party selector PS1.

Upon hearing the busy tone, the calling subscriber is expected to replace his receiver and bring about the release of the connection in the manner to be pointed out hereinafter.

Assuming now that the line of substation A5, Fig. 2, is idle when called, no ground potential is encountered on the test contacts of the called line by wiper 429, and relay 410 is accordingly not energized when the wipers 428 to 430 comes to rest. In this case, when relay 411 falls back, it makes an application of ground potential at its upper armature to

wiper 429 from the grounded release-trunk conductor 362, through the inner upper armature of busy relay 350 and its resting contact, the test winding of switching relay 412, and the resting contact and upper armature of relay 411, to wiper 429. The placing of this ground potential on wiper 429 through the test winding of relay 412, results in the closure of a circuit over the middle one of the three vertical conductors 75 immediately to the right of wiper 429, through terminal 255, Figs. 14 and 2, conductor 205, and the upper or cut-off winding of the magnet 207 of the lineswitch LS4. When energized through the upper winding 80 alone, the magnet 207 is strong enough to operate the cut-off armature 208, but is not strong enough to operate the pull-down armature 209. As a result, the bridge across the conductors of the called line including 85 the lower winding of line relay 208 is opened, but the lineswitch is not operated to make a connection with an idle trunk leading to a first selector repeater, such as SR2.

In the local connector LC2, relay 412 90 operates because its test winding is included in circuit in series with the cut-off winding of the called lineswitch. Upon operating, relay 412 locks itself energized by closing a circuit for the upper winding from the grounded conductor 450 at its inner upper contacts; applies ground potential directly to the test wiper 429 at its upper armature; prepares a circuit for pickup relay 408 at armature 451; opens a point in 95 the regular operating circuit of busy relay 410 at armature 452; and at its inner lower armature it transfers the operating circuit from rotary magnet 423 to the operating magnet 437 of the party selector PS1. 100

When final and party-selecting digit 5 is received at the connector LC3, the five impulses of current are delivered to the operating magnet 437 of the party selector PS1, causing wiper 434 to be set upon the fifth 110 one of the associated code conductors, over from the ringing-current-coding device (not shown). Series relay 411 remains connected to the operating circuit and is accordingly operated throughout the delivery of impulses to magnet 437. When relay 411 falls back at the end of the series of impulses, off-normal contacts 435 of the party selector PS1 having closed, a circuit is closed at the lower armature of relay 411 for relay 410. 115 Relay 410 operates and opens the operating circuit at its inner lower armature so as to prevent further operation of the party selector PS1 in case further impulses should be inadvertently transmitted to the connector. The operation of busy relay 410 at this time does not result in a busy signalling tone being transmitted back to the calling line on account of the fact that relay 412 has operated as hereinbefore described. 120 125

With relays 412 and 410 both operated, the common pick-up conductor 439 is closed through armature 451 and through the middle upper armature of relay 410 to the pick-up relay 408, so as to enable this pick-up relay to operate and start the ringing operation as soon as the common coding apparatus arrives in its starting position.

10 *Freeing the register-sender*

Returning now to the sending apparatus of Figs. 6 to 8, the way in which this apparatus is freed following the transmission of the last digit 5 in the desired number 15 will now be explained. When stop relay 814 energizes to terminate the fourth and last digit 5 and removes ground potential from control conductor 751, at the same time initiating the operation of the spacing relays 815 to 819; relay 724, which has been 20 short circuited by the ground potential on conductor 751 since the operation of the associated relay 733 took place over conductor 751 and through the contacts of the operated 25 relays 704, 714, and 724, now operates in series with relay 733 and removes ground potential at the last point from the holding conductor 645. When the conductor 645 is thus ungrounded, holding relay 625 of Fig. 30 6 falls back and at its lower armature opens the circuit of relay 628 and closes a point in the circuit of relay 629, but relay 629 does not operate at this time owing to the fact that its circuit is open at the lower 35 contacts of the operated relay 624. Relay 628 falls back and opens the circuit of the slow-acting relay 630 at its inner armature, and at its upper armature it removes ground potential from conductor 522. Relay 630 40 remains operated momentarily after its circuit is opened, maintaining ground potential on conductor 642 so as to maintain the repeating relay 313 of the selector repeater SR2 operated for a slight interval.

45 When ground potential is removed from conductor 522 by relay 628, relay 503 in the finder F3, Fig. 5, falls back and disconnects the test wiper 512 from the resistance 517 at its upper armature; it opens the locking circuit of the wiper-connecting relay 501 at its lower armature, but this relay is rendered slow-releasing by the locally closed circuit through its upper winding; and at its lower armature relay 503 removes ground potential 55 from the lower terminal of the upper right-hand repeating coil winding, thereby opening the circuit which was previously closed over conductor 351 for relay 310 of the selector repeater. Relay 310 now falls 60 back and immediately shunts the upper contacts of repeating relay 313 so as to avoid an opening of the talking circuit when the repeating relay falls back, and it shortly does. Relay 310 also connects ground potential at its slower contacts to conductor 65

353 and through the contacts of the now-operated relay 312 and contacts of relay 304. This ground potential maintains the selector repeater SR2 guarded against seizure by finders such as F3, and it would otherwise become unguarded upon the falling back of relays 309 and the disconnection of its low resistance winding responsive to the disconnection of wiper 512 of the finder F3, Fig. 5, upon the above-mentioned deenergization of relay 503.

In the finder F3, relay 501 falls back after a slight interval responsive to the opening of its locking circuit at the lower armature of relay 503 and opens an additional point in its locking circuit at its inner lower contacts before the slow-acting relay 504 has had time to fall back responsive to the deenergization of relay 503 and reestablish the locking circuit of relay 501. With relay 501 restored, the finder F3 is now in normal condition with its wipers disconnected. Relay 502, it may be stated, fell back responsive to the restoration of relay 503, and opened the circuit of the upper winding of relay 508, leaving this relay operating in a locking circuit controlled from the relay group FCR2.

In the relay apparatus SR2 of Fig. 3, the repeating relay 313 falls back when wiper 511 of the finder F3 is disconnected at armature 526 of relay 501. When it falls back, relay 313 opens a point in the talking circuit at its upper armature, but no harm results because its upper armature and the corresponding working contacts have already been shunted by the upper contacts of now-restored relay 310, as above mentioned. Slow-acting relay 314 falls back responsive to the deenergization of relay 313 and closes a point in the circuit of relay 305 at its lower armature, but this circuit is not completed as relay 311 is energized and is maintaining the circuit open at armature 354.

As an additional result of the deenergization of relay 501 of the finder F3, ground potential is removed from conductor 523 at the lower armature of the relay. When this occurs relays 622 and 624 fall back. Relay 622 removes ground from conductor 646, whereupon all operated relays of Fig. 7 fall back. Moreover, relay 624 removes the starting ground potential from conductor 643, whereupon the operated ones of the spacing relays 815 to 819, which have been operating one after the other under the control of the relay 801, fall back. Relay 814 also falls back, and relays 801 to 803 cease their operation. This final clearing out of the sender of course occurs before all of the spacing relays 815 to 819 have had time to operate; in fact the final clearing out of the sender following the removal of ground potential from conductor 13

751 requires only a small fraction of a second.

Signalling the called substation

- 5 Returning now to the connection established to the line of substation A5 by way of the switches SR2 and LC3, Figs. 3 and 4, the signalling operation will now be described. It may be pointed out at this time 75
- 10 that the common ringing apparatus employed in the present disclosure may be similar to the ringing apparatus disclosed in Fig. 8 of the drawings in the application of Norman H. Saunders, filed May 8, 1929, Serial No. 361,311 except that the common apparatus used herein requires that ten separate codes be provided instead of the five codes provided in the Saunders application. A code interrupter or generator capable of 80
- 20 generating ten codes is shown in the patent to Saunders 1,686,879. The code generator in this patent generates ground impulses on the various code leads; and these are, in turn changed into impulses of ringing current by 85
- 25 the associated relays 721-725. The relay 432 associated with the party selector PS1 may be one of the relays which responds to the impulses of ground current sent out by the ringing-code generator to, in turn, transform these ground impulses into impulses of 90
- 30 ringing current. It will be noted that the ringing current generator 431 has one terminal grounded and the other terminal connected to the contacts of the code-ringing 95
- 35 relays, such as 432, and that the first code conductor 433 is connected to battery when it is not connected to the grounded ringing current generator. The reason for this will 100
- 40 become apparent shortly.
- 40 When the code generator arrives in its pick-up position and grounds the pick up conductor 439, a circuit is closed for the pick-up relay 408 of the connector. This relay operates and locks itself to the grounded conductor 450, at the same time opening 105
- 45 its initial circuit. At its lower armature, relay 408 connects the wiper 434 of the party selector PS1, now standing on the fifth associated bank contacts, with the lower winding 110
- 50 of ring-cut-off relay 409. Accordingly, a path for ringing current is closed from the fifth conductor to the negative conductor of the called line by way of the lower winding of relay 409, upper contacts of the 115
- 55 same relay, wiper 428 and the bank contacts on which it is standing, the left-hand one of the three vertical conductors immediately to the right of the wipers 428 to 430, and terminal 254, Figs. 14 and 2, to the upper conductor 203 of the line of substation A5. Ringing current accordingly passes to the 120
- 60 called line to actuate all the ringers thereon, a return circuit being provided over the lower conductor 204, terminals 256, Figs. 2 and 125
- 65 14, the corresponding conductor extending 130
- to the bank of the connector LC3, wiper 430, contacts of relay 412, and contacts of relays 409 and 408 to ground. The ringing relay associated with the fifth lead and corresponding to relay 432 associated with the first lead is actuated by the ground code generator in accordance with the fifth of the ten assigned codes, applying ringing current to the line by way of the above-traced circuit each time it actuates. Since there is no source of direct current connected in this circuit at a time when ringing current is being applied, there is no tendency for a premature operation of the ring cut-off relay 409 due to the combined flow of direct current and alternating current, in case the called line is poorly insulated. With the ringing relay restored, the fifth code conductor, connected to the fifth contact in the banks of wiper 434, is connected to the ungrounded pole of the exchange battery as illustrated in the case of the first code conductor 433. As a result, a direct-current potential is applied to the ringing circuit each time the code ringing relay falls back and removes the ringing current. The ring-cut-off relay 409 is designed so that it does not respond to the flow of alternating current, and it is adjusted so that it does not respond to the relatively slight flow of direct current which takes place prior to the removal of the receiver in case the insulation of the called line is defective. The adjustment of the ring-cut-off relay 409 is such that in case the insulation of the called line is so defective as to bring about its premature operation, conversation on the line would practically be impossible; and the line, of course, should be repaired.
- A shunt path for ringing current exists to ground through the small ringing-tone condensers 426 and 427, by way of the right-hand repeating coil windings. The current flow through this path is limited by the small capacity of these condensers to a value suitable to send a mild ringing tone back to the calling line to inform him that the called substation is being signalled.
- When the subscriber at substation A5 responds to the ringing of his bell by removing his receiver, a direct-current bridge is placed across the conductors 203 and 204 of his line through the receiver and the secondary winding of the induction coil. This permits direct current to flow over the above-traced ringing circuit during the dialling period, resulting in the operation of ring-cut-off relay 409 by means of its lower winding. Upon operating, relay 409 closes a locking circuit for its upper winding at its inner-upper contacts to the grounded conductor 450, and at its upper and lower armatures it opens the ringing circuit and completes the talking circuit by connecting the wipers 428 and 430 to the right-hand re-

peating coil windings. Relay 409 also opens the circuit of the slow-acting relay 430 at its middle upper armature and closes a circuit for reversing relay 404 through contacts of relay 402. Relay 404 operates and reverses the connection between the inner left-hand repeating coil winding and line relay 405, thereby reversing the direction of current flow over conductors 361 and 363.

10 After a short interval relay 403 falls back and removes the shunt from around relay 400.

In the selector repeater SR2, the electro-polarized relay 308 now operates responsive to the reversing of current flow in its upper winding, caused by the operation of relay 404. Upon operating, relay 308 shunts the contacts of relay 318 at its inner armature and it operates relay 318 at its lower armature. In this way the circuits are prepared so that the selector repeater SR2 can be released when the called subscriber rings off.

Releasing the talking connection

25 Upon the termination of the ensuing conversation, the two subscribers are expected to replace their receivers, and the subscriber at the magneto substation A5 is expected to momentarily operate his hand generator to "ring off", as in standard manual telephone practice. In the present case it will be assumed that the called subscriber at substation A5 is the first to replace his receiver and that upon replacing his receiver he momentarily operates his hand generator to "ring off". When he does this, the back-bridge ring-off relay 400 of the local connector LC3 vibrates back and forth responsive to the impulses of ringing current.

30 In so doing, it closes a circuit for relay 401 from the grounded conductor 450 through contacts of the operated relay 400. Relay 401 closes a shunt at its inner lower armature around the corresponding contacts of

35 slow-acting relay 402, and at its upper armature it closes a circuit for relay 402. Relay 402 locks itself operated and at its inner lower contacts opens a point in the circuit of relay 404. Relay 404 remains operated for the time being through the inner lower contacts of relay 401.

Upon the cessation of the ringing current, relay 400 remains in normal condition and relay 401 shortly falls back. At its upper 55 armature, relay 401 opens the initial circuit of relay 402, but relay 402 remains operated by means of its locking circuit including its own upper armature. At its inner lower contacts, relay 401 opens the circuit of relay 404, whereupon relay 404 falls back and reverses the connection between line relay 405 and the incoming conductors 361 and 363 back to normal. With relay 402 locked in an operated condition and with 60 relay 401 restored, the ring-off relay 400 is

short circuited through the lower contacts of these two relays so as to prevent a re-operation of relay 404 in the case of a further application of ringing current from the called line. It may be pointed out at this time that the repeating coil at the local connector LC3 is preferably of a type which will not repeat sufficient ringing current from the calling end of the connection to bring about the operation of relay 400.

70 In the selector repeater SR2, the electro-polarized relay 308 now restores its armature on account of the fact that the current flow in its upper winding again opposes the current flow in its lower winding as a result of the above-mentioned deenergization of reversing relay 404 of the local connector LC3. As a result, the circuit of slow-acting relay 318 is opened at the lower contacts of relay 308, and the shunt is removed from the contacts of relay 318 at the inner contacts of relay 308. Relay 318 falls back again after a slight interval and recloses its contacts. This operation of relays 308 and 318 ordinarily results in the release of the connection by the removal of the ground potential from the release-trunk conductor 222. In the present case, however, this does not take place because relays 307, 306, and 305 are energized. The calling substation A6, as before explained, is so arranged that current-flow from the batteries 201 and 202 is maintaining relay 307 energized over the calling line, and relay 307 is maintaining relay 306 operated, which relay, in turn, is maintaining relay 305 operated. Ground potential, therefore, is being held on conductor 22 at the upper contacts of relay 306. Accordingly, the "ringing off" operation performed by the called subscriber has no effect in the selector repeater in the present case other than that of securing the release of relays 308 and 318.

75 90 95 100 105 110 115 120 125 130 As explained hereinbefore, the calling subscriber at a substation such as substation A5 is expected to "ring off" so as to bring about the release of the connection by the operation of relay 307 responsive to ringing current. The subscriber at substation A6, however, need only replace his receiver. When he does so, relay 307 which has been held operated over the calling line ever since the connection was made between the calling line and the selector repeater SR2, falls back and opens the circuit of relay 306. Relay 306 falls back and opens the circuit of relay 305 at its inner armature. Relay 305 is slow acting and does not fall back for an interval, during which time ground potential is removed from conductor 322, relay 306 being in its normal position with relay 305 operated. Under this condition, the upper winding of magnet 218 of the lineswitch LS3 deenergizes, permitting the armatures

216 and 217 to restore, returning the line-switch LS3 to its normal condition. Upon the restoration of armature 217, the springs 228-230 are permitted to restore and break 5 the connection between the lineswitch LS3 and the selector repeater SR2. When this connection is thus broken, spring 229 removes ground potential from conductor 223, permitting the trunk line extending to the 10 selector repeater SR2 to test idle to the master switch MS.

In the selector repeater SR2, when relay 304 falls back responsive to the removal of ground potential from conductor 223, it removes 15 ground potential at its inner upper and middle upper armatures from conductors 339 and 338. The removal of ground potential from conductor 338 opens the circuit of relay 311, permitting this relay to fall back, and the removal of ground potential from conductor 339 results in the removal of ground potential from wiper 336 and in the opening of the circuit of the polarizing winding of electro-polarized relay 20 25 308. At its inner lower armature, relay 304 disconnects the test conductor 353 accessible to the finders such as F3 of Fig. 5 from relay 309 and connects it to the local source of ground potential at its back contacts so as to maintain the selector repeater SR2 30 guarded against seizure by one of these finders after relay 312 has fallen back as a result of the deenergization of relay 311, above mentioned. At its lower armature, relay 35 304 disconnects the start conductor 350 from the lower armature of relay 303 so as to prevent an application of ground potential to the start conductor 350 as a result of relay 303 falling back when its locking circuit 40 is opened by the removal of ground potential from conductor 338 at the middle upper armature of relay 304. At its middle lower armature, relay 304 closes a circuit through off-normal contacts 328 for the release magnet 331 of the selector repeater SR2, and closes a circuit through off-normal contacts 341 of the timing switch TS (in case the timing switch TS has had time to operate) for release magnet 342. These two release magnets 45 function; magnet 342 to restore the timing switch TS, and magnet 331 to restore the selector SR2 to normal position. The circuits of the release magnets are opened by their respective associated off-normal contacts 50 upon the respective devices attaining their normal positions.

In the local connector LC3, line relay 405 falls back responsive to the disconnection of the wiper 334 and 337 of the selector repeater SR2 by relay 312 when it falls back responsive to the above-mentioned deenergization of relay 311. Upon falling back line relay 405 opens the circuit of slow-acting relay 406. This relay falls back after a slight interval and at its upper armature re-

moves ground potential from conductor 362 so as to render the local connector LC3 selectable again to selectors and to selector repeaters. At its inner upper armature, relay 406 removes ground potential from conductor 450, whereupon relays 402, 408, 409, and 412 all fall back. When relay 412 falls back it removes ground potential at its upper armature from test wiper 429, thereby permitting the upper winding of magnet 207 of the lineswitch LS4 of the called line to deenergize. The operated armature 208 falls back.

As a further result of the deenergization of relay 406, a circuit is closed through the lower contacts of relays 405 and 406 and off-normal contacts 424 for the release magnet 421. This release magnet operates and restores the connector LC3 to its normal position, whereupon off-normal contacts 424 opens the circuit of magnet 421. Also, a circuit is closed through the middle lower armature of relay 410 for release magnet 436 of the party selector PS1, whereupon magnet 436 operates and restores this party selector to its normal position, whereupon off-normal contacts 435 opens the circuit of the operated relay 410. When relay 410 restores it opens the circuit of release magnet 436 at its middle lower armature.

The connection previously established between the line of substation A6 and the line of substation A5 is now completely released and the apparatus involved therein is ready for use in setting up subsequent connections.

Timing an established connection

Since the release of a connection set up between two regular semi-automatic lines is dependent upon one or the other of the calling subscribers operating his generator to send out ringing current over his line to the exchange to operate a "ring off" relay in the selector repeater or in the connector as the case may be, it would often happen that connections would remain established and would not be released without some special provisions, as subscribers are prone to forget to "ring off". Accordingly, the selector repeater SR2 is provided with a timing switch TS which is arranged to be operated by time pulses received over conductor 349 at intervals of about one-half minute, and to release a regular connection that has been established for five minutes or thereabout. This time is perfectly arbitrary and may be lengthened or shortened, as desired. The object, of course, is not to limit the length of conversation, but rather to release connections that are not otherwise released after they have been established long enough to enable the ordinary conversation to be carried on and terminated.

When the selector repeater SR2 has been operated and the switching relay 311 has

been energized to accomplish the seizure of an idle trunk line, the time-pulse lead 349 is connected up to the operating magnet 348 at the lower contacts of relay 311. The magnet 348, therefore, responds to the impulses received over the time-pulse lead 349, advancing the wipers 344 and 345 one step for each impulse received. At the end of about four minutes, wiper 345 connects up the tick-tone lead 348 through the small associated condenser and through the shaft spring 328 and its associated contact to the upper talking conductor. The current placed on the tick-tone conductor 348 is such as to produce a mild but noticeable ticking, which will be taken by the two subscribers to mean that the connection will be released in about one minute in case they are still talking, but it does not interfere with the further carrying of the conversation.

Upon the next step of the timing switch TS the tick-tone is removed; and, upon the tenth and last of the switch, wiper 344 closes a circuit for relay 305. Accordingly, relay 305 operates and removes ground potential from conductor 322 so as to bring about the release of the connection in the manner described hereinbefore. The operation of relay 305 will, of course, be ineffective to cause the release of the connection in case the calling subscriber is one employing an instrument such as the one represented at substation A6, as in this case relay 307 is operated over the calling line and is maintaining relay 306 operated to prevent the release of the connection until the receiver is replaced at the calling substation.

40 *Call from semi-automatic substation A5 to semi-automatic substation A6*

Assuming now that the subscriber at substation A5 desires to converse with the subscriber at substation A6, the subscriber at 45 substation A5 operates his hand generator to project ringing current over the calling line, causing line relay 206 to operate and close a circuit for the operating magnet 207. Magnet 207 energizes and operates the 50 armatures 208 and 209. Armature 208 cuts off the lower winding of relay 206, and armature 209 operates the springs 210-213 (assuming the master switch to be in the 55 position shown in the drawings) to make connection with the trunk line comprising conductors 221 and 224 and extending to selector repeater SR2. Upon the seizure of the selector repeater SR2, a connection is set up to a register sender and the operator is brought into the connection in the manner hereinbefore described. When the calling subscriber gives the number of the desired substation, 2751 in the present case, and the operator sets up the digits of the 60 called number, the digits 2, 7, 5, and 1 are

retransmitted in the manner hereinbefore described. The digit 2 causes the selector repeater SR2 to raise its wipers 334-337 opposite the second level and select an idle trunk line in the usual manner, the trunk line extending to the connector LC8 of Fig. 4, for example. This connector is prepared for operation and it responds to the second and third digits 7 and 5 to extend a connection to the line of substation A6 by way of the conductors extending vertically along the extreme right-hand edge of the sheet to the line of substation A6, by way of terminals 251-253, Figs. 14 and 2. If the line is idle, the application of ground potential to wiper 429 in the manner hereinbefore described results in the operation of the magnet 218 by means of its upper winding, which is energized over conductor 214 sufficiently to operate the armature 216 to disconnect the lower winding of line relay 215. The transmission of the digit 1 results in the party selector PS1 being set on the first of its ten contacts, selecting the first of the ten codes for the signalling of the individual line substation A6.

When the subscriber at substation A6 responds, the ring-cut-off relay 409 in the local connector LC8 is operated during the silent period, upon the application of negative potential over conductor 433 and by way of wiper 434 to the called line through the ring-cut-off relay. The batteries 201 and 202 at the called substation A6 are included in the circuit of the ring-cut-off relay at this time, but they do not hinder the flow of current from the exchange battery, but rather increase it somewhat due to the fact that they are connected in the circuit in such a way as to assist rather than to oppose the flow of current from the exchange batter. Upon the operation of the ring-cut-off relay, the talking circuit is completed to the repeating coil windings and relay 403 falls back, whereupon the ring-off relay 400 is at once operated over the called line, from batteries 201 and 202 to close a circuit for relay 401. Relays 401 and 402 operate, but this does not interfere with the operation of the reversing relay 404 responsive to the operation of the middle upper armature of relay 409, because the circuit of the reversing relay 404 is maintained intact at the inner lower armature of relay 401.

When relay 404 operates and reverses the connection between the incoming conductors 361 and 363 and line relay 405, the electro-polarized relay 308 in the selector repeater SR2 operates as in the preceding connection and closes a circuit for the slow-acting relay 318. Relay 318, therefore, operates and prepares a circuit for relay 305.

In the present case, since the calling substation is not arranged to provide current for maintaining relay 307 operated during

- conversation, relays 305, 306, and 307 remain unoperated, with the result that the release of the connection is under the control of the timing switch TS, and the connection will therefore be automatically released at the end of about five minutes in case it has not been otherwise released by the time wiper 344 of the timing switch TS reaches its tenth bank contact.
- 10 Assuming that the subscriber at substation A6 replaces his receiver first at the end of the conversation and before the calling subscriber at substation A5 has replaced his receiver and "rung off", the release of 15 the "ring off" relay 400 of the local connector LC3 results in the deenergization of relay 401. With relay 401 released and with relay 402 operated and locked to conductor 450 through contacts of relay 409, 20 the circuit of reversing relay 404 is opened. Relay 404 falls back and reverses the current flow over conductors 361 and 363, whereupon the polarized relay 308 of the selector repeater SR2 falls back and closes 25 a circuit through contacts of the slow-releasing relay 318 for relay 305. Relay 305 operates and brings about the release of the connection by removing ground potential from conductor 242.
- 30 If, on the other hand, the subscriber at substation A6 does not replace his receiver until after the subscriber at substation A5 has replaced his receiver and operated his hand generator to send ringing current to 35 the exchange over the calling line, relay 307 responds to the ringing current and operates relay 306. Relay 306 makes a new application of ground potential to conductor 222 at its upper armature so as to prevent 40 a release of the connection while the ringing current is being applied, as this would result in a needless operation of the calling lineswitch. At its inner armature, relay 306 closes a circuit for relay 305. Relay 45 305, accordingly, operates preparatory to the release of the connection. Accordingly, when relay 307 ceases to vibrate in response to the ringing current and permits relay 306 to fall back, relay 306 opens the 50 circuit of the slow-to-release relay 305 and removes ground potential from conductor 222. The lineswitch LS4 accordingly releases before relay 305 can restore, and the entire connection is released as a result of 55 the removal of ground potential from conductor 223 when the lineswitch LS4 releases, the operation being the same as described hereinbefore.

60 *Clearing out false calls*

As mentioned hereinbefore, each subscriber is instructed to operate his hand generator momentarily at the end of each conversation, whether he is the calling subscriber or the called subscriber. There is

a tendency among subscribers to forget to "ring off" and the result is that in many cases neither subscriber "rings off" and the connection is released by the timer such as the timing switch TS associated with the selector repeater SR2 of Fig. 3. In other cases, one subscriber rings off in which case the connection is thereupon released in the manner hereinbefore described, while in still other cases both subscribers ring off and the results are the same as described hereinbefore in case they both ring off at about the same time. In case one subscriber delays ringing off until after the other subscriber has rung off and caused the release of the connection, the last subscriber to ring off merely operates his lineswitch in the same manner as it is operated in making a new call. The subscriber is, of course, not aware of this, and the connection is extended in the usual manner to a register sender and to the operator, who of course receives no reply when she asks for the desired number. Such occurrences are, of course, quite frequent and the operator has instructions to forthwith release the connection which has been extended to her telephone and release the seized register sender by merely operating her start key. The way in which this brings about the desired result will now be explained.

For this purpose it will be assumed that the subscriber at substation A5 has been involved in a conversation, either as a calling subscriber or as the called subscriber and that he operated his hand generator to ring off after the other party has previously rung off and brought about the release of the connection. In this case the lineswitch LS4 is operated responsive to the manipulation of the hand generator at substation A5 and it seizes an idle trunk line, the one extending to the selector repeater SR2, Fig. 3, for example. When this trunk line is seized, relay 304 in the selector repeater SR2 is operated over conductor 223 as previously described and it grounds start conductor 350 to start a finder to seek for the selector repeater SR2, the finder S3, for example. When the finder S3 connects with the selector repeater SR2, it will be recalled that relay 501 in the finder F3 operates and, among other things, ground conductor 523, operating relay 623, Fig. 6, to prepare the register sender for operation and to start the finder F4 searching for the register sender in use. When the finder F4 connects with the register sender in use, and the operator is placed in telephonic communication with the calling subscriber, the operator asks for the number but receives no answer. In this case, the operator depresses her start key ST to clear out the connection. Start key ST closes a circuit through contacts of the operated relay 621

for relay 622. When relay 622 operates, it closes a circuit at its middle lower armature through contacts of the unoperated relay 625 and contacts of the unoperated relay 624 for relay 629. Relay 629 does not operate when the start key is depressed under ordinary circumstances, because the operator has ordinarily set up the number on the registering apparatus of Fig. 7, resulting in the grounding of conductor 645 at the relays such as 701, 711, etc. to operate relay 625. With no digits set up, as in the present case, relay 625 is not operated and the circuit of relay 629 is closed as above pointed out.

Upon operating, relay 629 places a ground potential on the finder-release conductor 522 at its upper armature so as to operate relay 503 of the finder F3, and at its lower armature it extends its operating ground potential by way of impulse conductor 642 and thence by way of conductor 524 to the repeating relay 313 of the selector repeater SR2. This circuit, as previously traced, includes wiper 511 of the finder F3 and conductor 372.

When the operator releases the start key ST, relay 624, which has been connected in series with relay 622 at its inner contacts thereof, but short circuited by the initial operating ground potential, now energizes in series with relay 622 and opens the circuit of slow-acting relay 629. Opening the circuit of relay 629 at this time opens the circuit of the repeating relay 313 of the selector repeater SR2. When this occurs, relay 313 falls back, but relay 629, being slow acting, remains operated for the time being. Upon relay 313 falling back, a circuit is closed through contacts of relays 312 and 314 for vertical magnet 332, relay 314 having been operated upon the operation of relay 313. Vertical magnet 332 operates and raises the wipers of the switch one step, closing the off-normal contacts 328 and 329. Incidentally, relay 315 operates and closes a circuit through off-normal contacts 330 for relay 315, just as though the digit 1 has been received by the selector repeater SR2 in the usual manner. Repeating relay 313 does not operate again, but remains deenergized. As a result, relay 314 falls back after an interval, and at its lower armature closes a circuit from ground by way of off-normal contacts 329, through the resting contact and armature 354, for relay 305. Relay 305 operates and brings about the release of the line-switch LS4 by removing ground potential from conductor 222. Relay 304 now falls back and at its middle lower armature closes a circuit for release magnet 331, whereupon this release magnet operates and restores the selector repeater SR2 to normal. The opening of off-normal contacts 330 results in the deenergization of relay 316.

The finder F3 is cleared out in the herein-

before-described manner when the slow-acting relay 629 falls back and removes ground potential from conductor 522 and permits relay 503 to restore, the clearing-out operation being performed in the interval required for slow-acting relay 504 to fall back after its circuit is opened by relay 503.

The control of the selector-repeater finders

At this point it may be desirable to give further description of the way in which the selector-repeater finders such as F3 are controlled by the finder-control relays FCR2. It was explained hereinbefore how the finder F3 is started responsive to the grounding of conductor 350 and the consequent successive energization of relays 534 and 533. It was explained further that relay 508 is operated to disconnect the start relay 505 of finder F3 and extends the start circuit to the next finder. This, of course, does not happen until the initial starting ground potential has had time to be removed from conductor 350 so that the next finder is not started unless an additional call has come in to place a ground potential on conductor 350 at another point. It was pointed out hereinbefore that relay 508 locks itself, and that its locking current is obtained over the associated common conductor through contacts of relay 531 and resistance 535. Relay 508 opens one point in the circuit of relay 531 in the finder-control group. Relay 531 does not fall back when one point in its circuit is opened at relay 508, but it remains operated until all of the finders have been taken for use and all of the relays corresponding to 508 have become operated. At such time, the last point in the circuit of relay 531 is opened, whereupon relay 531 falls back and closes a circuit for relay 532 through resistance 535. Relay 532 operates and opens the finder starting circuit. With relay 531 restored, all of the relays such as 508 restore except those which are maintained operated by their respective upper windings on account of the continued busy condition of the respective associated finders. If all of the finders are still in use, at the time the last one is taken for use, all of the relays such as 508 remain operated, and relay 531 remains restored. However, as soon as a finder becomes idle and the relay corresponding to 508 therein falls back, a circuit is closed for relay 531, whereupon relay 531 operates and relay 532 restores. This permits the idle finder to be started upon the next application of ground potential to start conductor 350. By this locking arrangement involving relay 508 and the common relay 531, the finders are ordinarily operated one after another in regular sequence, and a finder that has been used is not again taken for use until each of the other finders has had its chance to be taken for use in the completion

of a connection to the associated register senders. Thus by this simple arrangement, the register senders all receive about the same amount of use, which is highly desirable from an operating standpoint.

It may be pointed out now that the busy-ing key 519 is operated whenever it is desired to remove the register sender shown in the drawings from regular use; for example, in case it is necessary to make repairs or adjustment. When the key 519 is operated, the closure of the upper contacts thereof completes a circuit for the upper winding of transfer relay 508, disconnecting start relay 505 and by-passing the finder F3 as regards the start circuit. At the lower contacts of the key 519, the lamp 518 is disconnected from the associated conductors 523 and is connected to ground so that it glows continuously as a reminder to the operator or to a supervisor that this one of the register senders is not available for handling calls. This is the same lamp that glows each time the register sender is taken for use and it enables the operator to observe the amount of time that a given register sender is in use.

A call between two substations on the same line

30 It will now be explained how a subscriber on a party line calls a subscriber at another substation on the same party line. For this purpose it will be assumed that the subscriber at substation A5, Figs. 1 and 2 desire 35 to converse with the subscriber at substation A4, Fig. 1, on the same party line. The substation A4 has been omitted in the circuit drawings of Fig. 2 in order to simplify the drawings. As indicated in Fig. 1, the 40 number assigned to substation A4 is the number 2322. The final digit 2 indicating that the substation A4 is the number 2 substation on the line, which may have as many as ten substations thereon. Two methods of 45 signalling from one substation to another substation on the same party line are available. One method permits the calling subscriber to operate his hand generator in accordance with the code assigned to the called 50 substation, repeating the code at intervals until the called subscriber responds or until the calling subscriber abandons the attempt. According to the other method, the calling subscriber signals the operator by operating 55 his hand generator in the usual manner, and gives the desired number to the operator who causes the central office apparatus to send back to the calling line the code of the desired substation thereon. This latter 60 method is preferable because if the former method is used, the operator is signalled each time the calling subscriber operates his generator, and has to clear out the apparatus following each application of the ring- 65 ing code to the line, resulting in more labor

on the part of the operator and much needless operation of the exchange equipment. Moreover, after the subscribers become used to hearing their codes rung from the central-office apparatus they are more likely to think well of the service than when they hear the code rung in a more or less distorted fashion by the manipulations of the hand generator by the calling subscriber. The codes assigned can very readily be rung by means of the code-ringing apparatus, but it is often difficult for a calling subscriber to manipulate his hand generator in such a way as to produce the assigned code. The latter method will now be described.

In order to initiate the call, the subscriber at substation A5 operates his hand generator momentarily and then removes the receiver. The lineswitch LS4 operates as hereinbefore described to seize an idle trunk line, for example, the trunk line comprising conductors 221-224 and extending to the selector repeater SR2, Fig. 3. When this occurs, a finder such as the finder F3 of Fig. 5 is operated to connect a register sender such as the one shown in Figs. 6 to 8 with the selector repeater SR2 of Fig. 3; and the finder F4 of Fig. 6 operates to place the operator in communication with the calling subscriber.

When asked by the operator for the desired number, the calling subscriber tells her to give him No. 2 on the same line. The subscribers ordinarily know who are the other subscribers on the same line and they know, therefore, that they cannot make a call to another subscriber on the same line in the regular way. Moreover, a subscriber can tell whether the substation of a desired subscriber is on his own line or not by merely observing whether the first three digits of a number are the same as the first three digits of his own number or not. If they are the same, the substation to which he is about to make a call is on his own line and he must tell the operator to connect him with the substation on his own line having the number indicated by the last digit of the complete number.

The operator, upon noting the request made by the calling subscriber, instructs the calling subscriber to replace his receiver while she signals the desired subscriber. The operator then sets up the ring-back number 99 on the register sender in use, followed by the suffix digit 2 indexing the called station on the calling line, following which she operates her start key ST, whereupon the register sender is started to operate in the usual manner.

When the first digit 9 is sent out by the register sender, the vertical magnet 332 of the selector repeater SR2 receives nine impulses from repeating relay 313, with the result that wipers 334-337 are raised step

by step until they come to rest opposite the ninth level of bank contacts. Relays 315 and 316 operate in the manner described hereinbefore, and relay 316 controls the 5 trunk-hunting movement after relay 315 has fallen back, causing the wipers 334-337 to be operated by rotary magnet 333 until an idle trunk line is reached; which trunk line it will be assumed is the one comprising 10 conductors 364-367 and extending to the ring-back switch RBS, Fig. 9. When this idle trunk line is reached, switching relay 311 operates as described hereinbefore and closes a circuit for the associated relay 312, 15 which operates and connects up wipers 334 and 337.

Responsive to the shaft of the selector repeater SR2 attaining the ninth level, the ninth-level spring 325 makes contact with 20 its associated grounded contact spring, operating relay 301 in series with resistance 302 to open the talking circuit and prepare the circuit over which ringing current is to be transmitted back to the calling line.

25 As a result of the seizure of the trunk line comprising conductors 364-367 and extending to the ring-back switch RBS, Fig. 9, line relay 901 therein operates over conductors 364 and 367 and through the upper 30 and lower wipers 334 and 337 of the selector repeater SR2 and through the bridge including the right-hand repeating-coil windings and the upper winding of electro-polarized relay 308. Relay 308 is not operated at this time owing to the fact that the current is flowing through the upper winding in the normal direction.

In the ring-back switch RBS, Fig. 9, line 40 relay 901 closes a circuit at its upper armature for release relay 902, whereupon release relay 902 operates and prepares the operating circuit at its upper armature, placing around potential on the release-trunk conductor 366 at its lower armature.

45 When the next digit 9 is received by the ring-back switch RBS, as transmitted by the register sender in use and repeated by repeating relay 313 of the selector repeater SR2, relay 901 deenergizes momentarily 50 nine times. Each time it deenergizes, it closes a circuit at its upper armature through the upper armature of the operated relay 902 and through contacts of relay 903 for series relay 904. Relay 904 operates responsive to the first impulse of current and 55 remains operated throughout the entire series of impulses as it is slow-releasing. At its lower armature, relay 904 connects up the slow-to-operate relay 906. As a result, 60 a circuit is closed for relay 906 at the lower contacts of relay 901 each time the line relay 901 reoperates following its first restoration. Relay 906, however, does not operate during the series of impulses as it is 65 provided with a highly inductive winding;

has a stiff adjustment; and is provided with a copper collar on the armature end, as is denoted by the shaded upper portion of the core of the relay.

When relay 901 comes to rest in an energized condition at the end of the digit, the circuit of relay 906 remains closed at the contacts of relay 901 and in series with relay 904 for a sufficient length of time to permit relay 906 to operate. Upon operating, 70 relay 906 locks itself to release-trunk conductor 366 at its lower contacts, and it extends the operating circuit to magnet 911 at its upper contacts.

When the final digit 2 is received, line 75 relay 901 deenergizes twice momentarily. Each time it does so it closes the same circuit as before for series relay 904 through contacts of the operated relay 902 and contacts of the unoperated relay 903. Relay 80 904 is accordingly maintained operated throughout the receipt of the final digit. Since relay 906 is operated at this time, the impulses pass to the operating magnet 911. The magnet 911 is accordingly actuated 85 twice and it steps the wiper 912 into engagement with the second of the associated bank contacts, selecting the second ringing lead.

At the end of the final digit, relay 904 90 falls back and closes a circuit at its inner lower contacts for relay 903 through off-normal contacts 909. Relay 903 prepares a circuit for release magnet 910 at its upper contacts; opens the operating circuit at its inner upper contacts; and at its lower contacts it closes a point in the circuit of pick-up relay 907.

As soon as the pick-up conductor 439 becomes grounded by the common-ringing apparatus, the ground potential on conductor 439 causes the operation of pick-up relay 907 through contacts of relays 903 and 907. Upon operating, pick-up relay 907 locks itself to conductor 366 and opens its own initial operating circuit, and at its upper contacts it completes the ringing circuit. Accordingly, the ringing code placed on the second of the ten code conductors associated with the ring-back switch RBS is now sent back 100 to the calling line through the second contact in the bank of wiper 912, through the said wiper, upper winding and upper contacts of ring-cut-off relay 908, contacts of pick-up relay 907, conductor 365, the corresponding ninth-level contact in the bank of wiper 335 of the selector repeater SR2 and the said wiper, working contact and upper armature of the adapting relay 301, and thence by way of conductor 221 to the called 110 line. The return circuit to ground includes conductor 204 of the called line, trunk conductor 224, and the lower armature of the operated relay 301. It will be noted that the 115 ring-off relay 307 is not actuated by the 120 125 130

ringing current sent back to the calling line on account of the fact that the front bridge of the selector repeater SR2 and including the left-hand repeating coil windings and relay 307 is disconnected and by-passed by the ringing current, which is received by the selector repeater SR2 over the fourth wiper 335 and the associated conductor as above pointed out.

- 10 When the called subscriber responds by removing his receiver, the closure of a direct-current bridge across the conductors of the line results in the operation of the ring-cut-off relay 908 from the direct-current source 75 which is connected to all of the ringing leads during the silent period as explained hereinbefore in connection with the party selector PS1 of the local connector LC3, Fig. 4. When it operates, relay 908 locks itself to 80 conductor 366 by means of its lower winding. At its upper contacts, relay 908 opens the ringing circuit, thereby terminating the ringing operation. The calling subscriber, of course, is listening to the applications of 85 the code of the called subscriber to the line, as his ringer is actuated by the ringing current, along with all the other ringers on the line. When the called subscriber notes the cessation of ringing current brought about 90 by the above-mentioned operation of the ring-cut-off relay 908 of the ring-back switch RBS when the called subscriber responds he knows that the called subscriber has answered, and he accordingly removed his receiver, whereupon the conversation may take 95 place.

The timing switch TS is started into operation in the usual manner in the course of setting up the present connection, being 100 started, of course, responsive to the closure of the connection between the time-pulse lead 349 and the operating magnet 343 at the lower contacts of switching relay 311, upon the extension of the connection to the 105 ring-back switch RBS. After the elapse of about one minute, when wiper 344 has been driven into connection with its second bank contact, ground potential is applied to the junction of the winding of relay 901 and the 110 resistance 302, shunting relay 901 to bring about its deenergization. With relay 901 thus deenergized, the upper talking conductor 221 is disconnected from wiper 335 over which the ringing current was received, and the conductors 221 and 224 are connected 115 again to the left-hand repeating-coil windings, placing the ring-off relay 307 under the control of the connected line. In case the called subscriber has not responded when 120 relay 901 is thus deenergized, the ringing operation is terminated by the restoration of relay 901 instead of by the removal of the receiver at the called substation. It has been found that in practically all cases the called 125 subscriber has already responded by this

time if he is going to answer at all. In case the calling subscriber does not receive a response from the called subscriber when he removes his receiver upon noting that the ringing has ceased, he operates his hand generator momentarily to release the connection, whereupon the connection is released in a manner to be pointed out hereinafter.

In the present case, as has been assumed hereinbefore, the called subscriber responds 75 and causes the ringing operation to be terminated in the hereinbefore described manner and the two subscribers start their conversation upon the removal of the receiver at the calling substation. The conversation 80 may continue as desired; and, when it is completed, the two subscribers replace their receivers and "ring off". When the ringing current is received responsive to the "ring-off" operation, relay 307 responds and 85 operates relay 306, causing the selector repeater SR2 and the line switch LS4 to release in the manner hereinbefore described.

When the selector repeater SR2 is released, line relay 901 of the ring-back switch 90 RBS falls back, with the result that relay 902 falls back after a slight interval and removes ground potential from release trunk conductor 366, whereupon the locked-up relays 907 and 908 restore. The release magnet 910 is operated through the contacts of the deenergized relays 901 and 902 and through contacts of the operated relay 903 to restore the mechanism to its normal position. When the normal position is reached, the off-normal contacts 909 are opened, whereupon relay 903 restores and opens the circuit of release magnet 910 at its upper contacts.

The ring-back connection is now completely released and the apparatus involved therein is restored to its normal condition.

In connection with the selector repeater SR2, it may be pointed out that the connection set up to the ring-back switch RBS is automatically released at the end of five minutes in case the subscribers have not rung off by this time to bring about the release. This is accomplished in the hereinbefore-described manner when the timing switch TS reaches its last bank contacts. The release of the connection does not interfere with the continuation of the conversation, and the two subscribers may converse with each other as long as they desire. The line, however, is unguarded by the removal of ground potential from conductor 205 when conductor 222 is ungrounded to permit the line-switch LS4 to restore. The conversation, therefore, is subject to being intruded upon by the setting up of a connection to the line from any other line. This condition is permitted because it is considered that subscribers have ordinarily finished their 130

conversation by the time the five-minute interval has elapsed.

Completing connections in exchange No. 1

5 The detailed description hereinbefore given has covered the setting up of local connections between subscribers of exchange No. 2 (see Fig. 1). The setting-up of connections between subscribers whose lines enter the exchange No. 1, EX-1, of Fig. 1 will 10 now be explained. Of the apparatus shown in Fig. 1 as belonging in exchange EX-1 and having to do with the setting-up of local connections; the lineswitches LS1 and LS2, the selector repeater SR1, and the local connectors LC1 and LC2 are similar 15 to the corresponding apparatus in the exchange EX-2 and shown in Figs. 2, 3, and 4. Accordingly, these switching devices 20 have not been illustrated in the circuit drawings, as they operate in the manner hereinbefore described in connection with the apparatus of Figs. 2 to 4. The same applies to the ring-back switch RBS-1 of 25 Fig. 1, which may be the same as the ring-back switch RBS-2 of Fig. 9, the operation of which has been hereinbefore described. The operating trunks OT1 and OT2 of Fig. 1, together with the finders F1 and F2 and 30 their associated equipment, have been shown in the circuit drawings, Fig. 11. In the following description, the operation of the apparatus of Fig. 11 and the way it cooperates with the equipment of Fig. 10 (located in exchange No. 2) to cause connections to be set up in the first exchange under the control of the apparatus of Figs. 5 to 8 will be explained. For this purpose it will be assumed that the subscriber at substation 35 A3, Fig. 1, desires to converse with the subscriber at substation A2, Fig. 1, whose number is 3687.

Call from substation A3 to substation A2

40 In order to signal the operator, the subscriber at substation A3, Fig. 1, removes his receiver and operates his hand generator in the usual manner to project ringing current over the associated line to the exchange. 45 As a result, the lineswitch LS1 operates in the manner explained in connection with the lineswitch LS4, Fig. 2, to seize an idle one of the associated selector repeaters, the selector repeater SR1, for example. When 50 the repeater SR1 is seized, the operations described in connection with the seizure of the selector repeater SR2 of Fig. 3 takes place. One of these is the grounding of the common start conductor 1118, Fig. 11, to 55 start one of the finders, either F1 or F2, to search for and connect with the selector repeater SR1 by way of conductors 1136—1138.

The finders F1 and F2 are controlled by 60 the finder-control relays FCR1, which are

similar to the finder control relays FCR2 of Fig. 5 which controls the finders such as F3. It will be assumed that the first finder F1 is idle and available for use when the call is made. In this case the transfer relay 1151 70 in the finder F1 is in the deenergized condition shown. Accordingly, when relay 1132 responds to the energization of relay 1131 over start conductor 1118 upon the seizure of the selector repeater SR1, Fig. 1, 75 relay 1132 closes a circuit through contacts of relays 1133 and 1151 for start relay 1154 of the finder F1. When relay 1154 operates, it closes a circuit at its lower armature for the upper winding of test relay 1155 in series with the operating magnet 1159. This circuit includes the lower contacts of relay 1158, the middle lower armature and its resting contact of relay 1155, lower contacts of relay 1154, upper winding of relay 80 85 1155, and the normally closed contacts controlled by armature 1174 of relay 1155. Relay 1154 also connects the junction of the upper winding of relay 1155 and the operating magnet 1159 to the test wiper 1160 90 through the resting contact and middle upper armature of relay 1155 and the upper contacts of relay 1158. As a result of this, the upper winding of relay 1155 is shunted until the conductors 1136—1138 extending to the selector repeater SR1 of Fig. 1 are reached, because ground potential is 95 encountered by wiper 1160 on all other contacts in its bank. The self-interrupting driving magnet 1159 is operated by the 100 ground potential encountered by test wiper 1160.

When the wipers 1160—1162 arrive on the contacts in which conductors 1136—1138 terminate, the operation of magnet 1159 105 ceases because direct ground potential is not encountered on conductor 1136 by wiper 1160. Also, the failure to encounter the direct ground potential on conductor 1136 by wiper 1160 results in the removal of the 110 short circuit from around the winding of relay 1155, whereupon this relay operates in series with the operating magnet 1159 over the circuit above traced for the two in 115 series. Upon operating, relay 1155 closes a locking circuit for its lower winding to the grounded conductor 1171 at its inner lower contacts; opens the circuit through the upper winding of the relay and extends the grounded conductor 1171 to relay 1153 at 120 its middle lower armature; connects up control relay 1156 at armature 1173; places a shunt around its upper winding at its inner upper contacts so as to render the relay 125 slightly slow to release; disconnects operating magnet 1159 at armature 1174 and substitutes a resistance element so as to maintain a current flow through wiper 1160 and over conductor 1136 after magnet 1159 has been disconnected; and at armature 1172 130

it shunts the upper contacts of start relay 1154 so as to maintain test wiper 1160 connected up after start relay 1154 has fallen back as it will shortly do.

- 5 As a result of the energization of relay 1153 upon the closure of its circuit from the grounding conductor 1171 at the lower armature of relay 1155, a circuit is closed for relay 1152 at the contacts of relay 1153.
- 10 The contact engaged by the armature spring of relay 1153 is a weighted contact and is arranged to vibrate for a short interval of time after it is struck by the armature, preventing the immediate operation of the relay 1152. This delay is thus provided for the purpose of enabling the start conductor 1118 to become ungrounded in selector repeater SR1 before the start circuit is transferred from the finder F1 to the finder F2.
- 15 When relay 1152 operates, it closes a circuit for the upper winding of transfer relay 1151, whereupon relay 1151 operates and closes a locking circuit through its lower winding and over the associated common conductor and through the resistance element 1135 by way of contacts of relay 1134. At its upper armature, relay 1151 disconnects the start circuit from start relay 1154 and extends it to the corresponding relay of
- 20 the finder F2, but the start conductor has already become ungrounded and relay 1154 has already fallen back responsive to the removal of ground potential in the selector repeater SR1 from conductor 1118 to allow relays 1131 and 1132 to fall back. This removal of ground potential at the selector repeater SR1 is responsive to current flow over conductor 1136 and is accomplished in the manner described in connection with the selector repeater SR2, Fig. 3, responsive to current flow over conductor 353.

When relay 1157 is connected up to the upper conductor of the operating trunk OT1 at armature 1173 of test relay 1155, a circuit is complete for relay 1157 in series with relay 1009 in the trunk circuit TR4, Fig. 10. This circuit includes the normally closed contacts controlled by the inner lower armature of relay 1001, lower contacts of relay 1004, and contacts of relay 1009. Relay 1009 energizes over the upper conductor of the operating trunk and in series with relay 1157, but relay 1157 does not operate on account of its own marginal adjustment and, on account of the relatively high resistance of relay 1009.

Upon operating, relay 1009 disconnects the test local conductor 1036 of the trunk from direct ground potential and connects it to the cut-off relay 1008 at the inner upper contacts of the relay. At its upper armature, relay 1009 closes a circuit for the busy lamp 1014 at the special operator's position; at its inner lower armature it closes a locking circuit for itself through contacts of

relay 1004, at the same time opening its initial circuit over the upper conductor of the trunk OT1; and at its lower contact it places ground on start conductor 350 through contacts of relays 1002 and 1006. Responsive to the application of ground potential to start conductor 350, the finder-control relays in the group FCR2 operate to start a finder, the finder F3, for example, searching for the calling trunk line.

When the wipers 510—512 of the finder F3 arrive on the contacts to which conductors 1035—1037 are connected, the hunting movement of the finder F3 ceases, because conductor 1036, now encountered by wiper 512, has been disconnected from the direct source of ground potential at the inner upper armature of relay 1009 and extended to the upper winding of relay 1008. Accordingly, relay 501 in the finder F3 is operated in the manner described hereinbefore. In the trunk circuit TR4 relay 1008 is operated over conductor 1036, and it places its low-resistance lower winding in shunt of the high-resistance upper winding, thereby re-establishing a guarding potential on conductor 1036. As a result of the operation of relay 1008, relays 1007, 1006, and 1005 are operated in quick succession, and relay 1006 removes ground potential from the start conductor 350.

When conductor 523 is grounded in the finder F3 at the lower contacts of test relay 501, the relay group shown in the lower portion of Fig. 6 is operated in the manner hereinbefore described to prepare for the operation of the register sender and to start the finder F4 to search for the seized register sender.

When the seized register sender is found and relay 605 in the finder F4 is operated momentarily, as hereinbefore explained, a circuit is closed momentarily over conductor 521 of the finder F3, which relay is accordingly operated momentarily. One result of the momentary operation of relay 506 is the momentary ground of test wiper 512 at the upper armature of the relay. While the test wiper 512 is momentarily grounded, cut-off relay 1008 in the trunk circuit TR4 is momentarily short-circuited and it thereupon falls back and makes a momentary application of tone current from the tone conductor 1047 to the upper one of the associated talking conductors. Relay 1008 is not deenergized long enough to permit the slow-acting relay 1007 to fall back. As a further result of the deenergization of relay 1008, a circuit is closed at its lower armature through contacts of relay 1007 for relay 1010. Relays 1010 and 1011 are successively operated.

When relay 1008 reoperates responsive to the removal of ground potential from test wiper 512 at the upper contacts of relay 130

506, when relay 506 falls back responsive to the deenergization of relay 605 in the finder F4, it again connects up its lower winding so as to reapply the guarding potential to test conductor 1036, and it disconnects the tone conductor 1047 from the upper talking conductor, thus terminating the momentary application of tone current. Relay 1008 also opens the circuit of slow-
 10 acting relay 1010 at its lower armature. Relay 1010 accordingly falls back after a slight interval and makes an additional application of tone current to the upper talking conductor during the interval required
 15 for relay 1011 to fall back after its circuit is opened at the inner contacts of relay 1010. It will thus be seen that two applications of tone current are made in quick succession to the talking circuit when the operator is
 20 placed in communication with the calling subscriber. These applications of tone current are heard by the calling subscriber and by the operator. The calling subscriber is signalled that he may now give the desired
 25 number to the operator, and the operator is informed that the call is coming from exchange No. 1 and not from exchange No. 2, there being no provision made for giving these two tone signals when the call is coming from exchange No. 2.
 30 Upon being informed that the desired number is 3687, the operator manipulates her digit keys shown at the left-hand side of Fig. 6 in accordance with the digits 3, 6, 8, and 7, causing these digits to be set up on the registering apparatus of Fig. 7.

When the operator depresses her start key and brings about the operation of relays 622 and 624 as hereinbefore described, relay 628
 40 is operated through contacts of relay 622 to place ground potential on ground conductor 522 and to close a circuit for relay 630 which operates and places ground potential on the impulse conductor 524 through contacts of
 45 the sending apparatus of Fig. 8. Responsive to the placing of ground potential on conductor 522, a circuit is closed over this conductor for relay 503 of the finder F3, which thereupon operates; and, among other things, makes an application of ground potential to the negative wiper 510 through the upper right-hand repeating coil windings, closing a circuit over conductor 1035, the upper right-hand repeating-coil winding associated with the trunk circuit TR4, contacts of the operated relay 1006, contacts of the unoperated relay 1001, the upper left-hand repeating-coil winding, the upper conductor of the trunk line OT1, and
 50 armature 1173 of relay 1155, for the control relay 1157 of the finder F1. Relay 1157 operates and closes a circuit for relay 1158 at its inner armature; shunts the lower contacts of relay 1158 at its lower armature; shunts the upper contacts of relay 1158 at
 55 its middle upper armature; and at its upper armature it makes an application of ground potential to the negative wiper 1162, thereby extending ground potential over conductor 1138 to the relay in the selector repeater SR1 of Fig. 1 which corresponds to relay 310 of the selector repeater SR2, Fig. 3. This relay in the selector repeater SR1 accordingly operates and prepares the selector repeater for operation.

As a result of the placing of ground potential on impulse conductor 524 as above pointed out, a circuit is closed through the lower right-hand winding of the repeating coil associated with the finder F3, armature 526, wiper 511, conductor 1037, lower right-hand winding of the repeating coil associated with the trunk circuit TR4, working contact and inner lower armature of relay 1006, lower left-hand repeating-coil winding, lower conductor of the operating trunk OT1, both lower windings of the repeating coil of F1, upper contacts of test relay 1155, wiper 1161, and conductor 1137 to the repeating relay in the selector repeater SR1 of Fig. 1, corresponding to repeating relay 313 of the selector repeater SR2, Fig. 3. As a result, the repeating relay of the selector repeater SR1 and the associated slow-acting relay are operated in quick succession, and the selector repeater is in readiness to respond to the impulses transmitted by the sending apparatus of Fig. 8 under the control of the registering apparatus of Fig. 7.

When the first digit 3 of the stored number 3687 is transmitted by the sending apparatus of Fig. 8, the selector repeater SR1, Fig. 1, is operated into association with the third level of bank contacts and it selects an idle trunk line leading to a connector in the third group, the local connector LC1, for example.

Responsive to the transmission of the second and third digits, 6 and 8, in the desired number, the local connector LC1 makes connection with the line of substation A2 provided the line is idle, and it sends back a busy tone to the calling line provided the line is busy. Assuming that the line is idle, the connection therewith is made, and the local connector LC1 receives the final digit 7 and operates its party selector, corresponding to the party selector PS1 of the connector LC3 of Fig. 4, to select the seventh of the associated code-ringing conductors. The code of the desired substation of the called party line is thus intermittently sent out.

In the manner described hereinbefore, the relay apparatus of Fig. 6 functions to remove ground potential from conductor 522 after all the digits of a number have been sent out and it removes ground potential from conductor 524 shortly thereafter. When ground potential is removed from con-

- ductor 522, relay 503 in the finder F3 falls back and causes the finder to be released in the hereinbefore-described manner, and it opens the circuit at its lower armature of relay 1157 of the finder F1. When relay 1157 falls back, it opens the circuit previously closed over conductor 1138 for the control relay in the selector repeater SR1, and at its middle upper armature it disconnects the test wiper 1160; it removes ground potential from conductor 1171 at its lower armature. When this occurs, test relay 1155 falls back, and likewise relays 1153 and 1152. Relay 1152 opens the circuit of the upper winding of the transfer relay 1151, so as to permit this relay to remain under the control of the finder-control relay FCR1. Relay 1157 also opens the circuit of relay 1158 which falls back after a slight interval.
- 20 In the trunk circuit TR4, cut-off relay 1008 falls back responsive to the disconnection of the test wiper 512 of the finder F3 upon the above-mentioned de-energization of relay 503. Upon falling back, relay 1008 opens the circuit of relay 1007. Relays 1007, 1006, and 1005 fall back one after the other in the order named. During the interval required for relay 1005 to fall back after its circuit is opened by the relay 1006, relay 1004 is operated to open the locking circuit of relay 1009 at its inner armature. Relay 1009 accordingly falls back and reapplies ground potential at its inner upper armature to the test lead 1036, with the hereinbefore-described results. When relay 1005 falls back it opens the circuit of relay 1004, whereupon relay 1004 falls back and the trunk circuit TR4 is in normal condition and in readiness for handling the next call.
- 40 The connection previously set up by way of the operating trunk OT1 to the sending apparatus is now completely released and the apparatus involved therein may be used in setting up subsequent connections.
- 45 In the exchange No. 1, when the subscriber at substation A2, Fig. 1, responds to the ringing of his bell by removing his receiver, the local connector LC1 functions in the manner described in connection with the local connector LC3 of Fig. 4 to remove the ringing current and to establish the talking circuit and exercise the described control over the selector repeater.
- 55 When the subscribers finish their conversation, the established connection is released in the manner described hereinbefore.
- Supervising the remote exchange No. 1*
- It is assumed that exchange No. 1 is un-
60 attended for the most part, for which reason it becomes desirable to signal an operator or other person in exchange No. 2 whenever an abnormal or trouble condition arises in exchange No. 1. The alarm circuit AC, shown in the upper left-hand corner of Fig.

11, is for the purpose of signalling the special operator, whose telephone is shown in the upper part of Fig. 10. This signalling may be accomplished over the operating trunk OT1 or over the operating trunk OT2, 70 as will now be described.

Referring particularly to the alarm circuit AC shown in the upper left-hand corner of Fig. 11, it will be assumed that an abnormal condition arises in the power board PB, used 75 to control and supply the current used in the exchange No. 1. This abnormal condition may be the "blowing" or disrupting of a fuse, or it may be the stopping of the ringing current generator, or the like. Whatever the cause, suitable arrangements are provided for making a connection from the exchange battery to conductor 1182, when an abnormal condition arises in the power board, closing a circuit through contacts of 80 relay 1104 for relay 1105. Upon operating, relay 1105 closes a circuit for relay 1106 at its lower armature. Relay 1106 operates and closes a locking circuit for itself at its lower contacts; and, at its inner upper armature, it closes a circuit for start relay 1107. At armature 1183, relay 1107 disconnects the test conductor 1113, coming from the bank of wiper 1160 of the finder F1, from ground potential directly and connects it to the stop 85 or cut-off relay 1109, and at its inner upper armature it disconnects the corresponding test conductor 1117 coming from the bank of the test wiper of the finder F2 from direct ground potential and connects it to the stop 90 or cut-off relay 1108. The alarm circuit AC is thus rendered selectable to either of the finders F1 or F2, whichever one may be started. Relay 1107 also places ground potential on start conductor 1118 at its lower 95 armature through contacts of relays 1108 and 1109. As a result, the finder control relays FCR1 operate to start one of the finders, either F1 or F2. It will be assumed that the finder F1 is started by the operation of its relay 1154 therein, as hereinbefore described.

The wipers 1160—1162 of the finder F1 are accordingly operated step by step by the buzzer-like action of magnet 1159 until these 110 wipers land upon the bank contacts in which the conductors 1111—1113 terminate. When this occurs, the hunting action of the finder F1 ceases because the direct ground potential has been removed from conductor 1113 at the armature 1183 of relay 1107. Relay 1109 operates over conductor 1113 and through test wiper 1160 and connects up its lower winding, thereby reestablishing the guarding potential on conductor 1113. At 115 its lower armature, relay 1109 removes ground potential from start conductor 1118 and replaces ground potential through the contacts of the operated relay 1107 on conductor 1117 so as to guard the alarm circuit 120 125 130

AC against subsequent seizure by the finder F2.

In the finder F1, relay 1157 is connected up to the upper conductor of the operating trunk OT1 at armature 1173 when the test relay 1155 operates, which it does at the same time that relay 1109 in the alarm circuit AC operates upon the seizure of this circuit by the finder F1. When relay 1157 is connected up, current flows over the upper conductor of the operating trunk and through contacts of relays 1001, 1004, and 1009 and the high-resistance winding of relay 1009. This is the circuit ordinarily established for the purpose of operating relay 1009 to close a start circuit at its lower contacts to start a finder such as the finder F3 into operation to make a connection with the trunk circuit TR4. It will be recalled that relay 1157 does not operate over the operating trunk at this time on account of its own marginal adjustment and the high resistance of relay 1009. It will be noted that relay 1009 is provided with a copper collar on the upper or armature end thereof, as denoted by the solid-black upper portion of the relay 4. This renders the relay slow in energizing and delays the operation for a slight interval. This delay is sufficient to permit the special operator to be signalled responsive to current flow over the lower conductor of the operating trunk and to permit the start circuit to be opened by relay 1002 before it is closed by relay 1009, as will now be explained.

In the alarm circuit AC, an additional result of the operation of relay 1009 is the placing of a ground potential, through the contacts of the operated relay 1107, on conductor 1110, and the consequent closing of a circuit over the lower conductor of the operating trunk OT1 and through contacts of relay 1006 for relay 1003. This circuit, of course, is not closed in a regular call as ground potential is not then applied to conductor 1110 in exchange No. 1. When relay 1003 operates, it closes a circuit for relay 1002 which operates and locks itself. At its lower contacts, relay 1002 disconnects ground potential from the lower armature of relay 1009 so as to prevent the application of ground potential to the start conductor 350; it applies ground potential directly to test conductor 1035 at its armature 1049, at the same time disconnecting conductor 1036 from the inner upper armature of relay 1009; it closes a lighting circuit for the busy lamp 1014 at the special operator's position at armature 1048; and at its upper armature it closes a circuit through contacts of the key 1012 for the call lamp 1013.

When the special operator notes the lighted condition of the call lamp 1013, she operates the key 1012 to the left, thereby operating the upper and lower left-hand contacts

thereof to connect the talking conductors 1031 and 1032 of her head set; to extinguish the call lamp 1013; to apply ground potential to the circuit-adapting conductor 1033; and to close a circuit for relay 1001. Relay 1001 operates and locks itself to the upper right-hand contacts of the key 1012; it completes the talking circuit from the operator's telephone through contacts of the key 1012 to the talking conductors of the trunk circuit TR4 at its upper and lower armatures; and at its inner lower armature it applies ground potential to the upper conductor of the operating trunk OT1, closing an energizing circuit over this conductor and through armature 1173 for relay 1157. Relay 1157 operates and brings about the operation of the associated slow-acting relay 1158 as before described, and it applies ground potential to wiper 1162 at its upper armature by way of the upper left-hand repeating coil winding. This closes a circuit over wiper 1162 and by way of conductor 1111 for relay 1185. Relay 1185 operates and closes a circuit for relay 1186, whereupon relay 1186 operates and prepares a circuit for relay 1104 which will be closed when the operator clears out the connection to her position.

The special operator is now telephonically connected to the operating trunk OT1, and she hears the tone produced by the connection of the generator lead 1102 through the contacts of the operated relay 1105 to conductor 1112, conductor 1112 being an extension of the lower conductor of the operator trunk OT1 through the repeating-coil windings of the finder F1. The operator makes a note of the character of the signal heard and gives the note to the proper person of authority, who at once knows that the signal heard by the operator indicates that there is an abnormal condition existing at the power board in exchange No. 1.

In order to clear out the connections established to her telephone over the operating trunk OT1, the operator manipulates the key 1012 to its opposite position, permitting the left-hand contacts of the key to restore, and operating the right-hand contacts of the key. When the upper right-hand spring of the key 1012 is shifted to its alternate position, the locking circuit of relays 1001 and 1002 is opened, whereupon both these relays fall back. At the same time, a circuit is closed for relay 1004, which operates and opens the circuit of relay 1009, permitting this relay to fall back also. The only other operated relay of the trunk circuit TR4 is relay 1003. The operator holds the key 1012 in this position momentarily to allow the connection to clear out.

When relay 1001 falls back, it disconnects ground potential from the upper conductor of the operating trunk OT1, permitting re-

lays 1157 and 1158 in the finder F1 to fall back one after the other and to clear out this finder in the manner described hereinbefore. At its upper armature relay 1157 disconnects ground potential from wiper 1162, thereby opening the circuit of relay 1185. Relays 1185 and 1186 accordingly fall back in succession. Relay 1186 is slightly slow in falling back; and, while it remains operated, a momentary circuit is closed through the contacts of the two relays for relay 1104. Relay 1104 operates and opens the locking circuit of relay 1106 at its middle lower armature, while at its upper armature it disconnects conductor 1182 from relay 1105 and closes a locking circuit for its own upper winding over conductor 1182. Relay 1105 now falls back and opens the initial circuit of relay 1106 at its lower armature, whereupon relay 1106 falls back and permits relay 1107 to fall back. Relay 1107 disconnects conductor 1113 from relay 1109 and connects it to ground potential directly, permitting relay 1109 to fall back. As soon as relay 1107 falls back, the ground potential is disconnected from conductor 1110 and consequently from the lower conductor of the operating trunk OT1, and relay 1003 in the trunk circuit TR4, Fig. 10, falls back. Accordingly, the operator may now restore her key 1012 without relay 1002 operating.

As long as the abnormal condition consists in the power board PB, Fig. 11, the battery potential remains connected to conductor 1182 and relay 1104 remains operated. A repairman is, of course, dispatched to the exchange No. 1 to make the necessary repairs, whereupon the potential is removed from conductor 1182 and relay 1104 falls back, conditioning the alarm circuit AC to respond again whenever another alarm condition exists.

Handling an all-trunks-busy condition in the remote exchange

When all of the trunks extending to the group of selector repeaters including the selector repeater SR1, Figs. 1 and 11, become busy, the conductor 1181, common to all of the selector repeaters accessible from the same group of lineswitches, becomes ungrounded. This conductor, it may be pointed out, corresponds to conductor 226 associated with the selector repeaters such as SR2, Fig. 3. When conductor 1181 becomes ungrounded on account of the fact that all of the associated selector repeaters are busy, relay 1103 falls back and closes a circuit for start relay 1106 at its lower armature, at the same time preparing a locking circuit for relay 1104 at its inner lower armature, and connecting the busy-tone conductor 1101 at its upper armature to conductor 1112 through contacts of relay 1105. Responsive to the energization of relay 1106,

either the finder F1 or the finder F2 is operated to make connection with the alarm circuit AC, either over conductors 1110 to 1113 or by way of conductors 1114 to 1117, as the case may be. At either case, the special operator whose telephone is shown in Fig. 10 is signalled in the manner hereinbefore described. Under the present conditions, with relay 1103 deenergized, it is a busy tone which is heard by the special operator rather than the tone produced by the ringing current from the generator lead 1102. The special operator accordingly makes a note of the different character of the tone heard and causes the connection to be cleared out in the hereinbefore-described manner.

When the impulse is delivered from relays 1185 and 1186 when the connection is being cleared out, relay 1104 operates as before and locks itself to ground at the inner lower armature of the now-deenergized relay 1103, at the same time opening both the initial circuit and the locking circuit of relay 1106.

Relay 1103 is again energized as soon as one of the selector repeaters such as SR1 becomes idle; and, when it reoperates, it opens the locking circuit of relay 1104, and this relay falls back to condition the alarm circuit AC for further operation. The special operator, however, has been signalled that the busy condition existed and a proper record may therefore be kept of the number of times that all the trunks in a group become busy.

It will be understood, of course, that other relays, such as 1103, may be provided for other groups of selector repeaters in the No. 1 exchange, and that additional relays may be provided for additional abnormal conditions.

Setting up a toll connection from a line in exchange 2 to a line in exchange 1

The exchanges 1 and 2 are assumed to be far enough apart to justify the making of a toll charge for interexchange connections. Accordingly, calls from one exchange to the other are handled by a toll operator at the toll board shown in the lower right-hand corner of Fig. 1. For the purpose of describing how a connection is set up from a line in exchange 2 to a line in exchange 1, it will be assumed that the subscriber at substation A5, Figs. 1 and 2, desires to converse with the subscriber at substation A3, Fig. 1.

In order to initiate the call, the subscriber at substation A5 removes his receiver and operates his hand generator in the usual manner, causing the lineswitch LS4, Fig. 2, to operate and seize an idle selector repeater, the selector repeater SR2, Fig. 3, for example. Responsive to the seizure of the selector repeater SR2, a connection is extend-

ed from this selector repeater to sending apparatus such as that shown in Figs. 6 to 8; and a connection is made by means of the finder F4, Fig. 6, to the seized register sender, and the operator is placed in communication with the calling subscriber. The calling subscriber asks for the long distance operator, whereupon the regular traffic operator whose telephone is shown in Fig. 6, sets up the digit 0 on the connected registering apparatus and then depresses her start key ST, disconnecting her telephone from the calling line and starting the sending apparatus to retransmit the digit 0 to the selector repeater SR2.

Responsive to the ten impulses in the digit 0, the selector repeater SR2 raises its wipers 334-337 opposite the tenth level of bank contacts and selects an idle trunk line extending to the toll board, the trunk line comprising conductors 368-370, for example, extending to the jack J1 at the toll board by way of the trunk circuit TR1, Fig. 18. When this trunk circuit is seized line relay 1356 therein, which is bridged across conductors 368 and 370 in series with the exchange battery and through contacts of reversing relay 1355, energizes over conductors 368 and 370; through wipers 334 and 337 and in series with the upper winding of the electro-polarized relay 308. Relay 308 is not operated at this time as the current flow in its upper winding is in the normal direction, opposed to the current flow in the lower winding.

When relay 1356 operates, it closes a circuit through contacts of relay 1354 for the call lamp 1351 in front of the toll operator. This lamp becomes lighted to signal the operator. At its upper armature, relay 1356 connects the source of interrupted generator, or ringing current, represented by conductor 1358 to the talking conductor 368, the connection being made by way of the associated limiting condenser. As a result, the calling subscriber hears an intermittent signal indicating that the toll operator is being signalled.

In the selector repeater SR2, the 0-level shaft springs 326 open the connection between the release relay 305 and the bank of the timing switch TS so as to prevent the release of the selector repeater by means of the timing switch; the shaft spring 328 which is operated on the ninth and tenth levels, disconnects the wiper 345 so as to prevent the warning signal from being given through wiper 345 and the eighth contact in the bank timing switch TS; and shaft spring 327, which is operated on the 0 level, disconnects the working contact of the armature of the "ring off" relay 307 from the associated release control relay 306 and connects it to the extra-control (EC) wiper 335 so as to permit the relaying of super-

vision to the operator, as will be hereinafter explained.

It will be noted that the selector repeater SR2 cannot now be released by the calling subscriber on account of the shifting of the circuit associated with the working contact of the armature of ring-off relay 307. In case all trunks to the toll board should be busy, however, the overflow contacts 306 reconnect the contact of the armature of relay 307 to relay 306 so as to permit the selector repeater SR2 to be released when the subscriber rings off. At the same time, it may be pointed out, the overflow contacts 322 and 323 close a circuit for applying busy tone to the calling line from the busy-tone lead 346. In the present case, however, it is assumed that an idle trunk line is found and that the connection is set up to the toll board over conductors 368, 369, and 370 by way of the trunk circuit TR1, as before explained.

When the operator observes the lighted condition of the call lamp 1351 associated with the jack J1, she responds by inserting the answering plug of an idle cord circuit of the type disclosed in the patent to Crocker #1,771,842, granted July 29, 1930. When the answering plug enters the jack J1, the upper spring-contacts of the jack J1 are pressed together by the movement of the tip spring of the jack, closing a circuit for relay 1355. Relay 1355 operates relay 1354 at its inner lower armature. Relay 1354 disconnects lamp 1351 at its upper armature and closes a locking circuit for itself, and it disconnects the ringing-tone conductor 1358 at its lower armature. Relay 1355 also reverses the connections between the windings of line relay 1356 and the trunk conductors 370 and 368. This results in a reversal of the current flow in the back bridge of the selector repeater SR2 and the consequent operation of the electro-polarized relay 309, to operate the associated slow-acting relay 318.

The toll operator now converses with the calling subscriber, and ascertains the destination of the call.

Upon learning that the desired subscriber is the one at substation A3, Fig. 1, whose number is 4581, and whose line terminates in the first exchange, the operator inserts the calling plug of the cord circuit into the jack of an idle toll trunk extending from her switchboard to the No. 1 exchange, the jack J3 of the toll trunk TT, Fig. 12, for example. The idle condition of the toll trunk TT is indicated by the nonoperated condition of the electromagnetic busy signal 1201.

When the plug is fully inserted into the jack J3, the upper contacts of the jack place ground potential on conductor 1272, and this ground potential is extended through 130

the contacts of relay 1207 to conductor 1273. The busy signal 1201 and its multiples are operated over conductor 1273, and cut-off relay 1210 is operated to disconnect the upper winding of the ring-up relay 1211 from across the conductors of the trunk. With ground potential on conductor 1273, a circuit exists for the upper and lower windings of the sleeve relay 1203 in series, through the contacts of relay 1201 and to battery by way of the sleeve of the jack J3 and the sleeve circuit of the plug inserted therein. Relay 1203 operates and prepares a circuit for relay 1205 at its inner upper armature, and at its upper and lower armatures it shifts the upper conductor of the toll trunk TT from the tip spring of the jack J3 to the upper left-hand repeating-coil terminal, and shifts the ring contact of the jack J3 from the lower conductor of the toll trunk TT to the lower right-hand repeating-coil terminal, thus placing the trunk circuit TR3 in regular talking condition. When this occurs, the line relay (not shown) of the toll selector TS, Figs. 12 and 1, whose windings are bridged across the incoming conductors of the toll selector TS in series with the exchange battery at the No. 1 exchange, energizes over the two conductors of the toll trunk TT, and through the left-hand repeating-coil windings of the trunk circuit TR3, in series with the polarized relay 1209. Relay 1209 does not operate at this time, because the current-flow is in the normal direction, whereas the relay operates only when the current-flow is in the reverse direction.

The toll selector TS is prepared for operation in the usual manner responsive to the above-mentioned energization of its line relay. The release relay 1271 is energized responsive to the energization of the line relay, and it places ground potential on the associated release trunk conductor 1247, thereby guarding the toll trunk TT from seizure in exchange No. 1 by the selector repeaters, such as the selector repeater SR1.

After inserting the calling plug of her cord circuit into the jack J3 and bringing about the above-described operation, the toll operator proceeds to dial the digits 4, 5, 8, and 1 in the number of the substation A3. Each time the operator's calling device (shown in the Crocker Patent 1,771,842, hereinbefore referred to) is turned from its normal position in the dialling of a digit of the desired number, the battery potential is removed from the sleeve conductor of the calling plug of the cord and consequently from the sleeve of jack J3 in which this plug is now inserted, resulting in the deenergization of sleeve relay 1203. Upon deenergizing and falling back, the sleeve relay 1203 shifts the conductors of the toll trunk TT from the bridge including the

left-hand repeating coil windings to the tip and ring conductors of the jack J3, thus extending these conductors back to the calling device associated with the operator's cord circuit, whereat these conductors are connected together through the impulse contacts of the calling device. Accordingly, upon the return movement of the calling device, the line relay (not shown) of the toll selector TS responds to the impulses of the first digit 4 of the desired number, and it causes the toll selector TS to raise its wipers step by step until they come to rest opposite the fourth level of bank contacts, whereupon the wipers are rotated over the bank contacts in the fourth level in search of an idle trunk line. It may be assumed that the first trunk line found to be idle is the one extending to the toll connector TC2, Fig. 1. Accordingly, this toll connector, which is similar to the toll connector TC3, Fig. 14, to be subsequently described in detail, is prepared for operation in the regular manner.

Following the dialling of each digit, the battery potential is reapplied to the sleeve terminal of the jack J3 over the sleeve conductor of the cord circuit in use, resulting in the reoperation of relay 1201 to shift the control circuit back to the bridge including the left-hand repeating-coil windings and relay 1209.

Responsive to the dialling of the second and third digits 5 and 8 in the desired number, the toll connector TC2, Fig. 1, raises its wipers opposite the fifth level of bank contacts and rotates them into engagement with the eighth set of contacts in the fifth level, thereby making a connection with the line of substation A3. This line is then tested and connection is made thereto if it is found to be idle, otherwise, a busy tone is returned, as will be explained in connection with the toll connector TC3.

If the line is found to be idle, the dialling of the last digit 1 in the number operates the party-selecting device associated with the toll connector TC2 to enable the toll connector to signal the subscriber at substation A3. At this time, the toll connector TC3 reverses the current flow over its incoming conductors, reversing the current flow back through the toll selector TS, Figs. 1 and 14, to the trunk circuit TR3. When this occurs, the polarized relay 1209 in the trunk circuit TR3 operates and closes a circuit through the contacts of sleeve relay 1203 for relays 1205 and 1204. Relay 1204 locks itself to conductor 1273 at its inner upper contacts, at the same time opening its initial circuit. At its lower armature, relay 1204 closes a local circuit for the upper winding of relay 1203 and disconnects the lower winding of relay 1203 from the upper winding. Relay 1203 is thus maintained

operated through resistance 1212 independent of the further current flow over the sleeve circuit. Relay 1205 places ground on the sleeve of the jack J3 at its lower armature through the low-resistance lower winding of relay 1203, thereby increasing the current flow over the sleeve circuit sufficient to give appropriate supervision to the operator, indicating to her that the called line is idle and has been seized.

When the operator desires to start the application of ringing current to the called line from the connector TC2, she operates the ringing key (not shown) in the calling end of her cord circuit, projecting ringing current through the tip and ring conductors of the jack J3 to the ringing-response relay 1206. The upper portion of the core of relay 1206 is split into two sections, and one section is provided with a shading coil, enabling the armature of the relay to remain attracted continuously while the winding of the relay is being supplied with alternating current. Upon operating, relay 1206 applies ground potential to the upper conductor of the toll trunk TT through contacts of relay 1204, unbalancing the current flow over the trunk line momentarily, which results in the starting of the application of ringing current to the called line. Relay 1206 falls back when the flow of ringing current from the cord circuit stops, and the trunkline balance is restored. Having once been started, however, the application of ringing current by the toll connector continues until the called subscriber responds, as will be explained hereinafter in connection with the toll connector TC3.

When the called subscriber responds by removing his receiver, the ringing current is cut off, and this direction of the current flow over the toll trunk TT is reversed back to normal, whereupon the polarized relay 1209 restores and opens the circuit of relay 1205. Relay 1205 falls back and terminates the flow of current over the sleeve circuit through the lower winding of relay 1203, giving the operator answered supervision in her cord circuit.

The conversation may now take place between the calling subscriber at substation A5, Figs. 2 and 1, and the called subscriber at substation A3, Fig. 1, the complete connection including the lineswitch LS4, the selector repeater SR2, the trunk circuit TR1 and the jack J1, a cord circuit at the toll board, the jack J3 and the trunk circuit TR3, the toll trunk TT, the toll selector TS, and the toll connector TC2.

After the conversation is completed, the two subscribers replace their receivers and ring off. When the subscriber at the called substation A3 of Fig. 1 rings off, the toll connector TC2 causes the current flow in its incoming conductors to be reversed back to

normal, bringing about the reoperation of the polarized relay 1209 to again operate relay 1205 for the purpose of again setting up a current flow over the sleeve circuit through the low-resistance lower winding of relay 1203 to give the operator disconnect supervision in the calling end of her cord circuit.

When the calling subscriber at substation A5, Fig. 2, rings off, relay 307, Fig. 3, closes a circuit through the 0-level shaft spring 327 and its right-hand contact, by way of wiper 335 and the bank contact on which it is standing, and conductor 369, for relay 1353 in the trunk circuit TR1, Fig. 13. Relay 1353 is provided with a copper collar around its core, and its winding is shunted, thus enabling the relay to operate and remain operated while its circuit is being intermittently closed by the ring-off relay 307, Fig. 3, responsive to the pulsations of ringing current. Upon operating, relay 1353 closes a circuit for relay 1352, which operates and projects ringing current from the exchange generator through the common limiting retardation coil, associated with common conductor 1357 into the operator's cord circuit. This operates a bridge alternating-current relay in the operator's cord circuit to bring about the operation of an associated relay which operates and remains operated to give the operator a disconnect signal on the answering end of her cord circuit.

When the operator notes the two disconnect signals, she takes down the connection by removing the plugs of her cord circuit from the jacks J3 and J1 of Figs. 12 and 13, respectively. When the plug is removed from the jack J3, ground potential is removed at the upper contacts of the jack from conductors 1272 and 1273, whereupon the electromagnetic busy signal 1201 and its multiplied signals restore, and the relays 1204 and 1203 fall back. With the plug removed from the jack J3, and with relay 1203 deenergized, there is no holding bridge across the conductors of the toll trunk TT, and the toll connector to which the connection was extended by the toll selector TS, releases and removes ground potential from its release trunk conductor, permitting the toll selector TS to release.

Relay 1209 in the trunk circuit TR3 falls back and opens the circuit of relay 305. After an interval of sufficient length to permit the release of the distant switches, slow-releasing cut-off relay 1210 falls back, and again connects up the upper winding of ring-up relay 1211. By this time the transient voltages have disappeared from the trunk line conductors, and relay 1211, does not, therefore, operate falsely.

The connection previously set up from the

toll board to the called line is now completely released.

Responsive to the removal of the plug from the jack J1, the circuit of relay 1355 is opened at the upper contacts of the jack whereupon relay 1355 falls back and reverses the current flow in conductors 368 and 370 to its normal direction. When this occurs, the electro-polarized relay 308 in the selector repeater SR2, Fig. 3, restores and closes a circuit through contacts of the slow-releasing relay 318 for the release relay 305. Relay 305 operates momentarily and brings about the release of the connection by removing ground potential from conductor 222 to allow the lineswitch LS4 to fall back and remove ground potential from conductor 223. The selector repeater SR2 releases responsive to the deenergization of relay 304 when ground potential is removed from conductor 223, whereupon relays 1356 and 1354, Fig. 13, fall back.

The entire connection set up between the calling and called lines is now released and the apparatus involved therein is in readiness to be used in setting up subsequent connections.

Calling from exchange No. 1 to exchange No. 2

The operations involved in setting up a connection from a line in exchange No. 1 to a line in exchange No. 2 by way of a toll trunk, such as the toll trunk TT of Figs. 1 and 12, will now be explained. For this purpose, it will be assumed that the subscriber at substation A3, Fig. 1, desires to converse with the subscriber at substation A5 in exchange 2, Figs. 1 and 2. In order to initiate the call, the subscriber at substation A3 projects ringing current over his line to signal the operator and removes his receiver and awaits her relay. It may be assumed that the selector repeater SR1, Fig. 1, is seized by the lineswitch LS1; that the finder F1 connects the operating trunk OT1 to the selector repeater SR1; and that the finder F3 connects the sending apparatus of Figs. 6 to 8 to the operating trunk OT1 by way of the trunk circuit TR4, Fig. 10. When this connection is completed through the finder F4, Fig. 6, the calling subscriber and the operator are in telephonic communication with each other, and the calling subscriber asks for "long distance". The operator sets up the digit 0 on the sending apparatus, with the result that the selector repeater SR1, Figs. 1 and 12, is operated into association with the tenth level of bank contacts and rotates its wipers over these bank contacts in search of an idle trunk line. The selector repeater SR1 is indicated by a rectangle in Fig. 12, together with its wipers and one set of bank contacts in the tenth level, contacts 1241-1244 associated with

the toll trunk TT. It will be assumed that the toll trunk TT is the first one found to be idle and is consequently seized. Connection is therefore made with the toll trunk by way of the ringing repeater RR through bank contacts 1241-1244 and conductors 1245-1248.

Upon the seizure of the toll trunk TT, ground potential is applied to the release trunk conductor 1247 through bank contacts 1243 by way of the control (C) wiper of the selector repeater SR1, corresponding to wiper 336 of the selector repeater SR2. This is the usual application of ground potential to render the trunk line busy to the other selector repeaters. The application of ground potential to conductor 1247 at this time results in the closure of a circuit through contacts of relay 1271 of the toll selector TS, and through other contacts of the switching relay (not shown) of the toll selector for relay 1251, by way of contacts of relay 1249 of the ringing repeater RR. Relay 1251 is accordingly operated to apply ringing current over the toll trunk TT to the trunk circuit TR3.

At its inner lower armature, relay 1251 closes a circuit for the weighted spring relay 1250. Relay 1250 accordingly operates and closes a circuit for relay 1249. Relay 1249 has a rather stiff adjustment and it accordingly does not operate until the weighted spring of relay 1250 ceases to vibrate. When this occurs, after about a second, relay 1249 operates and opens the circuit of relay 1251 and locks itself to conductor 1247. The slow-acting relay 1251 falls back after a slight interval and terminates the application of ringing current to the conductors of the toll trunk TT. Relay 1250 now falls back.

In the trunk circuit TR3, the ring up relay 1211, whose upper winding is normally connected across the conductors of the toll trunk TT through contacts of cut-off relay 1210 and through the associated condenser operates responsive to the ringing current and closes a locking circuit for its lower winding at its lower contacts, through contacts of relay 1207. At its upper contacts, relay 1211 prepares a circuit for relay 1208. The call lamp 1202 becomes lighted in multiple with the lower winding of relay 1211.

When the operator notes the lighting condition of the call lamp 1202, she inserts the answering plug of an idle cord circuit into the jack J3, thereby placing ground potential on conductors 1272 and 1273 with results hereinbefore described, including the operation of cut-off relay 1210. In addition, a circuit is closed from the grounded conductor 1272 through the upper contacts of relay 1211 for relay 1208. Relay 1208 closes a self-locking circuit at its upper contacts, and

at its middle upper armature and lower armature prepares to set up a reversed current-flow over the conductors of the toll trunk TT. At its inner upper armature, relay 1208 closes a circuit for relay 1207. Relay 1207 operates and disconnects the polarized relay 1209 at its inner armatures, at the same time connecting ground potential through its inner upper armature and the operated middle upper armature of relay 1208 to the upper conductor of the toll trunk TT by way of the upper left-hand repeating-coil winding and the upper contacts of the operated relay 1208, and connecting battery potential at its inner lower armature through the lower armature of the operated relay 1208 to the lower conductor of the trunk TT, by way of the lower left-hand repeating-coil winding. Current now flows over the conductors of the toll trunk TT in reversed direction, operating the electro-polarized relay in the selector repeater SR1, which corresponds to relay 308 in the selector repeater SR2, Fig. 3. The selector repeater SR1 is thus placed in condition to be released when the direction of the current flow is subsequently reversed upon the taking down of the connection.

The operator now converses with the calling subscriber. Upon learning that it is the subscriber at substation A5 with whom conversation is desired, the operator inserts the calling plug of the cord circuit into the jack of an idle toll-service trunk line, the jack J2, Fig. 13, for example, and she then proceeds to dial the necessary digits.

When the plug is inserted into the jack J2, the upper contacts of the jack apply ground potential to the upper terminal of sleeve relay 1302, and close a circuit for the electromagnetic signal 1301 and its multiples at the other positions. Sleeve relay 1302 is operated by current flow over the sleeve circuit, as explained in connection with sleeve relay 1208 associated with the jack J3. With relay 1302 operated, the right-hand repeating-coil windings are bridged across the conductors 1307 and 1308, and the tip and ring conductors of the jack J2 are extended to the left-hand repeating-coil windings. Current now flows over conductors 1307 and 1308 and through the polarized relay 1306, but relay 1306 is not operated by the current flow in its normal direction.

In the toll connector TC3, Fig. 14, conductor 1308 is connected to ground potential through the lower left-hand repeating-coil winding, and contacts controlled by the middle lower armature of relay 1402; and conductor 1307 is connected to the ungrounded pole of the exchange battery by way of the upper left-hand repeating-coil winding, upper armature and resting contact of the reversing relay 1403, upper contacts of relay

1402, and the upper winding of line relay 1405. Line relay 1405 accordingly energizes over conductors 1307 and 1308. Upon energizing, line relay 1405 closes a circuit for release relay 1406. Relay 1406 prepares the operating circuit at its lower armature, and at its upper armature it applies ground potential to release trunk conductor 1438. Conductor 1438 is terminated in this case at the terminal shown to the left, and is not included in the trunk line comprising conductors 1307 and 1308, but is included in the incoming trunk line when this switch is used following a toll selector, as in the case of the toll connectors TC1 and TC2 in exchange No. 1, Fig. 1.

The calling operator now turns her calling device off-normal in the dialling of the second digit 3 in the desired number (the first digit 3 is eliminated because the operator selects the toll connector TC3 directly by plugging in). The sleeve relay 1302 in the trunk circuit TR2 is deenergized in the usual manner by the cessation of current flow over the sleeve circuit, whereupon the conductors 1307 and 1308 are extended back into the operator's calling device associated with her cord circuit, bringing the line relay 1405 of the toll connector TC3 under the control of the operator's calling device. As the calling device rotates back to its normal position, the control circuit including conductors 1307 and 1308 is interrupted three times at the calling device as illustrated and described in the Crocker patent hereinbefore referred to. Accordingly, line relay 1405 of the toll connector TC3 de-energizes three times momentarily. Each time it does so, it closes a circuit through the lower armature of the operated release relay 1406 and through off-normal contacts 1418 for vertical magnet 1424, by way of series relay 1407. The vertical magnet is thus operated three times to step the wipers 1431-1433 opposite the third level of bank contacts. Relay 1403 operates responsive to the first impulse of current and remains operated throughout the series of impulses, shifting the operating circuit so as to maintain its own circuit and the circuit of magnet 1424 intact after the off-normal springs 1418 have shifted, upon the initial movement of the switch.

At the end of the digit, relay 1407 falls back and shifts the operating circuit from vertical magnet 1424 to rotary magnet 1419 by way of contacts of relays 1413 and 1415.

When the next digit 2 (the third digit of the number) is dialled, line relay 1405 de-energizes twice momentarily, closing the circuit of rotary magnet 1419 twice. By the operation of magnet 1419, the wipers 1431-1433 are rotated into engagement with the set of bank contacts connected with the vertical conductors leading to terminals

254—256, individual to the line of substation A5, Fig. 2. Slow-releasing relay 1414 is energized in multiple with rotary magnet 1419 and it remains operated throughout the 5 digit. In addition to shifting the test wiper 1432 into association with busy relay 1413 at its inner upper armature, and shunting contacts of busy relay 1413 at its lower armature, relay 1414 closes a circuit at its upper 10 armature for relay 1411, with the result that relay 1411 operates and remains operated as long as relay 1414 is operated. At its upper armature, relay 1411 opens a point in the circuit of relay 1402, and at its inner 15 armature it closes a circuit for relay 1410, which operates from the grounded conductor 1438 through contacts of relay 1404 and closes at its inner upper armature a locking circuit for itself so that it remains 20 operated after relay 1411 has fallen back and prevents the starting of the ringing operation until the operator causes it to become deenergized, as will be hereinafter pointed out.

25 The operations taking place at the end of the dialling of the third digit 2 in the desired number depend upon whether the called line is busy or idle. If this line is busy, the test conductor thereof is grounded, 30 and busy relay 1413 is energized through the test wiper 1432 by way of contacts of the unenergized relay 1415 and contacts of the energized relay 1414, when the wipers come to rest on the bank contacts of the 35 called line. In this case, when relay 1414 falls back, the busy relay 1413 becomes locked to the grounded conductor 1438 through its own inner upper armature and contacts controlled by the inner upper armature of relay 40 1414. Relay 1411 falls back when relay 1414 does, and it opens the initial circuit of relay 1410, but relay 1410 remains operated over its locking circuit closed at its inner upper contacts.

45 With relay 1413 locked operated, and with relay 1414 in a deenergized condition, the operating circuit is open at the inner lower armature of relay 1413. A circuit is closed at the upper contacts of relay 1413, and 50 through contacts of relay 1412 and 1411, for the upper winding of relay 1402, this circuit becoming closed upon the falling back of relay 1411 at the end of the digit. When this circuit is closed, relay 1402 operates and closes a locking circuit for its lower winding to the grounded conductor 1438 at its inner lower armature. At its lower armature, relay 1402 disconnects conductor 1308 from ground at the contacts of 55 relay 1402, and extends it through the lower armature of reversing relay 1403 and its resting contact, to ground by way of the lower windings of relays 1404 and 1405. At the same time, relay 1402 removes the shunt 60 at its upper armature from around the upper winding of differential relay 1404, so as to permit current to flow in the upper winding and balance the current-flow in the lower winding so as to prevent operation of relay 1404 at the present time. In addition, relay 1402 closes a circuit at its inner upper armature for reversing relay 1403, whereupon reversing relay 1403 operates and reverses the connection between the windings of differential relay 1404 and conductors 1307 and 1308. When this occurs, 70 the current flow is reversed over conductors 1307 and 1308, permitting the polarized relay 1306 to operate in the trunk circuit TR2. Upon operating, relay 1306 closes a circuit 80 for relays 1303 and 1304. Relay 1303 locks itself to ground by way of the upper contacts of the jack J2 at its inner upper armature, and at its lower armature it closes a holding circuit for the sleeve relay 1302 by 85 way of its upper winding and through resistance 1309, at the same time opening the connection between the two windings of the relay. Relay 1304 makes an application of ground potential to the sleeve of the jack J2 90 by way of the low-resistance lower winding, thereby increasing the current flow over the sleeve circuit sufficiently to give the operator supervision, as may be learned upon reference to the Crocker Patent 1,771,842, herein- 95 before referred to.

95 In the connector TC3, as a further result of the deenergization of relay 1411 at the end of the digit, and depending upon relay 1413 being operated and locked, the busy tone is applied from the busy tone transformer 1436 by way of lead 1434, to the lower talking conductor through contacts of the relays 1411, 1413, and 1415. The busy tone may accordingly be heard by the calling operator.

100 It will be noted that the busy-tone current is supplied from ground by way of the secondary winding of the busy-tone transformer 1436 to the common conductor 1434 105 by way of the condenser 1437, this condenser being of a relatively high capacity. The condenser 1437 is intermittently shunted by the interrupter 1435, at a rate of about 120 times a minute. Each time the condenser 110 is shunted, ground potential is applied to conductor 1434, closing a circuit through contacts of relays 1411, 1413, and 1415 to the lower talking conductor and thence by way of the lower armature of the operated relay 1410, the lower right-hand repeating-coil winding, relay 1401, upper right-hand repeating-coil winding, upper armature of relay 1410, and the upper armature of relay 1415 and its resting contact, to battery by 115 way of the associated resistance. Relay 1401 is accordingly energized over this circuit each time the interrupter 1435 closes. Each time relay 1401 operates it closes a circuit 120 through armature 1451 and its working con- 125

130

tact, and the middle lower armature and resting contacts of relay 1415 for relay 1412. Relay 1412 accordingly energizes each time relay 1401 does, and it opens the circuit of reversing relay 1403 each time it energizes. Relay 1402 does not fall back because it is locked by means of its lower winding and inner lower contacts. Each time reversing relay 1403 falls back it reverses the direction of current flow in conductors 1307 and 1308, permitting relay 1306 in the trunk circuit TR2 to fall back and open the circuit of relay 1304. Relay 1304 accordingly follows the opening and closings of the interrupter 1435, Fig. 14, opening the sleeve circuit through the lower winding of relay 1302 each time it falls back. The operator accordingly receives a flashing signal in addition to hearing the busy tone, so that she has both a visual and an audible indication of the busy condition of the called line.

Upon noting the busy condition of the called line, the operator informs the calling subscriber that the line is busy and takes down the connection, bringing about the release of the established connection in a manner to be explained hereinafter. In case the calling subscriber so desires, the operator makes a note of the calling and called numbers and later completes the connection both ways from her position, after the called line has become idle.

Assuming now that the line of substation A5 is idle when called, busy relay 1413 is not energized when the wipers land on the bank contacts of the called line. In this case, when relay 1414 falls back, ground potential from the grounded release-trunk conductor 1438 is applied to the test wiper 1432 by way of the inner upper armature, normal, of relay 1413, the lower winding of switching relay 1415, inner upper armature of relay 1414, and armature 1454. When this ground potential is applied, the upper winding of magnet 207 of the called lineswitch LS4, Fig. 2, is energized through terminal 255, Figs. 14 and 2, and through conductor 205, to disconnect the line winding of line relay 206 by means of the cut-off armature 208 and its contact springs. Relay 1415 in the connector TC3 is energized and it locks itself to conductor 1438 at its inner upper armature; applies ground potential directly to wiper 1432 at armature 1454; connects up the pick-up conductor 1439 at armature 1553; prepares a circuit for the auxiliary ring-off relay 1409 at its middle lower armature; shifts the operating circuit from rotary magnet 1419 to the operating magnet 1423 of the party selector PS2 at its inner lower armature; and at its upper and lower armatures completes the talking connection to the wipers 1431 and 1433.

When the final digit 5 is dialled, five im-

pulses of current are delivered to operating magnet 1423, resulting in this magnet stepping the wiper 1420 into engagement with the fifth one of the associated code-ringing leads. Relays 1414 and 1411 are again energized throughout the digit, and relay 1411 maintains the circuit of relay 1413 open at its lower armature after the off-normal contacts 1421 of the party selector PS2 have closed.

At the end of the digit, when relays 1414 and 1411 have fallen back, relay 1413 is operated through off-normal contacts 1421 and the lower contacts of relay 1411, closing a circuit at its upper armature through contacts of relays 1412 and 1411 for relay 1402. Relay 1402 operates as described hereinbefore in connection with the busy condition of the called line; it locks itself to conductor 1438; and it closes a circuit for relay 1403. As a result, the differential relay 1404 is cut in at the upper and lower armatures of relay 1402, and the current flow over conductors 1307 and 1308 is reversed by the action of relay 1403, bringing about the operation of relays 1306, 1303, and 1304, in the trunk circuit TR2 as above described. By the increase in current flow over the sleeve circuit including the sleeve conductor of the jack J2, the operator is informed by the associated signal in her cord circuit that the line is idle; that connection thereto has been made; and that the connection TC3 is in readiness to apply ringing current as soon as she desires.

It may be pointed out that the toll connector TC3 is arranged so that when the operator is making a tail-to-tail connection from her switchboard to each of the parties of a toll connection, as happens in toll practice when the operator is setting up a previously-ordered toll connection, the connector can be set on the contacts of a calling line which is being recalled, and the calling subscriber is not signalled until the toll operator has extended the connection in the other direction from her switchboard to the called subscriber and has secured a response. If, under this condition, a subscriber on the called line applies ringing current to the line to initiate a call, not knowing that the toll operator has seized the line, the ringing current operates relay 1401 in the connector TC3, which relay closes a circuit through armature 1451 and the middle lower armature, operated, of relay 1415 for relay 1409. Relay 1409 operates and locks itself at its upper armature to conductor 1438, through contacts of relay 1404, and at its lower armature it closes a circuit for relay 1412 by way of the middle lower armature of relay 1408. Relay 1412 opens the circuit of reversing relay 1403, which relay falls back and gives the operator dark supervision. The operator may listen in on

her cord circuit and request the intruding subscriber to replace his receiver for the time being until the toll call is disposed of. Relay 1409 is then deenergized when relay 5 1410 is deenergized to start the ringing operation responsive to the operation of differential relay 1404, to be hereinafter described.

In the call now being described, the connector TC3 is being used to set up a connection to a called line and the operator will, of course, not delay, but will start the ringing operation at once. In order to do this, the operator applies ringing current to the tip and ring conductors of the jack 10 15 J2 of the trunk circuits TR2, Fig. 13, by throwing her ringing key in the usual manner. When this is done, relay 1305 operates and it remains operated throughout the application of ringing current because one section 20 25 of its split core is provided with a shading coil. Relay 1305 applies ground potential to conductor 1307 through contacts of the now-operated relay 1303, unbalancing the current flow over the trunk line comprising conductors 1307 and 1308 sufficiently to bring about the operation of differential relay 1304. Relay 1404 opens the locking circuit of the ring-cut-off relay 1410, whereupon this relay falls back and opens an additional point in its locking circuit at its inner upper contacts, at the same time shifting wipers 1431 and 1433 from in connection with the right-hand repeating-coil windings into connection with the corresponding sections 30 35 of the ringing circuit.

When the application of ringing current made by the operator is terminated, relay 1305 falls back, whereupon differential relay 1404 in the trunk circuit TC3 again operates and prepares the locking circuit for ring-cut-off relay 1410 again.

Upon the next application of ground potential to the pick-up conductor 439 by the common code-ringing device, a circuit is 40 45 closed through armature 1453 and the middle upper armature of ring-cut-off relay 1410 for pick-up relay 1408. Relay 1408 operates and locks itself to conductor 1438 by way of contacts of relay 1404. With relay 1408 operated, ringing current flows 50 55 from the selected ringing lead by way of wiper 1420, contacts of relay 1408, lower winding of relay 1410, and the upper armatures of relays 1410 and 1415 to the called line by way of wipers 1431; and it returns over the other conductor of the called line by way of wiper 1433 and contacts of relays 1415 and 1410 to ground at the lower contacts of relay 1408. Upon each application 60 65 of ringing current to the called line, a small amount of ringing current flows back through the right-hand repeating coil winding by way of the condenser shunted across the upper armature and working contact of relay 1410, to ground by way of the small-

capacity condenser shunted across the working contact and lower armature of relay 1410. The small flow of ringing current in the right-hand repeating coil windings that enables the operator and the calling subscriber to hear a buzzing tone each time an application of ringing current is made to the called line.

When the called subscriber removes his receiver in response to the applications of ringing current corresponding to his assigned code, a path is provided across the two conductors of his line for a flow of direct current, which takes place over the selected ringing lead and through the lower winding of ring-cut off relay 1410. Relay 1410 energizes responsive to the flow of direct current through its lower winding, again locking itself at its inner upper contacts to conductor 1438 through the contacts of relay 1404. Relay 1410 completes the talking circuit at its upper and lower armatures. A circuit is closed at the inner lower armature of relay 1410 for relay 1412, which includes the middle lower armature of the operated relay 1408 and the lower armature of relay 1409. Relay 1412 is accordingly operated to open the circuit of relay 1403, whereupon relay 1403 falls back and reverses the current flow in the trunk line to normal. The polarized relay 1306 falls back and opens the circuit of relay 1304, which falls back and opens the sleeve circuit to give the operator answered supervision.

After the conversation has been carried on and completed, the two subscribers are expected to replace their receivers and "ring off." It will be assumed that the called subscriber rings off first. When he does so, ring-off relay 1401 in the toll connector TC3 is operated by the ringing current received from the called line. Upon operating, relay 1401 closes a circuit through armature 1451 of relay 1413 and through the middle lower armature, operated, of relay 1415 for relay 1409. Relay 1409 operates and locks itself to conductor 1438 through contacts of the differential relay 1404. At its lower armature, relay 1409 opens the circuit of relay 1412. When relay 1412 falls back, it recloses the circuit of reversing relay 1403, whereupon this relay reoperates and again reverses the current flow over conductors 1307 and 1308 to give the operator disconnect supervision, by operating relays 1306 and 1304.

When the calling subscriber in exchange No. 1 (the connection from whose line is set up by way of the selector repeater SR1, Figs. 1 and 12, and over the toll trunk TT) rings off, the selector repeater SR1 applies ground potential to its extra control wiper (EC) and by way of bank contact 1242 to the ringing-current repeater relay 1251 in the ringing-current repeater RR. This

130

ground potential is applied to the above-mentioned wiper of the selector repeater SR1 because the selector repeater is at this time raised to the tenth level, and the shaft 5 springs therein corresponding to shaft springs 327 have been operated to shift the circuit controlled by the ring-off relay, corresponding to relay 307 of the selector repeater SR2, to the (EC) wiper. When relay 1251 operates it projects ringing current over the toll trunk TT, which is repeated through the repeating coil in the trunk circuit TR3 and by way of the tip and ring conductors of the jack J3 to the 10 answering end of the operator's cord circuit, wherein a ring-up relay operates and locks to give the operator both ring-off or disconnect supervision. In case relay 1206 in the trunk circuit TR3 responds to the ringing current, it does not at this time apply ground potential to the upper conductor of the toll trunk TT because relay 1204 is not 15 operated.

Upon receiving disconnect supervision 20 from both parties to the connection, the operator may take down the connection. It is, however, the common practice for a toll operator to listen before taking down a connection, as one of the parties to a conversation, as one of the parties to a conversation, 25 may have hung up before the other party is through talking. In case the called subscriber, to whose line connection was extended by way of the toll connector TC, replaced his receiver and rung off before 30 the calling subscriber was through conversing with him, the calling subscriber removes his receiver after ringing off and converses with the operator when she listens in, requesting her to signal the called subscriber again. She does this by projecting 35 ringing current into the trunk circuit TR2, operating relay 1305 to apply ground potential to conductor 1307 through contacts of relay 1303. This unbalances the current flow in the trunk line extending to the toll connector TC2, resulting in the operation of differential relay 1404. This relay opens the locking circuits of relays 1408, 1409, and 1410. After these relays have fallen back, 40 the operator restores her ringing key, whereupon relay 1305 in the trunk circuit TR2 falls back, permitting relay 1404 in the trunk circuit TR3 to reoperate. Pick-up relay 1408 is again operated over the pick-up conductor 1409 to again close the ringing circuit at its inner lower and lower armatures. The code of the called subscriber is again sent out on his line; and, when he responds, he may again converse with 45 the calling subscriber.

When the conversation has been finally terminated, and the subscribers have again rung off, the operator takes down the connection.

60 When the plug is removed from the jack J3, Fig. 12, ground potential is removed from conductor 1272 at the upper contacts of the jack, but ground potential remains applied to conductor 1273 for the time being 70 at the upper armature of slow-acting relay 1207. Sleeve relay 1203 accordingly remains operated in a circuit for its upper winding from ground on conductor 1273, through the said upper winding, to battery, the middle lower armature of relay 1207 75 and resistance 1213, and maintains the upper conductor of the trunk TT connected to the upper left-hand repeating-coil terminal.

Responsive to the removal of ground potential from conductor 1272, relay 1208 falls back and reverses the connections between the upper and lower conductors of the toll trunk TT and the exchange battery. The ungrounded pole of the exchange battery is now connected to the upper conductor of the toll trunk by way of the resting contact and middle upper armature of relay 1208 and the inner armature of relay 1207, while ground potential is connected to the lower 80 conductor of the trunk line by way of the resting contact and lower armature of relay 1208 and the working contact and inner lower armature of relay 1207. The current flow over the toll trunk TT and consequently in the back bridge selector repeater SR1 is thus reversed back to normal, resulting in the deenergization of the electro-polarized relay therein corresponding to relay 308 in the selector repeater SR2, Fig. 3, resulting 85 in the release of the calling line switch and the selector repeater SR1 in the manner explained hereinbefore in connection with the selector repeater SR2 when it was operated to the tenth level, to extend a connection to the operator's switchboard. 90

Relay 1208 also opens the circuit of slow-acting relay 1207 at its inner upper armature with the result that relay 1207 falls back after a slight interval and disconnects 110 the conductors of the toll trunk TT from the exchange battery and connects them to the polarized relay 1209. Relay 1207 also removes ground potential at its upper armature from conductor 1273 and it removes the battery connection from sleeve relay 1203 at its middle lower armature. When this occurs, sleeve relay 1203 falls back and the busy signal 1201 restores, as does the cut-off relay 1210. The trunk circuit TR3 115 is now in normal condition. 120

When the plug is removed from the jack J2, sleeve relay 1203 and the busy signal 1301 both restore. The restoration of sleeve relay 1302 opens the holding bridge previously closed across conductors 1307 and 1308 by way of polarized relay 1306. When this occurs, line relay 1305 in the toll connector TC3 falls back and opens the circuit of release relay 1406. Relay 1406 falls back 125 130

- after a slight interval and removes ground potential from conductor 1438 at its upper armature, permitting all locked up relays in the connector to restore. The circuit of release magnet 1416 is closed by way of off-normal contacts 1417, and the wipers 1431-1433 are restored to their normal position by the action of the release magnet 1416, whereupon the release magnet circuit is opened at off-normal contacts 1417. The circuit of release magnet 1422 of the party selector PS2 is closed by way of armature 1452 of relay 1413, whereupon release magnet 1422 restores the wiper 1420 to normal. The circuit of relay 1413 is thereupon opened at off-normal contacts 142, whereupon relay 1413 falls back and opens the release-magnet circuit at armature 1452. The toll connector TC3 is now in its normal condition.

What is claimed is:

1. In a combined automatic and semi-automatic telephone exchange, semi-automatic lines terminating in said exchange, automatic lines terminating in said exchange, means including selector switches directly controlled over any calling automatic line responsive to impulses representing the first digit of a desired number for extending a connection to a desired called one of said semi-automatic lines or to a desired one of said automatic lines, means including operator-controlled selector repeaters arranged to respond to impulses transmitted from an operator's switchboard and representing the first digit in a desired number for extending a connection from the calling semi-automatic line to a desired called one of said semi-automatic lines or to a desired called one of said automatic lines, and means including a bank multiple extending between the banks of said selector switches and the banks of said selector repeaters for rendering the switches other than said selector repeaters and selector repeaters and used in extending connections to called lines common to the selectors and selector repeaters.
2. In a combined automatic and semi-automatic exchange, semi-automatic subscribers' lines and automatic subscribers' lines entering said exchange, selectors arranged to be operated over automatic lines in accordance with the first digits of desired numbers, selector repeaters arranged to be operated from an operator's switchboard in accordance with the first digits of desired numbers to extend connections from said semi-automatic lines, and other automatic switches directly accessible in common to said selectors and selector repeaters.
3. In a combined automatic and semi-automatic exchange, selectors arranged to be operated over automatic lines in accordance with the respective first digits of desired numbers, selector repeaters arranged to be

operated from an operator's switchboard in accordance with the respective first digits of desired numbers to extend connections from semi-automatic lines, other automatic switches directly accessible in common to said selectors and said selector repeaters, and still other automatic switches accessible from said selector repeaters and inaccessible from said selectors.

4. In a combined automatic and semi-automatic exchange, selectors arranged to be operated over automatic lines in accordance with the respective first digits of desired numbers, selector repeaters arranged to be operated from an operator's switchboard in accordance with the respective first digits of desired numbers to extend connections from semi-automatic lines, other automatic switches directly accessible in common to said selectors and said selector repeaters, an operator's switchboard, and trunk lines extending to said switchboard and accessible from said selector repeaters but inaccessible from said selectors.

5. In a telephone system, a telephone exchange, subscribers' lines entering said exchange, said subscribers' lines being normally free from connections to current sources at said telephone exchange, means for setting up a telephone connection to any desired one of said lines, a source of ringing current and a source of direct current at the exchange, means effective when a connection is set up to a called one of said lines for starting a ringing operation consisting in the intermittent application of current from said ringing-current source to the line and for applying said direct-current source to the line, means responsive to the removal of the receiver on the called line for setting up a current flow over the called line from the said direct-current source in the exchange, and means responsive to said flow of direct current for terminating the ringing operation and for disconnecting the direct-current source from the line so as to maintain the called line free from connection to any direct-current source in the exchange during conversation.

6. In a telephone system, a telephone exchange, subscribers' lines entering said exchange, said subscribers' lines being normally free from connections to current sources at said telephone exchange, means for setting up a telephone connection to any desired one of said lines, a source of ringing current and a source of direct current at the exchange, means effective when a connection is set up to a called one of said lines for starting a ringing operation consisting in the intermittent application of current from said ringing-current source to the line and for applying said direct-current source to the line, means responsive to the removal of the receiver on the called line for setting

- up a current flow over the called line from the said direct-current source in the exchange, means responsive to said flow of direct current for terminating the ringing 5 operation and for disconnecting the direct-current source from the line so as to maintain the called line free from connection to any direct-current source in the exchange during conversation, means on the called 10 line for projecting ringing current over the called line to the exchange, and means in the exchange responsive to said ringing current for breaking down the talking connection set up to the called line.
- 15 7. In a telephone system, subscribers' lines terminating in a telephone exchange, an automatic switch having access to said subscribers' lines, a trunk line incoming to said automatic switch, means for extending a 20 connection from a calling line to said automatic switch by way of said trunk line and for controlling said automatic switch over said trunk line to set up a connection to a desired called one of the lines accessible to 25 said switch, means in said switch for applying ringing current to the called line to signal the subscriber thereon, a source of direct current in the exchange, means responsive to the removal of the receiver on the called 30 line for setting up a current flow over the called line from said current source in the exchange, means responsive to said current flow for setting up a supervisory condition in the trunk line incoming to said connector 35 to give answered supervision in the direction of the calling line, and means for maintaining said supervisory condition on the said incoming trunk line independent of further current flow over the called line.
- 40 8. In a telephone system, subscribers' lines terminating in a telephone exchange, an automatic switch having access to said subscribers' lines, a trunk line incoming to said automatic switch, means for extending 45 a connection from a calling line to said automatic switch by way of said trunk line and for controlling said automatic switch over said trunk line to set up a connection to a desired called one of the lines accessible 50 to said switch, means in said switch for applying ringing current to the called line to signal the subscriber thereon, a source of direct current in the exchange, means responsive to the removal of the receiver on the called 55 line for setting up a flow of direct current over the called line from the current source at the exchange, means responsive to said current flow for setting up a supervisory condition in the incoming trunk of the 60 switch to indicate that the called subscriber has answered, and means also responsive to said current flow for disconnecting said source of direct current from the called line to terminate the current flow thereover and 65 for maintaining the established supervisory condition in said trunk line after the current flow over the called line has ceased.
9. In a telephone system, subscribers' lines terminating in a telephone exchange, an 70 automatic switch having access to said subscribers' lines, a trunk line incoming to said automatic switch, means for extending a connection from a calling line to said automatic switch by way of said trunk line and for controlling said automatic switch over 75 said trunk line to set up a connection to a desired called one of the lines accessible to said switch, means in said switch for applying ringing current to the called line to signal the subscriber thereon, a source of direct current in the exchange, means responsive to 80 said current flow for setting up a supervisory condition in the incoming trunk of the switch to indicate that the called subscriber has answered, means also responsive to said current flow for disconnecting said source of direct current from the called line to terminate the current flow thereover and for maintaining the established supervisory condition in said trunk line after the current flow over the called line has ceased, and means under the control of the subscriber on the called line for destroying the established supervisory condition in said trunk line to indicate that the conversation has been terminated.
- 100 10. In a telephone exchange system, lines entering a telephone exchange, means in the telephone exchange for setting up a connection from a calling one of said lines to a desired called one of said lines, sources of direct current and alternating current in said exchange, means including a ringing lead common to said connecting means and other similar connecting means for intermittently applying alternating current only to the called line to signal the subscriber thereon and for alternately applying a direct-current source to said line over said lead in place of alternating current, means responsive to the removal of the receiver on the called line for setting up a flow of direct current over the called line from the said direct-current source, and means responsive to the flow of direct current over the called line for preventing further application of alternating current to the called line.
- 105 11. In a telephone exchange system, lines entering a telephone exchange, means in the telephone exchange for setting up a connection from a calling one of said lines to a desired called one of said lines, sources of direct current and of alternating current in said exchange, means for applying alternating current to the called line to signal the subscriber thereon and for applying said 110 115 120 125 130

- direct-current source to said line, means responsive to the said removal of the receiver on the called line for setting up a flow of direct current over the called line from the 5 said direct-current source, and means responsive to the flow of direct current over the called line for preventing further application of alternating current to the called line and for terminating the flow of direct 10 current over the called line.
12. In a telephone-exchange system, means for setting up a telephone connection to a called subscriber's line, a ringing lead included in said connection, a direct-current 15 source and a ringing-current source, means for connecting said lead to the two sources alternately, the ringing-current source being effective to project ringing-current over the called line to signal the subscriber there- 20 on when the ringing-current source is connected to the lead, means responsive to the removal of the receiver on the called line for setting up a current flow over the called line from said direct-current source by way 25 of said ringing lead, and means connected between said lead and the called line and responsive to said current flow for disconnecting said ringing lead from the established connection.
- 30 13. In a telephone system, an automatic switch having access to a group of local-battery semi-automatic telephone lines, an operator's switchboard, means for controlling said automatic switch from said operator's switchboard to set up a connection to any one of said lines, means associated with said automatic switch for automatically and intermittently applying ringing current to the called semi-automatic line, and means in 35 40 said automatic switch automatically responsive to the removal of the receiver on the called line for terminating the ringing operation.
14. In a telephone system, an exchange 45 serving as the terminus for common-battery automatic telephone lines and as the terminus for local-battery semi-automatic telephone lines, a group of connector switches having access to the common-battery auto- 50 matic lines, a group of connector switches having access to the local-battery semi-automatic lines, a third group of switches having common access to both of the first-mentioned groups of switches, and means effec- 55 tive when a connection is set up through one of the switches of the third group to a called local-battery semi-automatic line by way of one of the switches of the second group for giving answering supervision of the same 60 kind given when a call is set up by way of one of the switches of the third group to a called common-battery automatic line through the medium of one of the switches of the first group.
- 65 15. In a semi-automatic telephone system,
- an operator's switchboard, an automatic switch arranged to be controlled from the operator's switchboard to extend a connection from a calling semi-automatic line, means including a current source on the calling line for setting up a current flow over the two conductors of the calling line in series and through said automatic switch, means responsive to the receiver being replaced on the calling line for terminating 70 75 said current flow, and means in said automatic switch responsive to the termination of said current flow for restoring the automatic switch.
16. In a telephone system, a subscriber's 80 line, means including an automatic switch for setting up a connection to said subscriber's line and for signalling the subscriber thereon, a current source on the line, means responsive to the removal of the receiver of the called line for setting up a current flow over the line from the current source thereon, and responsive to the receiver being replaced for terminating said current flow, and means responsive to said 85 current flow being terminated for releasing 90 said automatic switch.
17. In a telephone system, a group of subscribers' lines, means for setting up a telephone connection from any calling one of said lines through the medium of a train of automatic switches, means including a current source on the calling line for maintaining a current flow over the calling line during conversation, means for terminating said current flow when the receiver is replaced on the calling line, and means responsive to said current flow being terminated for releasing said automatic switches. 95
18. In a telephone system, a calling line, a current source connected in series with the talking bridge on the calling line whereby it is connected to the calling line when the receiver is removed, means including automatic switching apparatus for setting up a connection from said calling line, and means responsive to the receiver being replaced on the calling line and the consequent disconnection of said current source for releasing said automatic switching mechanism. 100 105 110
19. In a telephone system, a calling line, means including an automatic switch for extending a connection from said calling line, a battery on said calling line arranged to energize the transmitter at the calling substation, and circuit connections and apparatus responsive to said transmitter battery on the calling line for releasing said automatic switch when the receiver is replaced on the calling line. 115 120 125
20. In a semi-automatic telephone system, operator-controlled automatic switches arranged to set up connections between subscribers' lines, said switches arranged to be released at the end of a conversation re- 130

sponsive to an application of ringing current made over a calling line from a hand generator thereon, and means including a source of direct current on each of certain ones of said lines for automatically releasing said automatic switches responsive to the receiver being replaced at the end of the conversation.

21. In a telephone system, subscribers' lines, numerical switches arranged to extend any one of said lines, a source of direct current on each line, means responsive to the removal of the receiver on a calling line for setting up a current-flow thereover from the source of direct current on the line, a group of non-numerical switches arranged to extend any calling line to one of said numerical switches, means responsive to the said current-flow over a calling line for operating one of said non-numerical switches to extend the calling line to one of said numerical switches, a release-control relay in the numerical switch and arranged to be energized by the current-flow over the calling line, means for operating the numerical switch to extend the calling line, and means responsive to the deenergization of said release-control relay when the receiver is replaced on the calling line for releasing said numerical switch.

22. In a telephone system, a group of subscribers' lines, a group of plunger lineswitches terminating said subscribers' lines respectively, trunk lines accessible to said plunger lineswitches, a master switch arranged to operate the lineswitches to select idle ones of the trunk lines accessible thereto, a line relay in each of said lineswitches operable over the associated line, means responsive to the operation of a line relay over the associated line for operating the corresponding plunger lineswitch to seize an idle trunk, means effective when the lineswitch operates for disconnecting the line relay from the incoming line and for closing the locking circuit for the line relay under the control of the master switch, and means controlled by said master switch when it operates to select another trunk for opening said locking circuit to permit the operated line relay to restore.

23. In a telephone exchange system, a group of semi-automatic lines, a group of automatic switches common to said lines and arranged to extend any one of them under the control of an operator, automatic switching apparatus arranged to extend any calling one of said lines to one of said automatic switches, automatic switching apparatus arranged to connect the telephone of the controlling operator with any one of said automatic switches, means responsive to a calling line being extended to any one of said automatic switches for setting the last-named switching apparatus into operation

to connect the automatic switch with the operator's telephone and for sending a tone signal back over the calling line to inform the calling subscriber that the exchange equipment is functioning to connect his line with the operator's telephone, and means effective upon the final completion of the connection between the calling line and the operator's telephone for discontinuing the tone signal.

24. In a telephone system, a group of semi-automatic lines, numerical switches arranged to be operated under the control of an operator in accordance with desired numbers to extend said semi-automatic lines, non-numerical switching devices arranged to make connection between calling ones of said semi-automatic lines and said numerical switches, register senders arranged to be controlled by the semi-automatic operator in accordance with desired numbers and to control said numerical switches in turn, non-numerical switches arranged to connect any one of said register senders with any one of said numerical switches, automatic switching apparatus arranged to connect the telephone of the semi-automatic operator with any one of said register senders, means effective upon the extension of a calling line to one of said numerical switches through an associated one of the non-numerical switches for sending back a tone to the calling line from the numerical switch to inform the calling semi-automatic subscriber that the exchange apparatus is functioning to extend his line to the operator's telephone, means effective to operate a non-numerical switch of the second-mentioned group to effect a connection between the seized numerical switch and an idle one of the register senders, means effective upon the completion of this connection for discontinuing the sending back of the tone signal from the numerical switch and for thereupon sending the tone signal back from the register sender, means for operating the automatic switching apparatus to connect the seized register sender with the operator's telephone, and means thereupon effective for discontinuing the sending back of the tone signal from the register sender.

25. In a semi-automatic telephone system wherein a connection is extended from a calling semi-automatic line to an automatic switch, is then extended from the automatic switch to a register sender, and is finally extended from the register sender to the telephone of the semi-automatic operator; means effective upon the calling line being extended to an automatic switch for sending back a tone signal to the calling line from the automatic switch, means effective upon the connection being extended to a register sender for discontinuing the application of the signal from the automatic

switch and for continuing it from the register sender, and means effective upon the connection being extended finally from the register sender to the operator's telephone for discontinuing the sending back of the tone signal from the register sender.

26. In a semi-automatic telephone system, subscribers' lines each provided with a hand generator for signalling the semi-automatic operator and for releasing the automatic switches at the end of a conversation, the arrangement being such that a subscriber may initiate a call at a time when his line is included in an established connection with another line which has not been released or his line may be free from a connection with another line, the arrangement being further such that an application of signalling current from the hand generator on the calling line in the first case results merely in the release of the set-up connection and in the second case results in the signalling of the semi-automatic operator, and means responsive to the operation of the hand generator for giving the calling subscriber a characteristic signal after he has operated his hand generator and only in case the operation of the hand generator has started operations which will eventually result in signalling the semi-automatic operator.

27. In an impulse sender arranged to transmit a plurality of series of impulses, variably adjustable registers associated with said sender and arranged to be adjusted to predetermine the number of impulses in the respective series, a control circuit outgoing from said sender, a local counting circuit, means for sending impulses over said outgoing circuit and for sending impulses in said local counting circuit at the same time, means dependent upon the number of impulses for which the associated register is adjusted for stopping the transmission of impulses over said outgoing control circuit, while permitting the transmission of further impulses over said local counting circuit, and means dependent upon the transmission of a predetermined number of additional impulses over said counting circuit for again starting the transmission of impulses over said outgoing circuit.

28. In combination, a group of counting relays, a plurality of variably adjustable registers, an outgoing impulse circuit, means for sending impulses over said outgoing impulse circuit and for sending impulses at the same time to said counting relays, means dependent upon the adjustment of the first of said registers for stopping the transmission of impulses over said outgoing control circuit at a variable point, while permitting the transmission of impulses to said counting relays to continue, means responsive to the operation of a predetermined number of said counting relays after the transmission

of impulses over the outgoing impulse circuit has been terminated for again starting the transmission of impulses over said outgoing circuit, and means for making the number of impulses transmitted thereafter over said outgoing impulse circuit before the transmission is again stopped dependent upon the adjustment of the second register.

29. In an impulse sending and counting device, an impulse sender, a group of impulse counting relays, a group of digit conductors, a digit stop relay, and a group of digit-spacing counting relays; means for operating said impulse sender to send impulses and for at the same time operating the impulse counting relays successively to connect up the digit stop conductors successively to said stop relay, means responsive to a prepared one of said digit stop conductors being connected to said stop relay for operating said stop relay to terminate the said transmission of impulses and for starting the operation of said digit-spacing relays, means for operating said digit-spacing relays successively to count the further impulses, and means responsive to the operation of the last of said digit-spacing relays for again starting the said transmission of impulses.

30. In combination, a sender comprising a group of successively operable impulse-counting relays, a digit-stop relay, and a group of successively operable digit-spacing relays; variably adjustable registering apparatus, means for operating said sender to transmit impulses therefrom and to operate said impulse-counting relays successively, means dependent upon the adjustment of the said registering apparatus for operating said stop relay responsive to the operation of any one of said impulse-counting relays, means controlled by said stop for terminating the transmission of impulses from said sender and for starting the transmission of impulses to said spacing relays, and means responsive to the successive operation of all of said spacing relays for again starting the transmission of impulses from said sender.

31. In an impulse sender, a group of successively operable impulse counting relays, a stop relay, and a group of successively operable digit-spacing relays; means for transmitting impulses to said impulse counting relays to operate them successively, means for operating said impulse-stop relay responsive to the operation of any one of said impulse-counting relays, and means controlled by said stop relay for disassociating said impulse-transmitting means from said impulse-counting relays and for associating it with said digit-spacing relays to operate them successively.

32. In an impulse sender, three impulse-generating relays, means including contacts

- on said relays for causing said relays to operate successively and to fall back successively following the operation of the third one of them, contacts on one of said relays
- 5 for transmitting the impulses out from said sender, contacts on another of said relays for transmitting impulses in a local counting circuit, and means controlled over said local counting circuit for counting impulses
- 10 transmitted out from said sender.
33. In an impulse-generating and counting device for use in connection with variably-adjustable registers, a group of impulse-counting relays, an impulse conductor, means for sending impulses over said conductor to operate said counting relays successively, a stop relay, circuit arrangements controlled by said impulse-counting relays for operating said stop relay at a point in
- 15 the operation of the counting relays depending upon the adjustment of the associated registering apparatus, a group of digit-spacing counting relays, and means responsive to the operation of said stop relay for shifting said impulse conductor from said impulse-counting relays to said digit-spacing relays.
34. In an impulse-generating and counting device for use in connection with variably-adjustable registers, a group of impulse-counting relays, an impulse conductor, means for sending impulses over said conductor to operate said counting relay successively, a stop relay, circuit arrangements controlled by said impulse-counting relays for operating said stop relay at a point in the operation of the counting relays depending upon the adjustment of the associated registering apparatus, a group of digit-spacing counting relays, means responsive to the operation of said stop relay for shifting said impulse conductor from said impulse-counting relays to said digit-spacing relays, a locking conductor for locking the operated
- 40 impulse-counting relays, a locking conductor for locking the digit-spacing relays, a source of locking potential, and means including contacts on said stop relay for transferring said source of locking potential from the
- 45 first locking conductor to the second locking conductor when the stop relay operates.
35. In an impulse-generating and counting device for use in connection with variably-adjustable registers, a group of impulse-counting relays, an impulse conductor, means for sending impulses over said conductor to operate said counting relays successively, a stop relay, circuit arrangements controlled by said impulse-counting
- 50 relays for operating said stop relay at a point in the operation of the counting relays depending upon the adjustment of the associated registering apparatus, a group of digit-spacing counting relays, means responsive to the operation of said stop relay
- for shifting said impulse conductor from said impulse-counting relays to said digit-spacing relays, a locking conductor for locking the operated impulse-counting relays, a locking conductor for locking the digit-spacing relays, a source of locking potential, means including contacts on said stop relay for transferring said source of locking potential from the first locking conductor to the second locking conductor when the stop relay operates, and contacts on the last of said digit-spacing relays to be operated for bringing about the deenergization of said stop relay.
36. In a register sender, a group of impulse-counting relays, a group of digit-spacing relays, a stop relay, and locking conductors for the said two groups of relays arranged to be energized alternately under the control of said stop relay.
37. In a register sender, a group of impulse-counting relays, a group of digit-spacing relays, a stop relay, locking conductors for the said two groups of relays arranged to be energized alternately under the control of said stop relay, and a circuit for said stop relay controlled jointly by the said two groups of relays.
38. In a telephone system, an automatic switch arranged to set up telephone connections through control conductors incoming to said switch, means for operating said switch over said control conductors in series, a double-wound differential relay associated with said control conductors but normally excluded therefrom, and means effective after said automatic switch has been positioned responsive to control exercised over said conductors for inserting the two windings of said differential relay in series with said control conductors respectively.
39. In a telephone system, an automatic switch arranged to extend a connection to telephone lines including party lines, said automatic switch having an incoming control conductor over which the switch is controlled, a party-selecting device associated with said automatic switch and arranged to select the desired party on a called party line, means for operating said party selector over said incoming control conductor after the automatic switch has been positioned, and means effective responsive to the setting of said party selector for reversing the current flow over said incoming conductor.
40. In a telephone system, a toll connector arranged to be controlled over a trunk line extending from a toll board, said toll connector having access to party lines, a party-selecting device, means for setting said toll connector on any one of said party lines and for thereafter operating said party-selecting device, means effective in case the called line is busy for reversing the direc-

tion of current flow in said trunk line upon the switching being set upon the busy line, and means effective in case the called line is idle for delaying the said reversal of current flow until the party-selecting device has been operated.

41. In a telephone system wherein automatic switches are controlled from an operator's switchboard to set up connections to called lines, trunk lines extending from said switchboard to said automatic switching apparatus over which the control is exercised, means effective upon the completion of the necessary control for automatically reversing the current flow over the trunk line in use, and means automatically effective when the called subscriber responds for again reversing the current flow in the trunk line in use back to normal direction.

42. In a telephone system wherein automatic switches are controlled from an operator's switchboard to set up connections to called lines, trunk lines extending from said switchboard to said automatic switching apparatus over which the control is exercised, means effective upon the completion of the necessary control for automatically reversing the current flow over the trunk line in use, means automatically effective when the called subscriber responds for again reversing the current flow in the trunk line in use back to normal direction, and means controlled by the called subscriber and effective when he has finished his conversation for again reversing the current flow in the trunk line in use to give the operator disconnect supervision.

43. In a telephone system, an automatic switch arranged to be controlled over a trunk line extending thereto from an operator's switchboard to set up connections to called lines, a relay in said automatic switch arranged to be operated by ringing current transmitted thereto from a hand generator on the called line to give the operator disconnect supervision, and means effective in case the called line is busy for intermittently operating said relay from a local current source in order to give the operator a flashing supervision to denote the busy condition.

44. In a telephone system, a connector switch arranged to extend connections to subscribers' lines including party lines, a party-selecting device associated with said connector switch, means for transmitting digits to said connector switch to position the same on a line and to position said party-selecting device, a relay and means for operating it responsive to the termination of the last digit, a supervisory device, and means for operating said supervisory device responsive to the operation of said relay.

45. In a telephone system, an automatic switch arranged to be positioned on a sub-

scriber's line to make connection therewith in response to series of impulses transmitted thereto, a relay in said automatic switch and means for operating it responsive to the cessation of the last series of transmitted impulses, means for signalling the subscriber on the connected line, a second relay in said automatic switch and means for operating it when the called subscriber replies, a supervisory device, and circuit arrangements controlled by said relays jointly for operating said supervisory device.

46. In a telephone system, an automatic switch arranged to be set on the terminals of a called line, ringing apparatus common to said automatic switch and to other similar automatic switches, a pick-up relay in said automatic switch, means for operating said pick-up relay from said common ringing apparatus to start the application of ringing current to the called line, a ring-cut-off relay and means for operating it over the called line responsive to the removal of the receiver on the called line, a supervisory device, and a circuit for said supervisory device controlled by said relays jointly.

47. In a telephone system, an automatic switch having conductors incoming thereto, said switch being arranged to be controlled over said incoming conductors to set itself on the terminals of a called line, a ring-cut-off relay, means for operating said ring-cut-off relay incidental to the setting of said automatic switch, means responsive to an additional control over the said incoming conductors for deenergizing said ring-cut-off relay, a pick-up relay in said automatic switch and means for operating it from ringing apparatus common to said automatic switch and to other similar switches, and a circuit for said relay over which the said operation thereof is brought about, said circuit including contacts closed by said ring-cut-off relay when it deenergizes.

48. In a telephone system, an automatic switch having conductors incoming thereto, said switch arranged to be controlled over said incoming conductors to set itself on the terminals of a called line, a ring-cut-off relay, means for operating said ring-cut-off relay incidental to the setting of said automatic switch, means responsive to an additional control over the said incoming conductors for deenergizing said ring-cut-off relay, a pick-up relay in said automatic switch and means for operating it from ringing apparatus common to said automatic switch and to other similar switches, a circuit for said relay over which the said operation thereof is brought about, said circuit including contacts of said ring-cut-off relay, and a ringing circuit controlled by said relays jointly for supplying ringing current to the called line.

49. In a telephone system, an automatic switch having conductors incoming thereto, said switch arranged to be controlled over said incoming conductors to set itself on the terminals of a called line, a ring-cut-off relay, means for operating said ring-cut-off relay incidental to the setting of said automatic switch, means responsive to an additional control over the said incoming conductors for deenergizing said ring-cut-off relay, a pick-up relay in said automatic switch and means for operating it from ringing apparatus common to said automatic switch and to other similar switches, a circuit for said relay over which the said operation thereof is brought about, said circuit including contacts of said ring-cut-off relay, a supervisory device, and an operating circuit for said device controlled by said relays jointly.
50. In a telephone system, an automatic switch, talking conductors incoming to said switch and arranged to be extended thereby, means for operating said switch in accordance with a digit in a telephone number to extend said incoming talking conductors, a relay bridged across said incoming talking conductors and arranged to be operated by ringing current to bring about the release of said automatic switch, and means depending upon the value of the digit used to operate said switch for disconnecting said relay from in bridge of the incoming talking conductors.
51. In a telephone system, an automatic switch arranged to extend connections from subscribers' lines, a ring-back switch arranged to send ringing current back to a calling party-line to signal a called party on the same line with the calling party, means for operating said automatic switch to extend a connection toward a called line or to extend a connection to said ring-back switch, a release-control relay bridged across the incoming talking conductors of said switch and arranged to be operated by ringing current applied to the talking conductors of said switch from a calling line, and means effective when said switch is used to extend a connection to said ring-back switch for disconnecting said release-control relay from in bridge of the incoming talking conductors to prevent it from operating responsive to ringing current sent back to the calling line from the ring-back switch.
52. In a telephone system, an automatic switch arranged to extend connections from subscribers' lines, a ring-back switch arranged to send ringing current back to a calling party-line to signal a called party on the same line with the calling party, means for operating said automatic switch to extend a connection toward a called line or to extend a connection to said ring-back switch, a release-control relay bridged across the incoming talking conductors of said switch and arranged to be operated by ringing current applied to the talking conductors of said switch from a calling line, means effective when said switch is used to extend a connection to said ring-back switch for disconnecting said release-control relay from in bridge of the incoming talking conductors to prevent it from operating responsive to ringing current sent back to the calling line from the ring-back switch and means including an automatic switch having conductors incoming thereto, said switch arranged to be controlled over said incoming conductors to set itself on the terminals of a called line, a ring-cut-off relay, means for operating said ring-cut-off relay incidental to the setting of said automatic switch, means responsive to an additional control over the said incoming conductors for deenergizing said ring-cut-off relay, a pick-up relay in said automatic switch and means for operating it from ringing apparatus common to said automatic switch and to other similar switches, a circuit for said relay over which the said operation thereof is brought about, said circuit including contacts of said ring-cut-off relay, a supervisory device, and an operating circuit for said device controlled by said relays jointly.
53. In a telephone system a ring-back switch having talking conductors incoming thereto, said switch being arranged to be operated over said talking conductors to send ringing current back to a calling party line to signal the called party on the calling line, there being two digits transmitted to said ring-back switch, and means associated with said ring-back switch for absorbing or cancelling the first digit and for thereby preparing the ring-back switch to respond to the second digit.
54. In a telephone system, an automatic switch arranged to be operated to extend a calling telephone line toward a called telephone line, means normally effective when a connection has been set up through said switch from a calling line to a called line for exercising a control over said switch from either line to bring about its release, and means effective when said switch is set in a different position to connect with a line in a different group for preventing the release of said switch responsive to control exercised from the calling line.
55. In a telephone system, an automatic switch arranged to be operated to extend a calling telephone line toward a called telephone line, means normally effective when a connection has been set up through said switch from a calling line to a called line for exercising a control over said switch from either line to bring about its release, means effective when said switch is set in a different position to connect with a line in a different group for preventing the release of said switch responsive to control exercised from the calling line, and means effective in the last-named case for signalling the called subscriber responsive to the said control from the calling line.
56. In a telephone system, lines of two classes, means including an automatic switch for setting up a connection from a calling line to a line of either class, means on the calling line effective after the connection has been established for sending ringing current to said automatic switch, means responsive to said ringing current and

effective in case the called lines is of one class for releasing said automatic switch, and means effective when the connection is set up to a called line of the other class for signalling the party on the called line responsive to the application of ringing current from the calling line instead of releasing said automatic switch.

57. In a telephone system, subscribers' lines, an operator's switchboard, an automatic switch, means for setting up a connection from a calling subscriber's line by way of said automatic switch to a called subscriber's line, means for setting up a connection 10 from a calling line by way of said automatic switch to said operator's switchboard, a relay in said automatic switch responsive in either case to an application of ringing current from the calling subscriber's line, 15 means responsive to the operation of said relay in case the connection is set up to a called subscriber's line for releasing said automatic switch, and means responsive to the operation of said relay when the connection is set up to said operator's switchboard for relaying ringing current to said operator's switchboard instead of releasing said automatic switch.

58. In a telephone system wherein connections are set up through automatic switches from a calling line to a called line through a trunk line interconnecting a first automatic switch with a second automatic switch, means automatically controlled from the called line for reversing the current flow in said trunk line when the called subscriber replies, means effective when the calling subscriber replaces his receiver and sends ringing current to the exchange over his line for automatically releasing the established connection, means controlled from the called line in case the called subscriber replaces his receiver first for reversing the current flow in said trunk line back to normal, and 10 means responsive to said reversal of current flow back to normal for releasing said automatic switches.

59. In an automatic telephone system, means including a selector and a connector for setting up a telephone connection from a calling line to a called line, a relay in said selector responsive to ringing current applied from the calling line, a relay in said connector responsive to ringing current applied from the called line, and means responsive to an operation of either of said relays responsive to ringing current for releasing both of said automatic switches.

60. In a telephone system, a trunk line 10 extending from a manual switchboard in one exchange to an automatic switchboard in another exchange, automatic switching apparatus at said automatic switchboard, manual switching apparatus at said manual switchboard, means for extending a con-

nection to said trunk line at said automatic switchboard and for signalling the operator, means including said manual switching apparatus at the manual switchboard for making a connection therewith said trunk line, two alternative bridges for said trunk line at the manual switchboard, one of said bridges being a holding bridge arranged to be placed across said trunk line to permit current to flow therethrough from the two 15 conductors of the line in series to maintain the automatic switching apparatus operated when a connection is being set up through the automatic switching apparatus from the manual switchboard, the other bridge being 20 a battery-feed bridge arranged to supply current over the trunk line to the automatic switching apparatus for supervisory purposes, and means automatically effective when the operator makes a connection with 25 said trunk line and depending upon whether a connection has previously been made to a said trunk line at the automatic switchboard for placing the proper one of said two bridges across said trunk line.

In witness whereof, I hereunto subscribe my name this 3rd day of January, A. D. 1931.

EDWARD S. PETERSON.
